UNITED STATES PATENT OFFICE.

ERNEST J. ANTONI, OF KANSAS CITY, MISSOURI.

MATTRESS-FILLING MACHINE.

No. 867,936.

Specification of Letters Patent.

Patented Oct. 15, 1907.

Application filed June 5, 1906. Serial No. 320,234.

To all whom it may concern:

Be it known that I, ERNEST J. ANTONI, a citizen of the United States of America, residing at Kansas City, in the county of Jackson and State of Missouri, have 5 invented certain new and useful Improvements in Mattress-Filling Machines; and I do hereby declare that the following is a full, clear, and exact description of the invention, such as will enable others to make and use the same, reference being had to the accompanying 10 drawings, forming a part of this specification.

The principal objects of the invention are—First—the transmission of the mattress filling material to the machine from separate sources of the fine and coarse material. Second—the automatic spreading of the 15 mattress filling material in the mattress filling receptacle. Third—the self feeding of layers of fibrous material forming part of the mattress filling and the automatic separation of the layers into proper lengths. Fourth—the adaptation of the feeding mechanism for 20 the layers to the width of the compressing means for the mattress filling material. Fifth—the consecutive automatic movements of the separate operative parts of the machine for producing the various operations of mattress filling.

25 The invention consists in the novel construction and combination of parts such as will be first fully described and then specifically pointed out in the claims.

In the drawings—Figure 1 is a side view in elevation of the improved mattress filling machine. Fig. 2 is an 30 enlarged side view of the machine with the cotton layer supporting and feeding and cutting mechanism and the traveling mattress supporting table upon the forward ends of the machine removed. Fig. 3 is a plan view of the machine as seen in Fig. 2. Fig. 4 is a longitudinal 35 vertical sectional view of the machine taken upon the line xz on Fig. 3. Fig. 5 is an enlarged view in elevation of the forward portion of the machine taken in rear of the vertical line yy on Fig. 1. Fig. 6 is an enlarged detail broken view showing a portion of one of the forward 40 corner posts the slotted guide plate and a portion of the gate supporting bar within the guide plate as seen in Fig. 5, also showing a portion of the rack bar and one of the cog wheels for equalizing the vertical movement of the gate, the vertically movable bar when the gate 45 is in a lowered position and the gate releasing trip lever. Fig. 7 is an enlarged rear end view in elevation of the machine taken forward of the vertical line zz on Fig. 1 showing the material conveyors. Fig. 8 is a detail isometric view of one of the lower carriages with the 50 side and also the track wheels and knee plates removed, and the mattress material supporting plates and portions of the side channel beams of the carriage broken away to show the construction. Fig. 9 is a vertical sectional view of one of the material compressing sides to one of the carriages showing the brace bar and the 55 rack, the vertical shaft and cog wheels for removing the sides laterally in position. Fig. 10 is an isometric view of the cover grasping devices on the longitudinal side or channel beams on the lower carriages showing a portion of the guide rail secured to the channel beam 60 with which the cover grasping devices are movably connected. Fig. 11 is a detail plan view of a portion of the triple chain operating the sprocket wheels on the carriages. Fig. 12 is an enlarged isometric detail broken view of the lower forward portion of the machine 65 showing one of the centrally located standards, the lower carriages and track rails and the inwardly movable vertical sides forming the receptacle for the mattress filling material, also showing the lower telescoping plates in the bottom of the receptacle, a portion of the 70 plates being broken away to show the power actuated rollers upon the carriages supporting the plates also showing the racks for drawing the cover over the plates, the adjustable lower end of the cotton layer supporting pan or table and a portion of the layer holding and drawing mechanism within the receptacle, the mechanism for drawing the carriages toward each other and the chains for operating the carriages and rack bars, also a portion of the upper rack rail for the upper carriage and the weighted check bar and the reversing lever on the 75 standard for the lower carriages. Fig. 13 is an enlarged detail view of the carriage reversing trip lever on the standard as seen in Fig. 11. Fig. 14 is a detail isometric view of the movable board on the forward end of the main frame of the machine, showing a portion of the 80 lower end of one of the corner posts, the anti friction guide box and the spring controlled hook and the chain actuated by the bar forming part of the gate. Fig. 15 is a detail view of a portion of the side of the receptacle on the lower carriages taken from the outer 85 side of the receptacle and showing a portion of the rack bar and the devices actuated by the bar for moving the sides of the receptacle outwardly and inwardly. Fig. 16 is a detail view of an end portion of the side of the receptacle on the lower carriage reversed in position to 90 that seen in Fig. 1 and taken from the inner side of the receptacle adjacent to its forward end showing the hinged mattress cover holding device in an open position, the spring controlled catch, the spring controlled securing plate for the upper end of the plate, also showing the auxiliary plate for entering the mattress cover 95 hinged to the main plate, the pivoted locking bar with which the catch on the main plate is connected, the releasing bar for the locking bar and the stops on the inner surface of the side of the receptacle in the path of the 100 releasing bar. Fig. 17 is a view of the mattress cover holding device in an upright or closed position. Fig. 18 is an enlarged detail view of the pivoted locking bar 105

as seen in Fig. 15. Fig. 19 is a detail isometric view enlarged of the hook on the rear end of the lower carriages for drawing forward the rack bars showing a broken portion of the connecting bar to the rack bars and the yielding portions of the hook upon the upper surface of the connecting bar in the position when released by the action of the rod on the side closing rack bar. Fig. 20 is an enlarged isometric detail view of the cotton layer drawing devices on the sides of the receptacle for the material showing the cotton layer engaging devices on the receptacle also showing a broken portion of one of the sides to the receptacle and the movable locking bar on said sides. Fig. 21 is a detail isometric view of one of the locking or yoke bars for the lower carriages on the inner surfaces of the centrally located standards for holding the lower carriages from movement during the operation of drawing the cotton layers within the receptacle and the mattress cover over the material compressing plates showing the releasing devices for the bar. Fig. 22 is an enlarged isometrical detail broken view of the lower rear end portion of the machine showing the rear corner posts and standard, the main operating shaft, the rotary shafts and chains operating respectively the cotton layer grasping mechanism and rack bars and for communicating a forward and rearward movement to the lower carriages, also showing the automatically operated clutches and levers controlling the movements of said shafts, also showing portions of the suspended track supporting beams and track for the upper carriages and the hangers on the beam for the carriages showing the devices for effecting uniform movement of the hangers toward each other and the rear end portions of the frame connected with the head block. Fig. 23 is a detail isometric view enlarged of the self extensible head block showing the telescopic parts, the vertically adjustable frame connected with the head block and a broken portion of the transverse beam on the rear end of the main frame supporting the rear end of said frame. Fig. 24 is a vertical sectional view of the self extensible end of the head block. Fig. 25 is an isometric view of one of the upper material compressing carriages showing the power actuated rollers for drawing the mattress cover over the material compressing plates showing one of the upper plates connected with the lower forward portion of the carriage, also a longitudinal portion of the adjustably connected intermediate plate, the automatically operated compound hook carrying shaft for engaging with and supporting the forward ends of the plates, also showing the flexible cover engaging jaw and portions of the hangers upon the outer side and rear end of the carriage. Fig. 26 is a detail isometric view of the compound hook carrying shaft and bar showing the telescopic parts and portions of the transverse plate within the carriage supporting the bar and a portion of the plates engaged by the hook, also showing the catch for holding the rear portion of the bar in a forward telescopic position. Fig. 27 is a detail isometric view of the flexible mattress cover grasping jaw showing a portion of the angle bar on the side of the carriage and the slotted guide supports on the jaw supporting plate. Fig. 28 is a detail isometric view of the clutch operating device for operating the gate raising clutch lever on the forward part of the main frame of the machine. Fig. 29 is a detail isometric view showing broken portions of the suspended track for one of the upper carriages and the laterally spreading suspended section of track rails showing the automatically operated closing and connecting mechanism. Fig. 30 is a detail plan view of one of the outer track rails of the rear section of track as seen in Fig. 28 showing the rack and spring controlled rack moving arm and its position in dotted lines when acting to release the track rail connecting mechanism. Fig. 31 is a detail isometric view of the suspended adjustable box frame carrying the track rail spreading devices for spreading apart and drawing together the upper carriage track rails, also showing the hopper within the box frame and the devices on the box frame and hopper for spreading and distributing the material, a portion of the side of the box frame being broken away to show the latter devices on the inner surfaces of the box frame, also showing the adjustable transverse supporting rod for the hopper upon the box frame and the material dumping hinged doors within the hopper. Fig. 32 is a detail end view of one of the slotted guide plates on the box frame showing the guide roller within the slotted plate the shaft and the hanger roller for the upper carriages on the outer end of the shaft. Fig. 33 is a detail side view of the telescopic shaft on the box frame transmitting power to the material distributing devices on the hopper. Fig. 34 is a detail side view of the grooved wheel on the power transmitting shaft as seen in Fig. 32 showing the opening for the shaft. Fig. 35 is a detail isometric view of one of the material distributors on the hopper showing the sleeve for the crank shaft. Fig. 36 is a cross sectional view taken through the side of the box frame showing the material distributor and the crank shafts and band wheels. Fig. 37 is a detail broken view in perspective of the upper end of the hopper supporting frame, showing the transverse bars with which the hopper is connected, also showing the raising and lowering devices for the hopper and the device transmitting power to the material distributing devices, also showing the automatical devices for controlling the movement of said former devices. Fig. 38 is an enlarged side view in elevation of the cotton layer supporting feeding and cutting devices at the forward end of the machine taken forward of the line 20 on Fig. 1 showing the mattress cover supporting movable table, also the independent cover holding and traveling devices on the table showing a portion of the actuating bar connected with the connecting bar to the rack bars on the lower carriages, also showing the power transmitting devices and the automatically operated mechanism controlling the movements of the respective operative parts. Fig. 39 is a plan view of the cotton layer supporting feeding and cutting mechanism and the movable table as seen in Fig. 38. Fig. 40 is a detail broken view of the rear end portion of the table. Fig. 41 is a detail isometric view of the independent cover holding device on the table for forcing the open end of the mattress cover into the flexible jaws on the upper and lower carriages showing the retracting spring and the rack and jamb. Fig. 42 is a detail isometric view of the upward end portion of the forward corner post of the main frame and a broken portion of the upper horizontal beam and a portion of the longitudinal raising and lowering beam supporting the tracks for the upper and lower carriages showing a portion of the sup-

porting frame for the hopper and a portion of the transverse bar connected with the hopper, also showing the devices actuated in the downward movement of the hopper for controlling the lever to the hopper raising 5 and lowering mechanism, and also for actuating the cotton layer supporting pan in an upward movement and for releasing the gate. Fig. 43 is an enlarged isometric view taken from a position at the forward end of the machine showing the forward standards and 10 portions of the side beams of the cotton layer supporting frame, the upwardly movable inclined table, the throat plates for the layers of the cotton material, the forward apron carrying and pan actuating shafts and the automatically operated mechanism for communicating movement to the respective shafts and 15 the said table. Fig. 44 is a detail view in perspective of a portion of the shaft supporting arms for the cotton layer separating devices showing the yielding journal box for the layer cutting shaft and the power transmitting gear on said shaft and journal box and the milled gear.

Similar numerals of reference indicate corresponding parts in all the figures of the drawing.

The mechanism performing the operations of receiving and distributing the mattress filling material and compressing the same is arranged within a main supporting longitudinal frame herein referred to and the cotton layer supporting feeding and cutting mechanism is arranged within an auxiliary frame on the forward 30 end of the main frame and beneath which the movable table supporting primarily the mattress is located.

Referring to the drawings 40 indicates the main supporting longitudinally extended frame of the machine consisting of the vertical corner posts or standards 35 at its forward end and the vertical corner posts or standards 42 at the rear ends. 43, indicate the longitudinal upper side beams at the upper ends of the standards and 44 the lower longitudinal side beams, located at a point a short distance upwardly from the lower 40 ends of the standards, the said beams being halved near the ends and halved into and firmly secured to the inner surfaces of the standards, the ends of said beams 43 and 44 extending a short distance forward of the forward and rear ends respectively of said frame. 45, indicate the upper transverse beams at one end of the frame which are joined at the ends to the upper ends of the corner posts 41 and 41 respectively. 46 indicates the lower transverse beam which is joined to the lower ends of the corner posts 41.

50 At a point on the sides of the frame 40 a little over one third the distance rearwardly from the forward corner posts 41 are vertical standards 47, which are of the same height as the corner posts 41 and 42 and are connected with or halved into the longitudinal outer surfaces of the side beams 43 and 44 so as to give clearance between the inner surfaces of the beams. With these standards are connected at their upper ends the ends of a transverse beam 48, and at their lower ends the ends of a transverse beam 49. See Figs. 3 and 4.

60 At a point on the sides of frame 40, a short distance forward of the rear corner posts 42, are located vertical standards 50 which are connected with the side beams 43 and 44 in like manner as said posts. The upper ends of said standards extend a short distance above 65 the line of the upper beam 43 and with said ends are

connected the ends of a transverse beam 52. With the lower ends of said standard are connected the transverse beam 52^X.

Upon the upper surface of the lower transverse beams 46—49—52^X are grooved track rails 53 and upon the 70 inner side and parallel with the grooved rails 53 are rack bars 54—See Figs. 4 and 12.

Upon the track rails 53 are mounted the separated pairs of wheels 55, each wheel being pivoted within inverted V plates 56, and these plates in pairs rigidly 75 connected to longitudinal track rails 57, which extends from their position on the track rails on the rear transverse beam 52^X to the track rails on the transverse beam 46 at the forward end of the main frame. These parallel track rails 57 are connected with each other in 80 pairs by the transverse plates 58, which are secured to said track rails at points on the track rails intermediate the ends and short distances inwardly from the said ends. See Figs. 5 and 12. The pairs of track rails 57 are movable toward each other for purpose of adjustment as further described and in order to preserve the alignment of the track rails in the lateral movement a longitudinal rotary shaft 59 slightly less in length than the track rails 57 is journaled in hangers 60 on the under surface of the plate 58 between the one pair of 90 track rails at a point equi distant from the said rails.

Upon the ends of the rotary shaft 59 are cog wheels 62 which move upon the rack bars 54. With the inner ends of plates 58 connecting the other pair of track rails is connected one end of a rack bar 63, the other end of 95 which bar is extended downwardly to a position nearly in a horizontal plane with the track rails 53 in beams 46 and bent at right angles and extended horizontally beneath the plate 58 on parallel track rails 57, carrying the rotary shaft 59 as seen in Fig. 4 and 12. Upon the 100 said shaft 59 are cog wheels 64^X engaging with the rack bars 63.

Upon the longitudinal track rails 57 are mounted the separate parallel carriages 64, 64, which support the sides and bottom of the receptacle for the mattress cover 105 filling material. These carriages each consist of parallel channel beams 66, which are connected together by the vertical transverse plates 67, located at a point a short distance forwardly of the rear ends of said beams as seen in Fig. 8, and with the upper portion of the forward ends are connected a transverse plate or bar 68. The carriages 64 are supported on the longitudinal track rails 57 by the knee bars 69. These supporting bars are connected flatwise with the outer surfaces of the respective channel beams at their upper ends at 110 points on said beams at short distances forward and rearwardly respectively of the rear and forward ends of the beams and are bent at right angles and extended outwardly a short distance then again bent at right angles and extended downwardly to a position a short 115 distance above the track rails 59, and through the lower ends of said bars extends transverse shafts 70 upon which shafts are flanged wheels 70^X. The separate parallel carriages 64 are adjustable laterally to effect the reduction in width of the mattress filling receptacle 120 to that required for a reduced width of the mattress cover. The adjusting devices consist of stationary tubes 71, extending transversely through the parallel channel beams 66 of each carriage at points a short distance forwardly and rearwardly of a line extending 130

transversely through the knee bars on the channel beams and intermediate the upper and lower flanged portions of said beams. Upon the ends of these tubes opposite in position are fixed the nuts 72, as seen in Fig. 8, the threaded opening in which are smaller than the inner circumference of the tubes 71.

73 indicates the separate adjusting shafts each of which is provided with right and left hand screw threads, the circumference of the shafts permitting them to extend through the tubes to the outer sides of the channel beams and are squared to receive a winding crank (not shown) the screw threads fitting the respective nuts. Upon the shafts 73 equi distant from their ends are sprocket wheels 74 over which extends an endless chain 75. Within each of the carriages 64, the construction of which are alike and in rear of the forward connecting bar to the channel beams 66 and journaled in the side of said beams is a large traction roller 76, and between said roller and the rear transverse plate 67 are a series of small traction rollers 77 journaled in the journal boxes 78, upon the upper longitudinal surfaces of said beams 66 as seen in the detail Fig. 8.

79 indicates hollow rotary shafts extending through the rear ends of channel beams 66 of each carriage at a point a short distance in rear of the rear transverse plate 67 and in line with each other. The end portions of the hollow rotary shafts 79 extend a short distance beyond the outer surface of each outer beam on each carriage and upon said end portions are large differential gear wheels 80. Through both hollow shafts 79 extends a transverse shaft 81, rigidly connected with said hollow shafts by set screws 82, the ends of which shaft extend beyond the outer ends of the hollow shafts 79, and to a position in line with the outer surfaces of the standards 47. The differential gear 80 consists of a gear wheel with one periphery, the portion of the periphery as seen in the drawings in the direction of the outer side of the gear wheel is reduced in circumference and provided with teeth for the purpose herein-after explained, the hub of the gear wheel being movably secured to the hollow shaft 79 by the set screws 83.

Upon the lower longitudinal surfaces of the channel beams 66 are journal boxes 84 in a vertical line with the journal boxes 78 in which are journaled the ends 45 of rotary shafts 85.

Upon the journals to the large roller 76 and the small rollers 77 in the direction of the outer channel beam 66 of each carriage are sprocket wheels 86 and upon shafts 85 beneath said sprocket wheels are the 50 sprocket wheels 87, over each of the sprocket wheels 86 and the sprocket wheels 87 immediately below extend an endless sprocket chain 88.

Upon the hollow shafts 79 on the inner side of the outer channel beam of each carriage and at a point a short distance inwardly from said side are separate sprocket wheels 89.

At the forward end of the beams 66 and secured to the outer surfaces in a position below the line of the journals to roller 76 are the plates 90 which are bent outwardly over the lower flange of the channel beam 60 and extend downwardly a considerable distance below said flange and through the lower ends of plate 90 extends a transverse shaft 91 upon which are separate sprocket wheels 92.

93 indicates single sprocket on the respective shafts

85 at a point a short distance inwardly from the sprocket wheels 87 and of larger circumference. Directly above the sprocket wheels are longitudinally grooved guide plates 94 supported by the angle bars 95 connected with the inner surfaces of the outer beams 66.

70

Upon the inner surface of the channel beams 66 at a point a short distance forward of the rear transverse partition 67 are secured the flat bars 96 which extend downwardly below the lower surface of the beams the same distance as the plates 90 at the forward end of the 75 said beams.

In the lower ends of the bars 96 is journaled a transverse shaft 97 upon which shaft forwardly and downwardly from the sprocket wheels 89 are separate guide wheels 98. In the same bars 96 directly above the 80 shaft 97 and a point directly in rear of the rear end of the guide plate 94 is journaled the ends of a rotary shaft 99, upon which are guide wheels 100. Upon the sprocket wheels 89 are sprocket chains 101. These sprocket chains extend over the sprocket wheels 89 85 thence through an opening 102 (see Fig. 12) in the transverse portion 67, thence beneath the guide wheels 100 beneath the guide plate 94, thence over the sprocket wheels 93. For the purpose of communicating motion to the single sprocket wheels 86 on the rollers 77, in the 90 rearward movement of the carriage, the portions of the sprocket chains extending to guide wheels 92 and 98 are connected together by the links 103, thereby forming triple sprocket chains, which as before stated are in the position described when the carriages are in a forward position as seen in Fig. 1.

Upon the upper flanged surface and rear end of each carriage are transverse connecting bars 104 connecting one transverse channel beam with the other. Directly forward of bars 104—104 and immediately in rear of the transverse plate 67 and secured to the upper surface of the channel beams are the separate transverse bars 106, of the same height as the bars 104—104. To the upper surface of the bars 104 are secured the rear ends of the mattress material supporting plates 107, the 105 forward ends of which plates extend to a position in line with the forward ends of the channel beams 66 and bear upon the rollers 76 and 77, the plates 107 extending in width to a position in a vertical line with the outer flanged portions of the channel beams. Upon these plates is laid a plate 108 of the same length as the plates 107, the plate 108 extending in width from the upper surface of one plate 107 in one carriage to the upper surface of the plate 107 upon the other carriage. These plates 107 and 108 form the bottom to the mattress filling the receptacle and upon upper surface of the plates 107 are transverse guide strips 109 and upon the under surface of the plate 108 are slotted guide strips 110 to receive the former strips and retain the plate 108 in position and at the same time permit the self adjusting telescopic movement of the plates 107—108 when the carriages are brought closer together. 115

Upon the hollow shaft 79 and adjacent to the inner surface of the inner channel beams 66 of each carriage 125 is a large sprocket wheel 104 over which extends a sprocket chain 105. Upon the inner ends of the upper transverse bar 106 is journaled a guide wheel 111 and extending forward from the line of the periphery of the guide wheel is a T guide rail 112, supported in position 130

- by the bars 114, secured to the channel beam 66 and extending outwardly the proper distance and then bent at right angles and extended upwardly and secured to the adjacent side of the downwardly extended portion 5 of the T rail. This guide rail 112 extends forwardly to a position a short distance rearwardly of the forward end of the channel beams. Upon the strap 113 on the beam 66 is a small sheave wheel 115, and upon the side of beam 66 is a guide wheel 116 for the sprocket chain 105. 117 indicates the self closing jaws which grasp the lower portion of the mattress cover when about to be drawn forward to receive the plates 107—108 and actuated by the sprocket chain 105. This jaw consists of a flat longitudinally slotted plate 118, which receives 15 the longitudinal upper portion of the T rail and moves backward and forwardly thereon. Upon the upper surface of the plate 118 is secured a plate 119, the forward end of which extends beyond the forward end of plate 118 and between said plates is secured a thin flexible 20 plate 120 of the same length as plate 119 in the forward end of which plate 120 is a large opening 121. One end of the sprocket chain 105 extends forwardly and upwardly from the sprocket wheel 104^X over guide wheel 111, thence upon the upper surface of the T rail 112, 25 and is connected with the rear end of the jaw carrying plate 119. The other end of the sprocket chain extends downwardly and forwardly from the sprocket wheel 104^X, thence over the guide wheel 116 on beam 66, thence upwardly over the small sheave wheel 115 30 and connected pivotally with the forward end of plate 118 in a corresponding manner to that of the sprocket chain 492 with the plate in Fig. 27. Upon the sprocket chain is a pivotally connected pin 122 which extends through the opening 121 in the flexible plate 120. In 35 the outer end of the pin is a transverse opening in which is a pin 123, which serves to draw open the flexible plate when in position to receive the mattress cover and is closed upon passing with the sprocket chain over the small sheave wheel 115.
- 40 124 indicates the draft plates on the rear end of the carriages. A portion of the inner ends of these plates are bent at right angles and connected with the outer surfaces and near the upper ends of the rear transverse plate 67 in each carriage and the outer ends of said 45 plates extend rearwardly above shaft 81, thence at right angles and extended downwardly a short distance in rear of shaft 81 and beyond the line of the rear ends of the channel beams 66 and are provided with transverse slots 125. Through the slots 125 in each plate 50 extends the ends of a transverse connecting bar 126, the carriages being operated as further described.
- 127 indicates the vertical outer side boards to each carriage and which form the sides to the mattress filling receptacle. These sides are laterally movable as seen 55 in Fig. 9 and extend from a position at the rear ends of the carriages a slight distance in rear of the line of the rear transverse partitions 67 and forwardly a short distance forward of a vertical line extending through forward ends of the channel beams 66. Upon the outer 60 longitudinal surfaces and parallel with the upper edges of the sides 127 are grooved runways 127^X. The sides are supported in a vertical position by stationary brace bars 128 see Fig. 15 adjacent to the outer surfaces of the sides 127, and located at points at short distances inwardly from the vertical line of the ends of said sides.
- The lower ends of the brace bars are bent at right angles and extended in the direction of the under surface of the upper flange of the channel beams 66 and a portion 129 bent downwardly and bolted to the outer surface of said channel beams 66, the position of the brace bars being at short distances outwardly from said flanges on the channel beams. The brace bars are perforated at 130 a short distance downwardly from their upper ends and also a short distance above the bent lower end and upon the outer surface of said sides 75 are connected rigidly the inner ends of supporting guide pins 131, the outer ends of which pins extend through the perforations 130 in the brace bars 128, as seen in Figs. 9 and 15. On the inner surface of the brace bars 128 are vertical blocks 132 rectangular in cross section 80 the upper end being seen in Figs. 9, 12 and 15, secured to the inner sides of which blocks are the vertical plates 133, the upper and lower end portions 134 of which are bent at right angles and parallel with the sides 127 and in which portions 134 are journaled the vertical rotary 85 shaft 135 upon which are small upper and lower cog wheels 136.
- Between the separate upper and lower cog wheels and the side of the vertical block 132 are rack bars 137, rigidly connected at their inner ends with the outer 90 surface of the sides 127 of the receptacle and with which bars the cog wheels engage and by means of which the said sides move outwardly for the purpose of permitting the movement of the mattress cover and also to compress laterally the mattress filling material 95 within the receptacle.
- To the outer surface of the knee bars 69 on the channel beams 66 supporting the vertical sides 127 are secured outwardly extended boxes 138, through which the lower end of the shaft 135 extends and upon which 100 shaft within the boxes are cog wheels 139.
- Supported by the boxes 138 is a longitudinal rack bar 140 engaging with the cog wheels 139. A considerable portion of the rack bar intermediate the ends is smooth and extends loosely through the outer end of an arm 141 connected rigidly with the outer surface of the channel beam 66. Upon the said portion of the rack bar at a point a short distance in rear of the forward cog wheel 139 is a lug 142.
- Extending around the smooth portion of the rack bar 110 is a spiral spring 143, one end of which bears against the side of arm 141 and the other end against the lug 142.
- Upon the inner surfaces and lower ends of the corner posts 41 at the forward end of the main frame are secured the horizontal guide boxes 144. See Figs. 2—4— 115 5 and in the detail Fig. 14. Within these boxes extend the ends of a transverse forwardly and rearwardly movable board 145 and with said ends are connected the outside portion of a rectangular frame 146 in which frame are journaled the rollers 147. Upon the inner 120 surfaces of the corner posts 41 at points above and below the boxes 144 are connected respectively the inner ends of stay bars 148 the outer ends of which bars are connected together as seen in Fig. 2.
- With the inner side and outer ends of the stay bars 125 148 are pivotally connected the guiding lugs 149 provided with upper and lower grooves 150. 151 indicates a yielding check bar with the upper and lower surfaces and rear ends of which are connected the guide plates 152. These plates are bent at right angles to the bar 130

151 and outwardly and also extended in a parallel position within the grooves 150 of the guiding lugs 149.

Between the ends of the bars 151 and the lugs 149 are expanding spiral springs 153. The forward upper ends 5 of bars 151 rests upon the upper surfaces of the ends of the movable board 145 and upon the under surface of the bar are lugs 154 which engage the forward longitudinal edge of the board and under the pressure of the springs 153 forces the board 145 rearwardly, the anti-friction rollers 147 permitting the board to move rapidly in position. The supporting lugs 149 being pivoted the bar 151 is disengaged from the board 145 by the chain 155, connected at one end with a staple 156 upon the upper surface and outer end of the bar 151, this chain 15 being operated in the manner hereinafter described.

The forward ends of the rack bars 140 upon the carriages 64 in their forward movement come into contact with the rear longitudinal edge of the board 145.

157 indicates the mattress cover grasping and self releasing devices for drawing the cover over the plates 107—108, upon which the material is deposited in the mattress filling receptacle and also over the plates upon the upper compression carriages hereinafter described. The devices 157 as shown in position in Fig. 4 on both 20 sides 127 of the receptacle in position for the attachment of the mattress cover and in detail in Fig. 16 consist of vertical supporting plates 158 upon the inner surface of the sides 127, upon the upper ends of which plates are flanges 159 extending transversely to said 25 sides and upon the upper surface of the flange 127 and thence bent downwardly upon the outer surface of said flanges. The lower end of the plate 158 is bent at right angles and extends below the line of the lower outwardly flanged portions of the sides 127, thence extended beneath said edges and a short distance beyond the outer line of the outer surfaces of said sides, forming flanges 160. With the inner surface of the plates 158 at a point a short distance upwardly from the lower ends are inwardly extended plates 161 to the outer 30 edges of which plates is hinged the lower ends of the cover grasping and releasing devices, consisting of plates 162 of the same width as plates 158, hinged at their lower ends to the outer edges of the plates 161, their upper ends extending to within a short distance 35 of the upper ends of plates 158, and provided with short projections 163, upon said ends.

Above the upper ends of plates 161 are securing plates 164 hinged to the inner surfaces of the plates 158 near the outer edge of which are openings 165, which receive 40 the projections 163 on the plates 162. A leaf spring 166 is connected with the plate 158, beneath the securing plate 164, one portion of which bears upon the under surface of plate 164, the action of which is to move the plate 164 upwardly to release plate 162.

55 Upon the outer surface of the plate 162 is a spring catch bar 167 and in the outer edge of the hinged plate 164 is a notch 168 which is adapted to receive the upper end of the catch bar 167. In the plate 162 near its outer end and opposite the spring bar 167 is a large opening 60 169, in which opening is a vibratory clasp 170, extending around the spring catch bar 167.

On the inner surface of plate 162 in each side of opening 169 are pivot supporting plates or lugs 171 through which and the inner portions of the sides of clasp ex-

tends the pivot 172. With the lower inner portion of 65 the clasp 170 is connected one end of a spring 173.

Upon the outer surfaces of the hinged plates 162 and near the hinged portions are rigidly connected transverse angle plates 174, the ends of which plates extend a short distance forward of the forward edge of plate 70 162. At a point on plate 162 a short distance upwardly from the angle plate 174 is an angle plate 175 parallel with the plate 174. Above plate 175 is an angle plate 176, the outer projecting portion of which is rigidly connected with the angle plate 175. In the hinged 75 plate 162 are vertical slots 177. Through the upper angle of the plate 176 extends the adjusting bolts 178 which extend through the slots.

With the rear inner side portion of the hinged plate 162 is hinged one end of a cover engaging plate 179, 80 upon the forward end of which plates are vertical plates or jaws 180 the ends of which plates are adjusted to bear upon and extend a short distance beyond the inner surfaces and outer ends of the angle plates 174 and 175. A flat spring 181 is secured to the inner surface of plate 85 162 and extends between the said surface and the inner surfaces of the hinged plate 179. In the inner end of plate 179 is a slot 182.

183 indicates a locking device for the plate 179 consisting of a rear end portion 184 or block secured within 90 the slot by a block 183^X to the inner surface of the plate 162, to which is pivotally connected one end of an upwardly curved and forwardly extended latch bar 185, in the outer end of which bar is an opening 186, with which is connected the other end of the spring 173 95 leading to the clasp 170.

The bars 174—175 enter and spread apart the opening in the mattress cover and when the bars 118 are clamped against the said bars and cover by the compression of spring 181 by the plates 179, the latch is brought above 100 and is swung downwardly upon the upper surface of the plate thereby holding the spring catch 167 in engagement with the self releasing hinged plates 161.

With the inner surface of the plate 158 a short distance below the hinged inner portion of plate 161 is pivotally 105 connected the upper ends of the latch releasing bars 187. These bars extend from their pivotal point forwardly and horizontally a short distance, thence bent at an angle and extended forwardly and downwardly, 110 thence at an angle rearwardly to a point directly beneath the pivotal point of said bar, thence directly downward nearly to plate 161, the lower end 188 of said plate being bent outwardly from plate 158 so as to come into contact with the outer end 185 of latch 183 and release the latch. On the plates 158 are secured the 115 brackets 189 which limit the forward movement of the bars 187.

190 indicates stop blocks in the inner surface of the sides 127 with which the angular projecting portions of the bar 187 contact in the rearward movement of the 120 carriages after the filling of the mattress covers.

With the upper surface of the lower flanged portion 160 of plate 158 is secured the forward end of a rack bar 191. Upon said end of the bar is a pivot 192. See Fig. 16, 12 upon which pivots are guide wheels 193 bearing 125 against the outer surfaces of outwardly curved spring plates 194 secured to the sides 127, the effect of which is to draw the plates 158 close against the inner surfaces

- of said sides and free from contact with the plates 107 on the carriages. The rack bars 191 extend in length a short distance in excess of the length of the carriage channel beams 66 and in the position as seen of the 5 lower carriages the rear ends are a short distance in rear of the line of said rear ends of beams 66 and upon the under side of said ends are loops 192^X. The rack bars 191 engage with the cog wheel 193 which are mounted on the transverse hollow shafts 79 between the large 10 differential gear 80 and the outer surfaces of the channel beams 66 and said bars are retained from upward movement by the rollers 194^X pivoted to the said channel beams in vertical line with the gear wheels 193, and which bear on the upper surfaces of said rack bars. 15 Through the loops 192 on each rack bar extends a transverse connecting bar 195, the ends of which bar extend nearly to the line of the inner surfaces of the standards 47 of the main frame with which standard are connected the forward ends of longitudinally extended angle 20 plates 196, the rear end of which are connected with the inner surface of the rear standards 42. See Figs. 1 and 12 and within which the ends of the transverse connecting bar 195 is guided in its movements. 197 indicates hooks which are pivotally connected to 25 the outer surfaces of the channel beams at its upper end with the rearward pivoted end of which hook is connected the upper end of a releasing bar 198, the lower end of which bar extends downwardly and rearwardly inclined-direction, and directly in line with the rear end 30 of the rack bar 140. The hooks 197 are provided with inwardly inclined faces 197^X and engage with the transverse bar connecting the rack bars 191 with each other. These hooks have auxiliary barbs 199, triangular in form, the upper end of one angle of the barb being 35 pivotally connected at 199^X with the body of the hook 197, the other end is slotted at 200 and in said slot is a guide pin 201 extending on the side of the hook. Upon the pivot 199^X is connected a flat spring 202, the lower end of which spring extends around a pin 203 at the 40 junction of the angle of the barb which retains normally the inner engaging angle of the auxiliary barbs 199 within the line of the engaging portion of the hooks 197. The action of the hook is automatic and when released by the action of rack bar 140 the lower portions of the 45 auxiliary hook will prevent reengagement with the transverse bar 195 and leave the point of the auxiliary hook resting upon the top of said bar in which position the rack bars 191 operating the cover drawing mechanism may be operated prior to the rearward movement 50 of the carriages supporting the mattress filling receptacle. 204 indicates the apparatus upon the sides 127 of the mattress filling receptacle in rear of the mattress cover drawing devices for drawing within the receptacle the 55 cotton layers upon the plate 107—108, prior to the deposit within the receptacle of the mattress filling material. This apparatus consists of a sliding plate 205 short in length mounted upon the upper surface of the track way 127^X upon the upper outer surfaces of the 60 sides 127. A portion 206 of said sides are bent at right angles and extend a short distance downwardly on the inner surface of the sides 127, (see Fig. 20,) and another portion is bent at right angles and extended downwardly a short distance past the outer surface of the
- runway or guide track 127^X. This plate is located in 65 the rear of the cover drawing devices on the sides 127 and moves rearwardly nearly to the rear end of the sides. The runway consists of an upper horizontal portion secured to the sides and a return bent portion 127° extending in the direction of and to within a 70 short distance of the sides as seen in Fig. 20.
- With the lower edge of the portion 207 is connected an extension plate 208 which extends upon the under surface of the runway or track 127^X to the inner surface of the inwardly extended portion 127° thence bent 75 and extended upwardly past said surface thence bent at 209 and extended outwardly from the sides 127 within the groove of the runway.
- Near the rear end portion of the sides 127 and in the lower surface of the runways 127^X are transverse notches 80 210, the forward side of which notches are inclined forwardly at an angle to the upper surface of the notch. At points on the under surface of the guide ways 127^X about two thirds the distance in the direction of the forward ends of said guide blocks or the distance 85 requisite are notches 212, which are similar to notches 210. Upon the upper surfaces of the plates 205 intermediate the ends of said plates are upwardly extended supports 214—215, one of which is vertically in line with the outer flange 207 and the other with the flange 90 206, upon each plate.
- Through the upper portions of the respective plates 214—215, on each sliding plate 205 extends a rock shaft 216.
- From the lower edge of the downwardly extended 95 portions 207 of plates 205 extend short downward extensions 217, with which are connected the inner ends of stationary pivots or rods 218. Upon these pivots are mounted oscillating locking levers 219, each of which consists of a horizontal portion 220, through which the 100 pivots extend. One end portion 221 is bent at right angles and extends inwardly in the direction of the sides 127, and beneath the lower surface of the guide block 127^X and upon the inner end of said portion 221 is an upwardly extended locking projection 222 which extends through an opening 223 in the plate 208 and in the forward portion of the sliding plate 205. 105
- Upon the rear end of levers 220 are upwardly extended portions 224 which extend a short distance above the line of the upper surface of plate 205. 110
- From the rear ends of the portions 220 of the locking levers extend short arms 225 which are beneath the under surface of the plate 208 beneath the guide block and upon the upper surface of said arms are coiled springs 226 which bear upon the under surface of said 115 flange 208.
- Connected with the opposite sides of the portion 220 of the levers are vertical plates 227 through the lower ends of which pivot 218 extends. The upper ends extend a short distance in height above the line of the 120 vertical portion 224 of said lever and are connected together by a transverse portion 228.
- With the lower portion of the downwardly extended plates 206 are connected the upper ends of narrow supporting plates 229, clearly shown in Fig. 12, the 125 lower ends extending nearly to the plates 107 in the mattress filling receptacle.
- With the outer lower surfaces of the plate 229 are

connected the rear ends portions of forwardly extended plates 230, which plates at their point of connection with plates 229 are bent at angle and extended toward each other and then bent at right angles and extended 5 forwardly as described.

231 indicates the transverse indrawing devices for the layers of cotton which consist of hollow tubes adjacent to the plates 107—108, in the bottom of the mattress filling receptacle, the end tubes 232 being 10 smaller and fitting telescopically the intermediate tube 233 and are secured in position by set screws 234, when the lower carriages are brought into adjusted position. In the outer ends of the tubes 232 are pivots 235 which extend through the forward ends of the plates 230 at a 15 point a short distance upwardly from the lower surfaces of said plates.

With the sides of the tube 233 are connected the rods 236 with the outer ends of which rods is connected a tube 237 parallel with tube 233 and in the ends of tube 20 237 are telescopically fitted short tubes 238 which portions of the device is vibrated upon the upper surface of the plates 107—108 within the receptacle and engaging with the advanced ends of the cotton layers introduced within the receptacle. The tubes 237—238 25 are alternately raised in position and bear with their weight downwardly upon the cotton layers in the following manner.

With the outer ends of tubes 238 are connected the outer ends of the ropes 239, the inner ends of which 30 rope are connected with one arm of a bell crank lever 240 pivotally connected with the outer surface and rear end of the plate 230 in a line horizontally with the pivots 235 to the tubes 232.

With the other arms of the levers 240 are connected 35 the lower ends of rods 242 which are bent at right angles at 243, thence extended upwardly and connected with the outer end of an arm 244 on the inner ends of rock shaft 216. With the outer end of said arm is connected one end of a coiled spring 245, the lower end 40 of which spring is extended downwardly and connected with a pin 246 on the rear upper portion of the downward extension or plate 229.

Upon the outer ends of the rock shafts 216 are connected the arms 247 which are inclined at an angle at 45 their outer ends and extend downwardly and contact with the inner surfaces and upper ends of the portions 224 of the locking lever 220, the action of said arm being to retain the projection 222 on said lever within the notch 212 until released the spring 245 effecting the 50 yielding contact of said arm. With the end of said arms is connected one end of an operating cable 248 which extends forwardly over a pulley 249 connected pivotally with the outer surface of the flanged portion 207 of the sliding plates 205 and thence to the rear end 55 of the frame of the machine and operated as further described.

On the cables 248 immediately in rear of the vertical plates 227, is a block 250 which strikes said plates and oscillates the locking lever to disengage the projection 60 upon the lever with the notches, it being observed that the sliding plates 205 are moved rearwardly before the rearward movement of the carriages the locking lever engaging in said rear movement with the notches 210 and nearly to the rear end of the receptacle and in the rearward movement of the carriages 65

subsequently the locking levers engage with the notches 212 and consequently the cotton layer drawing devices are in position for action.

Upon the outer surfaces of the standards 47 on the main supporting frame are yoke bars 251, pivoted to 70 said standards, the pivot being below the forked portions the lower ends of which bars extend to a position near the horizontal beams 44. The rear forks 252^X of the bars are provided with weights 253 so as to vibrate the forked ends rearwardly within which the outer 75 ends of the transverse shaft 81 on the rear end of the carriages 64 enter in their forward movement, the lower end of the bars 251 vibrating forwardly for the purpose as seen in Fig. 21. When the carriages are drawn forward in the manner further described the said shaft 80 enters the yoke or fork of the bar and places said bar into a vertical position, the lower ends of the bars being engaged with a hook bar 252 at its forward end the face of which is rearwardly inclined the rear end of the bar being connected with the beam 44 by a staple 85 253^X. Through the bar 252 into the posts extend the bolts 254 upon which the bar is movable.

Between the head of the bolt and the outer surface of the bar 252 and extending around the bolt is a coiled spring 255 which retains the bar in engagement with 90 the shaft locking bar 252.

The mechanism for disengaging the locking bar 252 and releasing the shaft 81 on the carriages when the latter are in readiness to move rearwardly consists of a crank arm 256 between the locking bar 252 and the 95 beam 44 the ends of which are pivoted in staples 257, the upper end of one arm being bent at right angles and extended outwardly upon the upper surface of beam 44, and are linked with the rear end of a connecting rod 258, the forward end of which rod is linked 100 with the downwardly extending arm 259 of the transverse rock shaft 260 on the forward surfaces of the standards 47, secured at a suitable point above the beam 44 to the standards by the staples 261. The other arm 262 of the rock shafts extends upwardly adjacent to the inner surfaces of the standards and are automatically operated as further described.

At the rear end of the main frame of the machine and connected at the ends with the vertical standards 50 at a point upwardly on said beams in line horizontally with the upper surfaces of the plates 107—108 upon the carriages 64 is a frame supporting beam 263—see Figs. 4 and 23.

With the forward surfaces of beam 263 is connected horizontally a frame 264 which is vertically adjustable 115 and beneath which frame the lower carriages 64 pass in their rearward movements, the self expanding and adjustable head block 265 being connected with the forward end of the frame as further described.

The main portion of the frame consists of a rear end 120 strip 266 and a forward end strip 267 and longitudinally sides strips 268 and longitudinal strip 269 intermediate the strips 268 and connected with said ends of the frame.

Upon the sides of the main frame are longitudinally 125 extended strips 270 which are parallel with the sides strips 268 and movable toward said strips.

With one of the strips 270 are connected at points a short distance from its ends the ends of the screw threaded rods 271 which extend transversely through 130

openings on the outer strips 268 of the main frame and also through the intermediate strip 269. With the other strip 270 are collared the outer ends of rotatable hollow sleeves 273 which extend loosely through the 5 outer strip 268 and abut at their inner ends with the sides of strips 269 and upon the respective ends of the sleeves are nuts, 274 within which the respective screw threaded ends of the rods extend.

Upon the sleeves 273 are sprocket wheels 275 over 10 which extend the endless belt 276 the outer strips being adjusted inwardly in simultaneous movement of the sprocket wheels. The end strip 266 of the main frame rests in the brackets 277 the lower end of the bracket being secured to the lower surfaces of the beam 263, the 15 upper vertical arm of the bracket being adjacent to the inner surfaces of the meeting ends of the strips 266 and 268, the upper ends of the arms being flat and close to the said strips 268 and upon the inner surfaces of the said arms are teeth or racks 278. The forward end of the 20 frame 264 is mounted upon the carriages 64 and extends between the sides 127 and upon plates 107—108, upon said carriages and when the carriages are in a forward position as seen in the drawings (see Fig. 4) the forward end of the frame and head block 265 are in the position as seen in said figure.

Upon the upper surfaces of the main frame a short distance in rear of the head block 265 is a plate 268^X for the purpose hereinafter described. The self expanding and adjustable head block 265 consists of a frame 30 arranged in a vertical position at the forward end of the adjustable frame 268 and composed of upper and lower hollow sections or tubes 279 parallel with each other and an intermediate parallel tube 280, these tubes as shown are rectangular in cross section and in length being nearly equal to the width of the main frame. In the ends of said tubes 279 extend telescopically the inner ends of straight bars 281, and in the ends of the intermediate tube the ends of bars 282.

In order to give expansibility to the frame upon the 40 outer ends of the bars 282 are hollow boxes 283 as seen in section in Fig. 24 and as shown is rectangular in cross section and provided with rectangular shaped openings 284^X at each end, the upper opening being larger in size than the lower opening. The outer ends 284 of the upper 45 per bars 281 are bent at right angles and extended in a downward direction and said bent portions are hollow and at the lower end of said hollow portion and extending inwardly from their inner surfaces are flanges 286. These hollow ends of the bars are extended within the 50 openings in the upper ends of boxes 283. The outer ends 285 of the lower bars 281 in the frame are bent upwardly and are hollow and extended telescopically within the openings in the lower ends 284 of the upper bars 281.

55 Upon the upper ends of the bent ends 285 are external flanges 287 which are within the flange 286 and prevents withdrawal of the telescopic parts. Within the hollow ends 284 of the bars 281 are downwardly extended fixed pins 288^X around which extend the upper 60 ends of the spiral springs 288 the lower ends of which springs extend downwardly with the hollow ends 285 of the lower telescopic bars 281 and to the lower ends of said openings. Upon the parts 281 of the head block are rear extended guide plates 281^X.

65 Connected with the lower hollow portions 279 of the

frame 265 are brackets 290 which are the same as the brackets 277 at the rear end of frame 264 and which extend beneath said hollow portion 279, the rack 291 on each bracket being upon the rear side of the head block and within the forward transverse bar 267.

70

292 indicates rods within the frame 264 and parallel with the inner surfaces of the longitudinal bars 268. The ends of these rods extend within the ends 266 and 267 of the frame 264 and at a point a short distance upwardly from their lower surfaces. Upon these rods 292 75 at both ends are small spur gear 292^X which engage with the racks 278 and 291 respectively.

75

Upon the rods 292 are square enlargements 293 with which a wrench may be engaged and turn the rods so as to adjust the height of the main frame 268 to a position 80 higher than that ordinarily required for the filling of mattress covers of ordinary depth.

80

Upon the upper surface of the transverse beam 263 is a vertically extended plate 294, located in position in vertical line with the inner surface of said beam and its 85 office further explained.

85

At the rear end of the machine and journaled in the boxes 295 located on the rear surfaces of the standards 50 on the main frame and at a point a short distance above the longitudinal beams 44 is a transverse shaft 90 296 upon an extended portion of which shaft past the journal box is a large gear wheel 297.

90

Upon shaft 296 are winding spools 298 with which are connected the forward ends of the chains 299 which are operated to draw the carriages 64 forwardly, the forward 95 ends of which chains extend forwardly past the standards 47 and to and over a pulley 300 supported by the oppositely inclined bracket arms 301 connected at their lower ends with the inner surfaces of the longitudinal beams 44, and from said pulley the chains extend 100 rearwardly and are connected with the outer ends of the transverse shaft 81, on the rear ends of the carriages 64.

95

With the outer ends of the connecting bar 126 connecting said carriages 64 at their rear ends is connected the 105 forward ends of the chains 302 which extend rearwardly over the winding spools 303, on the said shaft 296 and by means of which the rearward movement of the carriages is effected.

105

Upon the rear surfaces of the rear corner posts 42 on 110 the main frame and journaled in the boxes 304 located at a point a short distance above the beams 44 is a transverse rotary shaft 305, one end of said shaft the one at the side opposite to that having the large gear 297 and past the corner post 42. Upon said end of said shaft is 115 a large gear wheel 307.

110

Upon shaft 305 are winding spools 306. With the outer ends of the transverse connecting bar 195 connecting the rack bars 191 are connected the 120 forward ends of the chains 308, the rear ends being connected with the winding spools 306 on shaft 305.

120

On the corner posts 42 directly above the shaft 305 is a rotary shaft 309 journaled in the boxes 310 on said posts. Upon one end of shaft 309 extending past the journal box 310 is a small gear wheel 312 which gears 125 with the gear wheel 307.

125

A short distance above the shaft 309 is located a rotary shaft 314 journaled in the boxes 313 on the rear surfaces of the posts 42 and upon which shaft are winding spools 315, with which spools are connected the 130

130

rear ends of the cables 248 on the devices 204 on the sides 127 of the mattress filling receptacle for drawing rearwardly the layers of cotton over the plates 107—108. The spools 315 are keyed to and slideable on shaft 314.

5 316 indicates the main driving shaft of the machine which is journaled at the ends in the journal boxes 316 $\times$ on the rear surfaces of the standards 50 at a point upon said standards about two thirds the distance upwardly from the lower ends of said standards, both 10 ends of the shaft extending a considerable distance outside of the journal boxes. See Figs. 7 and 22.

Upon shaft 316 is a band wheel 317, with which is connected a band 318 which band extends over a band wheel on an engine (not shown), located in rear of the 15 main frame of the machine.

On the rear surfaces of the standards 50 and journaled at the ends in the journal boxes 319 located on said standards about midway of the journal boxes 295 and 316 $\times$ of the respective shafts 296 and 316 is a transverse 20 rotary shaft 320. Upon the outer extended end of said shaft past the journal boxes is a small gear wheel 321. Directly beneath this gear wheel 321 is a large gear wheel 322 which meshes with the large gear 297 on the shaft 296 on the standards 50, the gear wheel 322 being 25 mounted on a stud shaft 323 which stud shaft is journaled in the journal box 324 on the adjacent standard 50.

On the shaft 320 adjacent to the inner surface of standard 50 is a loose band wheel 325 and on the main 30 driving shaft 316 and rotating therewith is a band wheel 326 over which wheel extends an endless crossed band 327 through which band the power is communicated reversely to shaft 320 thence through the gear 321—322 and 297 to shaft 296 and the chains 302 connected with the carriages 64 are wound upon the spools 303 to draw the carriages rearwardly at the proper time.

On the shaft 320 is keyed a self releasing clutch 328 which clutches the brake neck of the loose band wheel 325, the clutch shown being of the well known lever type and employed in each instance upon the machine, the outer ends of the lever arms upon the clutch grasping the brake neck on the loose pulley, the inwardly bent inner ends being operated by the beveled 45 end of the slideable collar 329. Between the collar and the clutch bar is a coiled spring which disconnects the clutch when the lever is free. With the collar is pivotally connected the clutch operating lever 330, the upper end of which lever is pivotally connected with a 50 bracket 331 extending outwardly from the inner surface of the standard 50, see Figs. 7 and 22, the lower ends of the lever extending downwardly and rearwardly and to a position in line transversely with the rear ends of the lower longitudinal beams 44.

55 332 indicates the vertical sliding lever or bar on the outer surface of the standard 47 of the main frame which when operated causes the clutch 328 to engage the loose wheel 325. This bar 332 is arranged in position on the inner surface of an angle plate 333, secured 60 rigidly to the outer surface of the said standard at a point about one half the distance upwardly from the lower in the direction of the upper end of said standard.

In the upper end and outwardly extended portion of the angle plate 333 is an opening 334.

65 Upon the side of the bar 332 is a bell crank lever 335,

the upper arm of which lever when the bar is raised in position to bring the lever opposite the opening 334 will extend within the opening in which position the other arm is parallel with the bar. This bar 332 is movable within guiding strips 336 on the angle plate 70 and upon said bar beneath the lower arm of the lever 333 is secured the inner end of an outwardly extending spring plate 337, the action of which is to retain the lever in frictional contact in the inner surface of the angle plate and throw the upper arm within the opening 75 334 upon the upward movement of the bar.

With the lower end of the bar is connected a cord or rope 338, the lower end of which rope is connected with the upper arm of a bell crank lever 339, pivotally connected with the outer surface of the standard a 80 short distance above the lower end. Below the bell crank lever and connected with the standard is a horizontal locking bar 340, which is movable within the guide straps 341 upon the plate 342 on the standard.

Upon the lower surface of the locking bar is a lug 85 343, which is engaged with the forward extended end portion 344 of a pivoted lever 345 which is located upon the rear side of the standard 47, adjacent to its inner surface and extends upwardly in position and is moved forwardly in position to release the locking 90 bar 340 in the contact of the shaft 81 in the carriages 64 in their forward movement. The intermediate transverse portion of the lever 345 with which the forward end 344 is connected is secured to the rear surface of the standard by eye bolts. With the outer surface of the standard 47 is connected one end of a spring plate 346, the other end of which plate bears upwardly on the under surface of the lever 345.

With the rear end of the locking bar is connected a 100 rope 347 which is also connected with the lower arm of the bell crank lever 339. With the said end of the bar 340 is connected one end of the rope 347, the other end of which rope is connected with the lever 349 at a point intermediate its ends. The upper end of lever 349 is pivotally connected with the outer surface of 105 the angle plate 196 on the standard 47.

With the lower end of the lever 349 is connected one end of a rope 350 (see Fig. 2) the other end of which rope is connected with an arm of the bell crank lever 351 (see Fig. 22) pivotally connected with the 110 under surface and rear end portion of the lower longitudinal beam 44 on the main frame. With the other end of said bell crank lever is connected one end of a rope 352, the other end of which rope is connected with the lower end portion of the clutch operating 115 lever 330.

Upon the extended end portion of the main driving shaft beyond the standard 50 on the near side of the main frame is a band wheel 353 and upon the extended end portion of shaft 320, directly beneath the 120 said extended portion of shaft 316 is a loose band pulley 354. Over the said pulley 353 and 354 extend an endless belt 355. Upon the outer end of said extended portion of shaft 320 is a clutch 356, engaging with the loose pulley 354.

With the sleeve of the clutch is pivotally connected an operating lever 357, the upper end of said lever being pivotally connected with the forwardly extended end portion of a supporting bar 358 connected at its inner end with the rear surface of the standard 50. 130

The lower end of lever 357 extends downwardly below the line of the under surface of the longitudinal beam 44 and with said end is connected one end of a rope 359, the other end of which rope is connected with 5 one arm of a bell crank lever 360 which lever is pivotally connected with the upper surface of a bracket 361 extending horizontally and forwardly from the outer surface and lower end portion of standard 50 beneath the large gear wheel 297. With the other end of 10 lever 360 is connected one end of a rope 362 the other end of which rope is connected with the rear end of an automatic lever releasing bar 363, which is slideable when released in the guide loops 364 connected with the outer surface of the longitudinal beam 44, which 15 loops are located a short distance forward of the standard 50.

Upon the upper surface of the bar 363 is a lug 365. The bar releasing device consists of a vertical portion 366 of a rod which is rearwardly vibrated by the end 20 of the shaft 81 on the carriages in their rearward movement. The lower rocking end 367 of rod 366 is bent at right angles and extended outwardly upon the upper surface of the longitudinal beam 44 and said portion secured within the straps 368 from which portion 25 367 extends forwardly and horizontally an arm 369 of said rod, the forward end portion of said arm being bent at right angles and extended transversely to the bar 363, in rear of the lug 365.

With the upper end of the vertical arm 366 of the 30 releasing rod is connected an end of a coiled spring 370, the other end of which spring is extended forwardly and connected with the upper surface of beam 44.

With the forward end of the releasing bar 363 is connected one end of a rope 371, the forward end of which 35 rope is connected with the lower end of the lever 372, the upper end of which lever is pivotally connected with the outer surface of the angle plate 196.

With the lever 372 at a point intermediate its ends 40 is connected one end of a rope 373 the other end of which rope is extended forwardly and is connected with the outer end of a bar 374 pivoted intermediate its ends to the lower surface of the angle plate 196 at a point about two thirds the distance from the standard 45 50 to the standard 47.

With the inner end of the pivoted bar 374 is connected one end of a rope 375 the other end of which 50 rope is extended rearwardly and connected with the forward end of a sliding bar 376 with the side of and rear end of which is pivotally connected a spring actuated bell crank lever 377.

In the horizontal portion of the angle plate 196 a short distance in rear of the lever 377 is an opening 378 into which one end of the bell crank lever 377 is 55 upset in like manner as lever 335 in the angle plate 333 on the standard 47.

379 indicates the sliding bar on shelf 380 a short distance below the horizontal surface of the angle plate 196 and parallel therewith. (See Fig. 22.) With the 60 forward end of bar 379 is connected one end of a rope 381 the other end of which rope extends forwardly and is connected with the arm 262 on the rock shaft 260 on the inner surfaces of standard 47 and which arm disengages the locking bar 252.

65 Upon the bar 379 is a bell crank lever 382 which is

pivoted to the outer side of bar 379, the said lever on the bar 379 being located a short distance forward of the position of the lever 379 on the sliding bar 376, so that lever 382 will be forced back in the rearward movement of ends of the bar 195 previously to the contact of 70 said bar with the lever 377, the lever 382 upsetting in an opening 383 in the step 380 in like manner as the lever 377.

Upon the rear surface of corner post 42 of the main frame and directly above the shaft 314 operating the 75 cotton layer drawing devices on the carriages and upon the side of the main frame having the large gear 307 is an outwardly extended rotary shaft 384 short in length, journaled in the journal box 385 the inner end of the shaft being supported in the upper end of a bracket 386. 80

On the inner surface of the corner post on the shaft between the bracket and the post is a small band wheel 388.

Upon the outer end of shaft 384 is a broad band wheel 389 and rotating with and upon the outer end of shaft 85 314 is a band wheel 390 over which wheels extend an endless belt 391.

Upon the main driving shaft 316 is a broad band pulley 392 loosely mounted on the said shaft over which band wheels 392 and 389 extends an endless belt 393. 90

Upon the shaft 384 is a clutch 394 for clutching the band wheel 389.

395 indicates a clutch operating lever one end of which extends upwardly a short distance and with said end is pivotally connected one end of a clutch bar 396, 95 the other end of said bar extending inwardly and bearing upon a pin 397 on the rear surface of the corner post 42.

Upon the under surface of the bar 396 is an inclined lug 398 for passing readily over the pin. This bar is 100 disengaged by the rotary band wheel 399 pivotally connected with the inner surface of the post 42 beneath the inner end of the releasing bar 396.

Over the band wheel 399 and the small band wheel 388 on shaft 384 extends an endless belt 400. 105

On the inner surface of the wheel 399 is a curved arm or lug 401 extending a short distance beyond the line of the periphery of the wheel and also transversely thereto so that on the rotation of the large wheel 399, which is once made during the rearward movement of 110 the cotton layer holding devices on the carriages the clutch bar 396 will be struck by the lug 401 and the clutch releasing lever 395 released.

With lever 395 is connected one end of a bell crank lever 403 one arm of which is connected with the lever 115 395 and the other arm is operated by the cotton layer feeding devices hereinafter described.

With the lower end of the lever 395 is connected pivotally the outer end of a bar 404 the inner end of which bar is pivotally connected with the rear surface of the 120 post 42.

Over the broad band pulley 392 on the outer end of shaft 316 is extended an endless belt 405, which belt is extended downwardly and forwardly over a band pulley 406 on the outer extended end of the rotary shaft 125 309 and rotating therewith, which operates to draw rearwardly the rack connecting bar 195 connecting the rack on the sides of the carriages which operates the mattress cover grasping devices 157.

Upon the outer end of the main shaft 316 is a self re- 130

leasing clutch 407 which acts upon the loose broad band pulley 392 and imparts the rotary motion to the pulley and in turn to the belt 405. The operation of these belts is controlled by a clutch lever 408, the upper end 5 of which lever is connected pivotally with the outer end of an arm 409 on the standard 50. At a point on lever 408 about two thirds the distance downwardly from the clutch is connected one end of a rope 409^X, the other end being connected with one arm of a bell 10 crank lever 410 pivoted to a block at 411 (see Fig. 22) on the outer surface of the standard 50. With the other arm of the bell crank lever is connected one end of a rod 412, small in size, the other end of which rod extends horizontally and forwardly to the forward end of the 15 main frame (see Fig. 3) and connected with one arm of a rock shaft 415 journaled on the forward surface of the corner post 41. The other arm of the rock shaft 415 (see Fig. 5) is extended forwardly and is in the path of and operated by the upper transverse bar 416 supporting the end closing gate hereinafter described to the 20 mattress filling receptacle upon the carriages 64 when the gate is raised in position.

The releasing devices for the lever 408 consists of a bar 417, pivotally connected at its outer end to the 25 lower end of said lever and provided upon its lower surface with a lug 418, having a rearwardly inclined forward surface which lug engages with a horizontal bar 419 connected at its ends with the surface of the corner post 42 on the right hand side of the frame of the machine.

Pivots connected with the corner post 42 on its inner surface is a lever 420 the forward end of which extends beneath the inner end of the engaging bar 417.

With the rear end of lever 420 is connected the upper 35 end of a rod 421 the lower end of which rod extends downwardly and forwardly nearly to a line transverse to the forward surface of the standards 50 and is pivotally connected to the upper end of a lever 422 which lever is pivotally connected with the inner surfaces of the standard 50, a short distance above the beam 263, the rear end of said lever extending downwardly in rear of said beam 263, and a portion bent at right angles and extended forwardly beneath said beam, thence extended downwardly a short distance in the path of the 40 transverse connecting bar 195 to rack bars 191 on the carriages 64. See Fig. 4.

Extending horizontally upon the inner surfaces of the corner posts 41 at the forward end of the main frame to the line of the rear surfaces of standards 50 are the 50 longitudinal supporting carriage raising and lowering beams 425.

At the rear ends of the beam 425 is a transverse track beam 426 and at a point a short distance forward of the intermediate standards 47 of the main frame is a transverse track beam 427 and a short distance forward of beam 427 is a transverse beam 427^X and at forward ends of the beams is a transverse track beam 427°. The ends of these track beams 426, 427, are supported upon rollers 428, these rollers being journaled in the parallel 55 plates 429, secured to and extending transversely to the lower surfaces of said beams.

With one of the parallel beams 425 is connected one end of a spring 430, the other end being connected with a staple 431 in the upper surface of the beam 427.

65 Parallel with the inner surfaces of the beams 425 are

the auxiliary track rails 432. These plates extend in length from the line of the rear ends of beams 425 to a position a short distance forward of the line of the standards 47, the forward end 433 of the beams being bent at right angles and extended downwardly a short 70 distance and said end pivotally connected at 433^X with the lower end of a block 433° which is connected with the inner surface of the beam 425 and extended downwardly the required distance, the upper surfaces of which plates affording a bearing for the rollers 428 in 75 the ends of the track beams 427. The rear ends of the track beams 422 are connected with the lower surface of the rear beams 426.

The longitudinal beams 425 are supported in position and raised and lowered by hoisting ropes on the inner side of the main frame which are connected as follows: With the forward ends of the beams are connected one end of a rope 434 which extends upwardly over sheaves 435 on the upper longitudinal beams 43 of the main frame thence rearwardly to a position forward of the 80 position of standards 50. Intermediate the ends of the beams 425 is connected the lower ends of ropes 436 which extend upwardly over sheaves 437 on the inner surfaces of beams 43, thence extended rearwardly and connected with the ends of the ropes 434. With the 85 rear ends of beams 425 is connected the lower ends of hoisting ropes 438 the upper ends of which ropes extend over the sheaves 439 on the inner surface of beam 43, thence extended forwardly over sheaves 440 a short 90 distance in rear of sheaves 437 from which sheaves the 95 ropes extend rearwardly and are connected with the ends of the hoisting ropes 434 and 436 at 438^X and thence extended rearwardly from said point and connected with the pulleys 441 on the transverse rotary shaft 442, (Fig. 3) the ends of which shaft are journaled at 443 100 upon the upper surfaces of the upper longitudinal beams 43 of the main frame in a vertical line with the sheaves 439.

Upon the upper surfaces of the beam 43 a short distance in rear of the shaft 442 is journaled the ends of a 105 shaft 444 upon which are the sheaves 445.

Connected at one end with the sheaves 445 are hoisting ropes 446, the lower ends of which ropes extend downwardly and are connected with the rear transverse track beam 426. See Figs. 4 and 7.

110 Upon the main power shaft 316 is a band pulley 447 and upon the shaft 442 is a broad loose pulley 448. Over the band pulleys 447—448 extends an endless belt 449, through which belt the power to raise the longitudinal beams 425, supporting the transverse track beams 426—427 and 427^X and 427° is communicated, operation of which shafts automatically will be subsequently explained.

Upon each of the transverse track beams 426—427—427^X and 427° are mounted separate hanging carrier 120 frames 450, each frame being composed of hanger bars 451 in pairs on each side of the transverse beams between which bars at their upper ends are rollers 452, which bear upon the upper surface of the said beams. Between the lower ends of the separate pairs of hanger 125 bars are secured the bars 453. See Fig. 22. Each frame 450 is braced diagonally by the brace bar 454.

Connected with the ends of the respective bars 453 on the carrier frames 450 which are mounted on the transverse track beams 426 and 427 are the longitudinal 130

parallel track bars 455 and which forms sections of track at the rear end of the main frame of the machine and with the ends of the bars 455 of the frames 450 on the transverse track beams 427^X and 427° are connected 5 parallel track bars 456, which constitute the forward section of the track, the contiguous meeting ends of the respective track bars in the sections being at a point forward of the pivoted end of the track plate 432 on the longitudinal beams 425.

- 10 From the track bars are suspended the separate parallel upper material compressing carriages 457, which are of the same length and width as the lower carriages 64, the particular construction of each carriage being shown in Fig. 25 in which the sides 458 are composed 15 of channel beams in like manner as the carriages 64. With the outer surfaces of the said channel beams 458 are connected the lower ends of hangers 459, the upper ends being bent outwardly past the upper flange of the channel beam and extended upwardly and above the 20 track bars 455 and on the hooked upper end of said hangers are journaled the rollers 460 which bear upon said track bars. The position of the hangers at rear ends are at a considerable distance forward of the rear ends of the channel beams and the forward hangers a 25 slight distance in rear of the forward ends of said beams.

Upon the lower surfaces of the channel beams are journaled in the boxes 464, the rollers 462 which are alike in circumference to the rollers 76 in the lower carriages and upon the journals of which rollers adjacent to the inner surface of the outer channel beams 30 are sprocket wheels 463.

- Connected at their ends with the inner surface of the channel beams 458 at their ends are the vertically disposed transverse partitions or plates 458^X, these partitions being placed so as to separate pairs of rollers, the upper surfaces of the plates and rollers being horizontally in line with each, the rear partition being slightly forward of the rear ends of the channel beams and the upper surfaces in line horizontally with the 40 upper flange of said beams.

Upon the upper surfaces of the channel beams are journaled in the journal boxes 461 the ends of the rotary shafts 466 upon the ends of which adjacent to the inner surface of the outer channel beams are sprocket wheels 45 467.

At the forward end of the carriage and journaled upon a stud shaft 468 are separate sprocket wheels 469—470 slightly larger in circumference than the sprocket wheels 467.

- 50 Through the rear hanger bars 459 a short distance above the line of the channel beams extends a rotary shaft 471 upon which is a guide pulley 472.

Directly beneath shaft 471 and journaled at the ends in the channel beams 458 in a horizontal plane with the 55 upper surfaces of the division plates 464 is a rotary shaft 473 upon which is a guide pulley 474 which is beneath the pulley 472.

- In rear of shaft 473 and journaled at the ends in the channel beams 458 a short distance in rear of the shaft 60 473 is journaled the ends of a hollow rotary shaft 475 upon which are sprocket wheels 476—477.

Beneath the sprocket wheels 476 is a longitudinally extended grooved or channel plate 478 secured to the upper surfaces of the division plates 458^X and extend-

ing from a position above the forward roller 462 to the 65 guide pulley 474 on shaft 473.

479 indicates separate endless sprocket chains extending over the sprocket wheels 469 and 470. These sprocket chains are precisely the same as the sprocket chains 101 on the lower carriage a portion of the chains 70 being connected together to form a triple chain, the links in which engage the sprocket wheels 467 which are in position on the shaft 466 to engage at the proper time with the middle links of the chain. The sprocket chains extend over the guide wheel 472 on shaft 471 75 thence over the sprocket wheels 476—477, thence over the guide pulley 474 and upon the upper surface of the channel plate 478.

Upon the shafts 466 on the inner side of the sprocket wheels 467 are small sprocket wheels 480. 80

Over the sprocket wheels 480 extend sprocket chains 481 which extend over the sprocket wheels 463 on the journals of the rollers 462. As the triple links on the sprocket chain pass over the sprocket wheels 467 motion is communicated to each roller 462 progressively 85 from the forward end of the carriage.

The outer ends of the hollow rotary shaft 475 extend a considerable distance beyond the outer surfaces of the outer channel beams of each carriage as seen in Fig. 7, and upon said ends are large differential gear wheels 90 482, which are in reverse positions to the differential gear wheels 80 on the lower carriages 64 with which said gear wheel is caused to engage.

Through the hollow shafts 475 on the rear ends of each carriage extends the shaft 483, the ends of which shaft 95 extend laterally from the outer surfaces of the outer channel beams the same distance as the ends of the shaft 81 in the lower carriages the said shaft being adjusted and rotating with the hollow shaft 475.

The separate carriages 457 are adjustably connected 100 with each other by means of the right and left hand screw threaded shafts 484, which are precisely the same in construction as the adjusting shaft 73 connecting the lower carriages 64 with each other, these shafts fitting within screw threaded nuts 485^X on the ends of 105 hollow tubes or sleeves in like manner. On these shafts are sprocket wheels 485 and over which extend the endless chain 486, (see Fig. 3,) by means of which the carriages are adjusted when the decreased width of the mattress filling receptacle is desired. 110

Beneath the respective upper carriages are material compressing plates 487, which are the same in width and length as the plates 107 on the lower carriages. The rear ends of the plates 487 are rigidly connected with the transverse blocks 487^X which latter are connected at their ends with the under surface and rear ends of the channel beams 458. Separate supporting blocks 489 extend between the upper surface of the plates 487 and the under surface of the channel beams and are secured thereto at points a short distance forward of the point of connection of the rear hanger bars 459 with said beams. 115 120

With the under surface of these plates 487 is telescopically connected a plate 488 as seen in Fig. 25 as follows: Upon the under surface of the plates 487 are 125 transverse grooved plates 489 arranged a short distance apart and parallel with each other.

Upon the upper surface of the plate 488 are angle

plates 490, secured to the said plate the horizontal members of the said plate extending within the grooved plates 489 and slidable therein. See Fig. 25. These supporting plates 489 and 490 are connected with the 5 said material compressing plates at the forward ends of said plates and also at a point intermediate the forward and rear ends thereof.

491 indicates the mattress cover drawing devices on the upper carriages which consists of endless sprocket 10 chains 492 which are located on the inner surfaces of the inner channel beams 458 of the carriages and which pass over small sheave wheels 493 and guide wheels 494 at the forward ends of the beams 458, thence rearwardly beneath the upper flange of the channel beams 15 to and over the sprocket wheel 495 on the shafts 475, thence over the guide wheels 496 on the journals on the underside of beam 458 and the ends connected with the cover grasping devices 491 which are precisely the same as the cover grasping devices on the channel beams 20 of the lower carriages 64. The inverted T guide rail 498 is supported by brackets 499 on the sides of the channel beams and which extend over the lower flanges of said beams and upon the flanges of which the slotted guide plates on the upper surface of the jaw carrying 25 plates 500 are supported in their movements. The jaws consist of the flexible plate 501 which moves downwardly upon the plate 502 when drawn beneath the sprocket wheels 493 in like manner as upon the lower carriages.

30 The material compressing plates 487 and 488 upon the upper carriage are supported in position at their forward ends and automatically grasped and released by means of the device 503 as seen in detail in Fig. 26. This consists of a non rotatable shaft 504, the rear end 35 of which is flat and extends through an opening 505 in the rear plate or partition 458^X of the upper carriage at a point a short distance downwardly from its upper edge and nearest in position to the inner surface of the inner channel beams of each carriage, the rear ends of 40 the shafts extending a short distance in rear of the line of the rear ends of the channel beams. In the upper surface of the said shaft a short distance forwardly from the rear end is a notch 506. The forward end of the shaft is circular in cross section and extends through 45 the respective partitions 458^X and through the partitions located about one fourth the distance rearwardly from the forward ends of the channel beams 458 and in which partitions are loosely mounted spools 507 in which are made grooves 508 through which 50 spools the forward end of the shaft extends. Upon the said end of the shaft is a spiral thread 509.

Connected rigidly with the forward end of the spool 507 is a hook 510, in two slidable parts and these parts extended adjustably by a spring 513, bearing upon a 55 pin 513^X.

Upon the upper surfaces of the plates 487 are loops or staples 512 with which the hooks 510 engage in a partial rotation of the spools.

Upon the shaft forward of the rear portion 504 is a 60 collar 514 and extending around said shaft is a coiled spring 515, one end of which bears upon the said collar and the other end against the rear surface of the partition 458^X forward of the said rear partition.

Upon the inner surface of the rear partition 458^X is a vertical locking plate 516 for the shaft, in the upper 65 portion of which plate is a rectangular shaped opening 517 through which the rear end of shaft 504 extends. This spring 515 is of a sufficient size to permit a movement vertically of the plate 516. The upper edge of the opening 517 engages with the notch 506 in the shaft 70 when the shaft is moved in a forward direction to engage the hook with the compressing plates.

Connected at the ends with the inner surfaces of the plate 458^X is a retaining guide strip 518, which extends over the outer surface of the locking plate 516 and permits the said plate to move freely. In the forward movement of the upper carriages 457 conjointly with the lower carriages the rear ends of these shafts 503 come into contact with the inner surface of the vertical portion of angle plate 294, on the rear supporting 80 beam 263 on the standards 50 of the main frame and the shaft is moved forward a short distance and when the hook 510 engages with the loops 512 on the plates 487 the notch 506 in the shaft is in a position within the plate 464 and the locking plate 516 engages with 85 the notch. This plate 516 is released in the forward movement of the upper carriages when in a position directly above the lower carriages and lowered within the receptacle for the material in which movement the lower ends of the plates 516 come into contact with the 90 upper surface of the plate 268^X upon the frame 264 supporting the head block 265 and located immediately in rear of said head block. The rear hanger bars on the outer surface of the outer channel beams 458 are made with a U shaped offset 519 as seen in Fig. 25, for the purpose subsequently explained. In lowering the main supporting beams 425 a limit of their downward movement is obtained by the short rods 520 with the upper ends of which rods are connected the ropes 521, the lower ends of the rods being connected with the said 100 longitudinal beams 425 a slack being given in the ropes which is taken up in the downward movement of the said beams. Adjusting nuts 521^X connect the said ropes and rods.

In order to preserve an alignment of the carriage 105 track supporting frames 450 on the transverse track beams 426—427, upon the rear surfaces of the inner hanger bars 451 in the frame 450 on the respective track beams are upwardly and rearwardly curved extensions 522 of said hanger bars and upon the upper ends and forward surfaces of the inner hanger bars upon the adjacent frame 450 are upward extensions 523 same in height with extensions 522. Upon the upper ends of these extensions 522—523 are connected the outer ends of rack bars 524—525, the inner ends of said rack bars 115 being in parallel planes with each other and at short distances apart. The ends of a rod 526 extend above the upper portions of rack bars 525 upon the respective frames on transverse beams 426 and 427, upon which are bevel gear 527, the ends of the rod being also supported in the upper ends of standards 528, connected at their lower ends with the transverse track supporting beams 426 and 427. Vertical rods 529 are connected with the upper surfaces of the transverse beams 426—427 the upper ends of which rods extend upwardly 125 between the rack bars 524 and 525, upon the upper ends of which rods are horizontal bevel gear 530, en-

gaging with the rack bars and with which the bevel gear 527 on the rods 526 also engage and a lateral uniform movement of the upper carriages is obtained whenever a lateral adjustment of the carriages is desired.

- 5 Upon the outer surfaces of the standards 47 of the main frame of the machine immediately in rear of the vertical angle plate 333 and the lower end of said plates are outwardly extended horizontal brackets 531, the forward portions of which brackets are bent at right angles and extended forwardly a short distance and upon said forward extension is pivotally connected a forked yoke bar 532, the end portion of the forked bar being carried outwardly and the pivot 533 passing through the lower fork of the bar. Upon the forward ends of the 10 forked bars are weights 534. The bars are held in a normal horizontal position by a ratchet toothed segment plate 535 connected with the inner surface of forked end of the bar and through which the pivot 533 passes. A ratchet bar 536 is pivotally connected with the 15 bracket 531 at a point equi distant from its ends the inner end of which ratchet bar engages with the notched segment plate 535. With the outer end of the ratchet bar 536 is pivotally connected the lower end of a vertical bar 537, the upper end of which bar is pivotally connected with a horizontal lever 538, a short distance inwardly from its outer end the inner ends of which lever is pivotally connected with the outer end of a bracket 20 539, secured to the rear surface of the standards 47.

Upon the outer surfaces of the longitudinal vertically 25 movable beams 425 supporting the transverse track beams for the upper carriages are connected the inner ends of separate outwardly extending bars 540 and 541. The bar 540 extends from said beams adjacent to the forward surfaces of standards 47 and in the downward movement of the beams 425 the outer ends of the bars come into contact with the horizontal spring held arms of the bell crank levers 335 which yield to the bar and the said bar passes beneath said arm of the lever and upon the upward movement of the beams the clutch 30 operating bar 532 is drawn upwardly until the vertical end of the bell crank lever enters the opening 334 in the angle plate 333 and the hold of the bars 540 are released. The bars 541 are secured to the beams 425 a short distance forward of the bars 540. Upon the forward movement of the upper carriages 457 upon the track rails to a position above the lower carriages 64 the movement of which is by gravitation as further described the ends of shaft 483 upon said carriages enter the forked portion 35 of the yoke bars 532, and in the downward movement of the carriages the shaft 483 throws the forward ends of the yoke bars upwardly the ratchet bar 536 engaging with the ratchet teeth and supporting said bar in its vertical position. Upon the full descent of the upper carriages upon the mattress filling material in the receptacle the bars 541 comes into contact with the outer end 40 of levers 538 and releases the ratchet bars and the yoke bars fall under the control of the weights 534 into a normal horizontal position.

Upon the rear end and outer surfaces of the outer 45 channel beams upon the lower carriages 64 are connected rigidly the lower ends of the coupling bars 542 (see Fig. 12.) The upper ends of the bars are bent outwardly and extended upwardly past the outer edges of the flanges upon the channel beams and are also carried forwardly of the rear vertical edges of said beams.

Upon the outer surfaces of the outer channel beams upon the upper carriages are vertically slotted guide plates 543, which receive the coupling bars 542 when the upper carriages are directly above the lower carriages 64 and compressing the material. The coupling 70 devices for the upper and lower carriages also hold the carriages in position while the power of the machine is applied to draw the cover over the material compressing plates.

Extending transversely to and connected with the 75 upper surfaces of the channel beams of both the upper carriages 457 is a bar 544—See Figs. 4 and 25. This bar is located about one third the distance rearwardly from the forward ends of the said carriages and upon the outer ends of said bar are loops 545 opening forwardly. 80

Upon the outer surfaces of the outer channel beams of the lower carriages 64 are pivot plates 546 which support pivotally the rods 547, the lower ends of said rods extending below the carriages. Upon the upper ends of said rods are forwardly directed barbed hooks 85 548, the purpose of which devices are to hold the carriages together after the compression of the mattress filling material and prevent expansion. Coiled springs 547^X connected with the rod and also with the outer surface of the brace bars 128 hold the hooks in engagement with the loops.

Fixed rods 547° extend outwardly from the outer surface of the outer track rails 57 supporting the lower carriages as seen in Fig. 7 and are located so as to be struck by the lower ends of the rods 547 upon the full rearward movement of the lower carriages. 95

In the construction of the forward section of the double elevated tracks for the upper material compressing carriages it will be observed that the forward sections of track are movable laterally and independently of the rear sections. For the purpose of automatically locking the ends of these track rails in each section together and also unlocking them at the forward ends of the rear sections of the track bars 455 supporting the respective upper parallel carriages 457 100 105 are transverse bars 550 connected at their ends by angle plates 550^X with the inner surfaces of the parallel track bars 455 for each carriage, these bars being at a point a short distance rearwardly from the forward ends of the said track bars, the under surfaces of the 110 transverse bars 550 being in the same plane as the under surfaces of the track bars 455. With the rear ends of the parallel track bars 456 for each carriage in the forward section of the track are connected at the ends transverse bars 551, which are located a short 115 distance forward said ends of the track bars and horizontally in line with the transverse bar 550.

With the upper surface of each of the bars 551 to the track bars for each carriage upon one side of a point equi distant from the track bars 456 is connected 120 one end of a plate 552 which is twisted edgewise and extended rearwardly a short distance and from said rear end extends upwardly an extension 553 which is provided with a rearwardly inclined forward surface or notch which forms a hook. 125

Upon the upper surface of the bars 550 is a longitudinal flat plate 554 and upon said bar is a strap 555 extending over said plate and connected at the ends with the said bar.

Upon the forward end portion of the plate 554 is a 130

barbed extension 556 bent laterally at an angle to said plate in the direction of the hook 553 and in the portion of said extension facing the hook 553 is a notch 557 which is adapted to engage with the notch 5 in the plate 552.

With the rear end of plate 554 is pivotally connected at 558^X the forward end of a plate 558.

The rear end of the plate 558 extends rearwardly a considerable distance and is bent at right angles in 10 the direction of the outer track bars 455. Beneath said bent portion of the plate 558 is a transverse supporting plate 559 connected at its ends with the lower surfaces of the parallel track bars 455.

Pivotally connected with the upper surface of the 15 transverse supporting plate 559 flatwise and adjacent to the inner surface of the outer track bars 455 is a large gear wheel 560, with the upper surface of which wheel and near its periphery is pivotally connected the bent end of the plate 558.

20 Upon the inner surface of the outer track bars 455 on each parallel track a mounted plate 560^X is located at a point about two thirds the distance downwardly from the upper surface of said track bar and extending about an equal distance in length forwardly and 25 rearwardly of a vertical line extending through the plate 559.

Upon the lower surface of plate 560^X is an outwardly extended flange 561 upon the outer surface of which is a short downward extended flange 562.

30 Beneath the flange 561 and connected with the track bar is a lip 563.

Fitted in the under surface of the flange 561 is a horizontally movable bar 564 upon the inner surface of which is a rabbet 565 and above said rabbet a tongue 35 566^X, fitting upon said lip 563 and supported thereby.

Upon the portion of the outer surface of the bar 564 beneath the flange 562 on plate 561 is a longitudinal rack bar 566 which is engaged with the gear wheel 560 on the transverse bar 559.

40 Beneath the lower surface of the track bar 455 is a longitudinal guide plate 567, at each end of which plate are upwardly extended portions 568, bent outwardly at right angles and secured to the under surface of the track bars, thus leaving a space between 45 the upper surface of said plate and the under surface of the track bar. The forward portion of the plate 567 is bent at right angles as at 569 and extended upwardly a short distance and nearly to the lower surface of the rack bar 566.

50 Between the lower surfaces of the bar 564 and the upper surface of the plate 567 is a T shaped trip lever 570, the cross piece 570^X of which is pivotally connected at a point equi distant from its ends upon pivot 571 with the bar 564 and is movable longitudinally 55 guided by the upwardly extended portion 569 of said plate 567, the outer end or arm of the lever extending a short distance beyond the line of the outer surface of the track bar in the path of the forward hanger bars 459 on the separate carriages. The ends of the horizontal plate 567 are notched as at 572 (see Fig. 30) and the ends of the upwardly extended portion 569 of said plate are cut away as far backwardly as the notch 572 and upon said upwardly extended portion 569 are secured the inner ends of flat spring plates 573.

60 65 In the movement forwardly of the upper carriages

457 the offset 519 in the rear hanger for the said carriages, before referred to, permits the outer end of lever 570 to pass said lever without contact. When the forward hangers come into contact with the levers the lever and bar 564 move forward the rack bar 566 imparting partial rotation to the gear wheel 560 which movement draws the jointed bar 588 rearwardly causing the hook 556 to draw upon hook 553 and draw the ends of the track bars 455 and 456 upon the sections of track closely in contact. As soon as the lever 570 reaches the notched forward end of plate 567 the cross piece 570 at its forward end passes from the upwardly extended portion 569 of plate 567 to the spring plate 573 and the spring yields so as to permit the outer end of the lever 570 to pass the hanger bar as seen in dotted 80 lines in Fig. 30 and immediately resumes its position to be acted upon to reverse the movement of the bar 564 and release the hooks 553 and 556 from engagement which as before alluded to come into position in a lateral movement of the forward section of the tracks and when 85 said tracks are actuated as further described.

Upon the extended end of the main rotary shaft 316 beyond the outer surface of the far side of the main frame carrying the band pulley 392, and upon the inner side of said pulley is a band pulley 574, and upon the shaft 444 upon the longitudinal upper beams 43 is a band pulley 575 over which pulleys extend an endless belt 576 (see Figs. 3 and 7) and upon the outer end of said shaft is a clutch 577 and a clutch lever 578, the upper end of which lever extends above the line of 95 shaft 444 and upon the inner side of the beam 43 is a vertical bar 579 with the upper end of which bar is connected pivotally with bar 581, the lower end being connected with the outer end of a horizontal bar 580 on beam 50. The lower end of the lever 578 extends 100 downwardly to a position a short distance below the line of the main shaft 316, thence bent at right angles and extended outwardly. The bar 580 pivoted to 578 is caused to rest upon a projection or lug 582 on the rear surface of the standard 50.

Upon the transverse track bar 426 for the upper carriages beneath the end of the lever 578 is an upward projection or pin 583. The outer side portion of the lever 578 forms a starting lever. This lever is operated by hand and will be referred to in the description of the 110 operation. When the lever 578 is operated to throw the clutch 577 in engagement with the band wheel 575 on shaft 444 the power from the shaft 316 causes the shaft to wind the ropes 446 connected with the track bar 526 and also elevate the said track bar, and the 115 carriages move forwardly on the forwardly inclined auxiliary track rails 432 by gravity to a position above the lower carriages 64, in which upward movement of the transverse track bar 426 when the carriages have reached their forward position in the machine by 120 gravitation the upward projections 583 come in contact with the inner extended end of the lever 580 and releases the said end of the lever from the keeper permitting the clutch 577 to exert its power to disengage the clutch 577 from the pulley 575. The shaft 444 125 when the hoisting ropes are wound upon the pulleys 445 and the auxiliary track 432 raised in position the shaft is prevented from unwinding by means of a ratchet wheel 585 on the extension of shaft 444 beyond the outer surface of the upper longitudinal beam 43— 130

see Fig. 3. Upon the outer surface of the said beam is a self engaging pawl 586, the rear end of which having a weighted arm, which pawl engages with the ratchet wheel 585—see Fig. 2. With the pawl is connected 5 one end of a rope or cord 587, the other end of which cord extends forwardly over a sheave 588, upon said beam near the standard 47, thence downwardly and connected with a horizontal bar 589, which is pivoted at its forward end to the standard 47 opposite the position 10 of the longitudinal beams 425. Upon the rear end of the bar is a weight 590.

Upon the outer surface of the beam 425 is a projection or bar 591 which extends beneath the rear end of the bar 589. When the beam 425 is lowered by the hoisting 15 ropes the projection or bar 591 is removed from beneath the weighted end of the bar and this causes the weight to exert power on the ropes 587 and disengages the pawl 586 from the ratchet wheel 585 and the shaft 444 permits the ropes to unwind and the transverse track 20 bar 426 falls into its horizontal position.

Upon the extended end of the shaft 442, carrying the hoisting ropes for the beams 425, and on the horizontal upper beams 43 of the main frame and beyond the rear surfaces of said frame is a large gear wheel 594— 25 see Fig. 3.

Journaled upon the upper surface of the beam 43 in the journal box 595 located a short distance forward of the journal box 443 for shaft 442 is a shaft 596, its outer end being supported by the bracket 596^X, the forward 30 bent end being secured to beam 43, upon which shaft is a spur gear 597 meshing with the large gear on shaft 442. Upon the outer end of shaft 596 is a large band wheel 598 and upon the rear end of said shaft is a band wheel 599 and a clutch 599^X.

35 Upon the main power shaft 316 and the extension carrying the pulley 353 (see Fig. 22) is a pulley 600 over which pulley extends an endless belt 601 which also extends over the pulley 598 on the shaft 596, and upon said shaft 316 is a band pulley 613 over which pulley 40 and the pulley 599 on shaft 596 extend a belt 613^X.

Upon the shaft 316 is a clutch 602 and a clutch operating lever 603. With lever 603 is connected pivotally at a point a short distance above the clutch 602 with a fulcrum or bar 604, the inner end of the bar being rigidly 45 connected with the forward inner surface of the corner post 50. With the extreme upper end of the lever is pivotally connected one end of a link or bar 605, the inner end of the said bar being connected with the forward end of a brake bar 623 on shaft 596. The 50 lower end of the lever 603 extends rearwardly to a position opposite the rear corner post 42.

Upon the rear surface of the corner post above the journal boxes 313 for shaft 314 is a rectangular case or box 606 narrow in width, which is secured at one end 55 to said corner post, said case or box being open at each end and in said box is a sliding bar 607 upon the upper surface of which bar are ratchet teeth 608, the forward ratchet tooth 609 extending above the line of the other teeth so as to nearly contact with upper surface of the 60 box and prevent the raising of the bar 607 from the lower surface of the box.

The forward end of bar 607 is connected with the lower end of the clutch operating lever 603. A bar 608° extends with the inner end of the box upon the

end of which is a hook 608^X, which engages with the 65 teeth 608 of the bar 607.

Directly beneath the box 606 is a horizontal bar 610 connected with the post 42 and extending in the direction of the opposite corner post upon the outer surface of which bar is pivotally connected a bell crank lever 70 612, the upper arm of which lever is pivotally connected with the rear end of the bar 608° carrying the hook 608^X. With said upper end of the arms is also connected one end of a coiled spring 614, the other end of which spring is connected with the post 42. 75

On the beam 263 connected at its ends with the standards 50 is a bracket 615, secured at its rear end to the rear surface of said beam and extending downwardly a short distance below the under surface of said beam, thence forwardly beneath said surface and upon one 80 side of the forward upwardly bent portion of said forward end of said bracket is pivotally connected a bell crank lever 616—see Fig. 4. With the inner arm of said lever is connected one end of a rope 617, the other end of which rope is connected with the lower arm of 85 the bell crank lever 612 operating the hook bar 607.

On the inner surface of the post 42 is pivotally connected one end of a bar 618, the other end of which bar extends transversely to the box 606 beneath the bar 608°. 90

With the inner surfaces of the post 42 at a point in line with the raising and lowering beams 425 at their highest point of elevation is pivotally connected the inner end of a lever bar 619. With the side of said bar a short distance from its pivotal point, the forward end 95 of which bar extends forwardly and horizontally on the inner side of the beam 425, is connected one end of a rod 620, the other end of which rod is pivotally connected with the bar 618 at a point a short distance from its pivotal point on post 42. 100

On the rear end of the adjacent raising and lowering beam 425 for the upper carriages is an inwardly bent bar 621, which extends transversely to and beneath the forward end of the lever arm 619 on post 42, which releases clutch 602 on shaft 316. 105

On the shaft 596 on the upper beam 43 of the main frame upon which is the band wheel 598 is a brake wheel 622.

623, is a longitudinally extended brake lever pivoted at 623^X to the outer end of a supporting bar 624, 110 which is connected with the beam 43 at its inner end and is also connected with the forward end of the bracket 596^X, supporting the journal boxes for shaft 596.

Connected with the outer surface of the brake bar near the pivot 623^X is a brake block 624^X which bears 115 upon the periphery of the brake wheel 622. The forward end of the brake bar extends in a direct line to a point in rear of the brake wheel and is bent at an angle outwardly, thence extended rearwardly as far as the end of beam 43 and with said rear end is connected one 120 end of a coiled spring 625, the other end being connected with the upper beam 43.

Upon the rear surface of the standard 47 is a vertical rod 626, the upper end of which rod extends a short distance above the line of the upper beam 43 and upon 125 said upper end is connected rigidly a short bar 627, the rod forming a pivot therefor. The outer end of the bar which is longer than its inner end is pivotally con-

nected with a short chain 627^X which chain is connected with the rear end of the brake operating bar 623. With the inner end of the bar 627 is pivoted one end of a link 628 which extends a short distance parallel with the 5 upper transverse beam 48 and with the inner end of which bar is pivotally connected the rear end of the clutch operating lever 629, which lever is connected with the clutch 599^X, and also extends to and is pivotally connected with the inner surface of the end 10 standard 50.

Upon the lower end of the pivot rod 626 is a crank arm 630, on the outer end of which arm is a ring 631—see Fig. 12. At a point a short distance downwardly from the upper end of the pivot rod is a separate crank arm 15 630^X, which is the same as crank arm 630. In the rings or loops of the crank arms 630—630^X is a vertical rod or lever 632, the lower end of which rod extends downwardly in the path of the ends of the transverse shaft 483, on the upper carriages 457.

20 Upon the forward end of the main frame of the machine is the vertically movable gate 634, which forms the forward end to the receptacle for mattress filling material upon the lower carriages 64. This gate is composed of the laterally adjustable parts 635, which slide 25 within the rearwardly extended upper and lower flanges upon the rear part 636 of the gates as seen in Fig. 5.

637 indicates the supporting vertical bars for the gate, the lower ends of which bars extend downwardly upon 30 the rear surfaces of the parts 635 of the gate and secured at their ends to the outer surfaces of said bars are longitudinally slotted bars 638.

Connected with the sliding parts 635 of the gate are adjusting bolts 639 which extend outwardly through the 35 slots in the bars 638 and upon said bolts are adjusting nuts 640^X. The supporting bars 637 for the gate are bent at right angles at a point in line horizontally with the upper surfaces of the upper flanges of the part 636 of the gate and extended rearwardly to a position nearly 40 in vertical line with the rear end of the sides 127 on the lower carriages 64, thence bent at right angles and extended upwardly and rigidly connected with the under surfaces of the transverse bar 416 hereinbefore referred to. At short distance below the transverse bar 416 and connected with the said vertical bars is a transverse bar 640. The ends of these bars 416 and 640 are 45 slidably in the vertically grooved guide boxes 641 on the inner surfaces of the forward corner posts 41 of main frame—see Fig. 6.

50 With the inner side of the boxes 641 are connected the angle plates 642, as seen in Fig. 6, and arranged in guide loops 643 on said angle plates are the vertical movable bars 644, upon which bars are the bell crank levers 645, one arm of which extends outwardly in the 55 path of the transverse bar 416, and in the lateral portion of said angle plates are openings 646, which permit the rearward release of the lever. With the lower ends of the bars 644 are connected the upper ends of the ropes 155, which operate the bars 151, and release said bars 60 from the transverse board 145 before referred to.

647 indicates vertical rack bars in the angle plates 642 and adjacent to the vertical sliding bars 644 and 648 is a shaft on the outer surfaces of the supporting bars 637 for the gate 634. This shaft is located between the

transverse guide bars 416 and 640 and supported in the 65 boxes 649 in the vertical bars 637.

Upon the end of shaft 648 are cog wheels 650 which engage with the rack bars 647 and control the upward and downward movement of the said transverse bars 416 and 640 in the guide boxes 641.

Extending through and journaled in the posts 41 of the main frame at a point a short distance below the forward ends of the longitudinal upper beams 43 is a transverse shaft 651 upon which are the winding pulleys 652 with which pulleys are connected the upper ends of the 75 gate hoisting ropes 653, the lower ends of which ropes are connected with the upper gate guiding bar 416 in the guide boxes 641. Upon the extended end of said shaft 651 beyond the corner post 41 upon the rear side of the main frame is a band pulley 652 and upon said 80 outer end of the shaft is a clutch 653 and a clutch lever 654, the upper end of said lever being pivotally connected with a bar 655, the inner end of which lever is connected with the upper surface of the longitudinal beam 43.

Upon the band pulley 652 is an endless belt 666. This belt extends rearwardly to the rear end of the main frame of the machine and over a band pulley 667 on the main shaft 316—see Figs. 7 and 22.

For the purpose of automatically controlling the power 90 from shaft 316 to the gate raising shaft 651 a box or casing 668 is connected at one end with the outer surface of the corner post 41 a considerable distance below the line of shaft 651. This box consists of the upper and lower parallel plates 669, having the ends bent at right 95 angles and secured to the post. In the said plates are slots 670 adjacent to their forward ends in which extend the lower end of the clutch operating lever 654—see Fig. 28. Upon the forward side of said lever between the plates 669 is a pin 671.

A vertical connecting bar 672 is connected at its ends with plates 669 in the upper end of which bar is a vertical slot 673. On the inner surface of the vertical bar 672 is a securing bar 674 and on the side of said bar is a longitudinal slot 675 in which slots 675 and 673 is a connecting bolt 676. Upon the forward end of the bar is a barbed hook 677, which engages with the pin 671 in the clutch operating bar 654.

With the rear end of the hook carrying bar is pivotally connected the forward arm or end of a bell crank 110 lever 678, this arm being bent at right angles and extended upon the other side of the box or casing and upon which side the bell crank lever is pivotally connected with the blocks or plate 669^X on the post 41. The lower arm 679 of the bell crank lever extends to a 115 position in a vertical line with the longitudinal beam 425, supporting the upper carriages and which arm is operated in the downward movement of said beam.

Pivotally connected with the forward surfaces of the upper plate 669 of the box or casing is a lever 680, a 120 bent portion 681, extending at right angles beneath the hook carrying lever 674, forward of the pivotal point of said bar in the vertical bar 672.

With the lever 680 is connected one end of a rope 683, the other end of which rope extends over a sheave 125 604 on the forward surface of the post 41, thence upwardly a considerable distance and is connected with a lever 685, the rear end of said lever being pivotally

connected with the post 41 and the outer end in a position in a vertical line with the pin 685^X projecting from the upper transverse bar 416 supporting the gate 634, and which lever cause the release of the hook on 5 the clutch operating bar 654 upon the upward movement of the gate.

690 indicates the material distributing apparatus adjacent to the forward end of the main frame and which consists in detail of a material retaining box frame 691 10 for preventing the scattering of the material, the sides 691^X of which are in a vertical line with the sides 127 of the lower carriages and the ends of said box are within vertical lines extending through the head block 265 and about in line vertically with the gate 634.

15 The ends of the box 690 consists of three separate parts 692 and 693 adjustably connected with each other. The outer parts 692 are rigidly connected with the sides of the box while the inner parts are provided with outwardly extended angle plates 694 above the line of the 20 upper and lower surfaces of the said plates within which the parts 692 are slidably. In the plates 693 are horizontally extending slots 695. In the parts 692 are adjusting bolts 696 which extend through the slots 695 and upon which bolts are the nuts 697.

25 Connected rigidly at their lower ends with the lower portions of the parts 692 of the ends of the box 691 are the upwardly extended oppositely inclined supporting and guide plates 698, the longitudinal portions of which plates are bent at right angles and extended inwardly toward each other to form the slots 699, the upper ends of the guide plates at their upper ends being bent inwardly and extended a short distance in a vertical direction. In the slots 699 in the guide plates 698 are box supporting rollers 700 which are secured to the outer ends of the extensions 701 of the journals of the inner rollers 452 on the hanger bars 451 on the frame 450, supporting the forward section of the track and mounted on the respective transverse track beams 427^X and 427°—see Fig. 32.

30 Upon the upper surfaces of the sides 691^X of the box frame 691 is the transverse power shaft 702, which is located a short distance in rear of the line of the forward end of the box and journaled in the upper ends of the straps 703, secured to the outer surfaces of the said 35 sides. The shaft is made in sections. The longer main portion 704 of the shaft and a shorter portion 705, these portions having openings in the opposing ends rectangular in cross section as seen in Fig. 34 in which extend the ends of a short section 706. Upon said portion 50 of the shaft is a band wheel 707.

708 indicates circumferentially reduced grooves which are mounted in the straps 703.

Upon each end of the shaft 702 which extend a short distance beyond the line of the outer surfaces of the 55 sides 691^X of the box are separate band wheels 709—see Fig. 33. The material distributors and tampers are upon the inner surfaces of the sides 691^X of the box in vertical positions and alternate with each other in location upon each side, the distributors 710 being located adjacent to the ends of the box. The distributors each consist of a supporting flat plate 710^X, the ends 711 of which are bent at right angles in the same direction and in said portions 711 are perforations 712. Through the perforations extend the material distrib-

uting rods or needles 714, the upper end of said rod 65 being provided with a head 713 which bears upon the upper surface of the upper flange 711.

At a point on the needle or rod 714 a considerable distance downwardly below the lower surface of the lower bent portion 711 of the supporting plate is a collar 70 715. Extending around said rod 714 is a coiled spring 716, one end of which bears upon the collar 715 and the other end against the lower surface of the lower bent portion of the supporting plate.

Upon the outer portion of the plate 710 equidistant 75 from the line of the bent portion is secured transversely the thimble 717.

Upon the inner surface of the sides 691^X of the box at a point about equi distant from the upper and lower surfaces and between the distributing rods 714, and 80 the inner surfaces of the box are rectangular shaped blocks or boxes 718, through which and the sides 691^X extend the shafts 719 short in length upon the inner end of which shafts are crank arms 720, which arms extend within the thimbles 717 on the supporting 85 plates 710 for the distributing needles.

Upon the other end of the shafts and adjacent to the outer surface of the side 691^X are band wheels 721—see Fig. 36.

Upon the inner surface of the sides 691^X at a point a 90 short distance upwardly from the lower surface of the box is a horizontal plate 722, in which are perforations 723, through which the lower ends of the needles 714 extend.

Upon each shaft 719, except the shafts adjacent to the rear end of the box, are band wheels 724, larger in circumference than the band wheels 721. Over the pairs of band wheels 721 adjacent to each other extend the endless belts 725—see Figs. 1 and 2. Over the larger band wheels 724, adjacent to each other and connecting the pairs of shafts 719 are endless crossed belts 726. 100

With the crank arms 720 operating a pair of the distributing rods or needles 714 in the direction of the rear end of the box, and the ends of said arms projecting beyond the thimbles 717, are pivotally connected the ends of a connecting bar 727. 105

Between the distributing needle 714 are the tampers 728, which consist of flat bars, the lower ends of which bars extend downwardly through the longitudinal slots 729 in the plate 722, this slot being closer in position to the inner surface of the sides 691^X than the perforations 723. 110

With the upper ends of the tamping bars are pivotally connected crank arms 730.

With the arm 730 is connected the inner end of a shaft 731, upon the outer end of which arm on the outer 115 surfaces of the sides 691^X of the box are large band wheels 734. As shown the crank arms of the two forward tampers 728 are pivotally connected with the ends of the connecting bars 733.

Upon the shaft 731 on the inner side of the small 120 band wheels 732 are band wheels 734 larger in circumference than the band wheels 732. Over larger pairs of band wheels 734, in the direction of the rear end of the box extend endless crossed belts 735. Over forward larger band wheels 734 and the large wheel 709 on the 125 shaft 702 extend endless belts 736. The smaller band wheels 732 adjacent to each other connecting pair of cranks shafts are connected by the endless belt 737.

Endless belts 738 extend over the forward large band wheels 724, and the band wheels 709^X on the shaft 702. The crossed belts 726 and 735 communicate oppositely directed movements to the pairs of tampers from the movements of the distributing rods or needles 714 and alternate in their reciprocating movements.

740 indicates the material feeding hopper, which collects and holds a measured quantity of the coarse material sufficient for the mattress cover and to be discharged in bulk therefrom, which consists of a rectangular shaped box smaller in dimensions than the box 691, its lower end extending downwardly within the box 691 and about two thirds the distance in the direction of its lower surfaces and its upper end extending upwardly to a considerable distance above the line of the upper surfaces of the upper beams 43 of the main frame of the machine.

The hopper 740 is supported in position by the adjustable rods 741 extending transversely to the sides 691^X of the box 691, and upon the outer surfaces of the forward and rear ends of said box. The rods 741 are screw threaded and fitted within a screw threaded tube 742, which is also externally screw threaded at 743, the rods and tubes passing through perforate lugs 744 on the outer surfaces of the hopper, the latter fitting within screw threaded lugs 745 located equi distant from the lines of the sides of said hopper. The outer end of the rods are supported in plates 746 on the outer surfaces of the box 691 and the outer ends of the tubes are provided with annular grooves 747 and are journaled in the plates 746 on the outer surfaces of the opposite side of the said box. Upon the outer end of the tubes 742 are square shoulders for the convenient rotation of the tube. This adjustment is made in adjusting the width 35 of the box 691 and in the rotation of the tube 742 on the threaded lug 745, the end of the tube moves inwardly drawing the rods within the tubes at the same time.

With the outer surfaces of the respective sides and forward and rear ends of the hopper 740 are connected 40 material distributors which are the same as the distributors 714, the plate 710 and the thimble 717 being in parallel planes with the outer surfaces of the hopper, these thimbles being connected with U crank on the crank shaft 749, extending in opposite directions from 45 the axial line of the shaft the ends of the shaft extending through vertical plates 749° connected by means of angle braces or plates with and extending at right angles to the outer surfaces of the respective sides and ends of the hopper in parallel lines with the corners of 50 the hopper. The lower ends of these angle plates extend downwardly to a position in line with the lower surfaces of the box 691, and with the lower ends of plates 749° are connected the ends of horizontal plates 750 in which are the perforations 750^X through which 55 the lower ends and rods or needles 714 extend.

Upon one end of each of the crank shafts on the sides and ends of the hopper is a small sprocket wheel 751, the sprocket wheels being connected with the shafts so as to locate a single sprocket wheel at each corner of 60 the hopper and are operated as further described.

Within the hopper at a point about midway the upper and lower surfaces of the sides of the hopper are hinged at 752°, the separate doors 752 and 752^X (see Fig. 31) which form the bottom to the hopper and upon 65 the upper surface of one door is secured a plate 753

overlapping the joint between the inner surfaces of the doors and extending a short distance upon the upper surface of the other door.

Upon the forward and rear ends of the doors 752 and 752^X are pins 754, which extend through slots 755, 70 curved in the arc of a circle in the forward and rear ends of the hopper and are operated as further described.

The devices for operating the hopper and material distributors and discharging the material from the hopper to the receptacle are located upon the upper portion of a supporting frame 756, consisting of the vertical standards or bars 757 opposite in position to the corners of the hopper 740, the lower end of which bars are secured rigidly to blocks 757^X short in length, the inner ends of which blocks are connected rigidly with the 80 inner surfaces of the raising and lowering longitudinal beams 425—see Fig. 42. The standards are supported on beam 43 by guide loops or straps 757° (see Fig. 42) and connected together at their upper ends by the horizontal connecting bars 758, connected at their ends 85 edgewise with the respective forward and rear standards transversely to the main frame of the machine and the connecting bars 759, which are connected with the forward and rear standards at their ends and are flatwise in position.

With the forward and rear surfaces of the hopper 740 at a point a short distance below the line of the upper end of the hopper are transverse raising and lowering bars 760, which are bolted to the hopper and upon the ends of the bars are bolted forked extensions 760° which 95 extend upon the opposite surfaces of the vertical standards 757. With the inner surfaces of these bars are connected the ends of bars 760^X extending at right angles upon the outer surfaces of the sides of the hopper—see Fig. 37.

Directly beneath the transverse connecting bars 759 and journaled in the journal boxes 761 on the inner surfaces of the forward and rear supporting bars are rotary shafts 762 and 762^X upon which shafts are winding pulleys 763, with which pulleys are connected the upper ends of hoisting ropes 764, the lower ends of the ropes being connected with the outer forked ends of the bars 760. The forward ends of shafts 762—762^X extend a short distance forward of the line of the vertical bars 757 and upon said extended portion of these shafts are 110 the band wheels 765 in pairs, the outer band wheels being loosely connected with the shafts. On said extended portion of shaft 762 between the band wheels 765, 765^X and the vertical bar 757 is a brake wheel 766.

At a point upon the upper surface of the forward 115 transverse connecting bar 758 equi distant from its ends is a stud shaft 767, mounted at its inner end in the journal box 768, and upon the outer end of said shaft is a large band wheel 769. Upon the same shaft 767 forward of the band wheel 769 are mounted two smaller 120 band wheels 770 and 771.

Extending over the band wheels 765^X is a crossed belt 772.

Extending over the band wheels 765 and 770 is an endless belt 773 and extending over the band wheels 125 765 and 771 is an endless belt 774—see Fig. 37.

On the transverse bars 760 connected with the hopper 740 and adjacent to and parallel with the sides of the hopper are journaled in the boxes 775 the rotary shafts 776 and 776^X, upon the forward end of which shaft 776 130

is a band wheel 777 and upon the forward end of shaft 776^X is an inner band wheel 778 and an outer band wheel 779. Over the band wheels 777 and 779 extends an endless cross belt 780. Upon the said shafts 776—5 776^X in rear of band pulleys 777 and 778 and also upon the rear ends of the shafts are sprocket wheels 781.

Over the band wheel 779 extends an endless crossed belt 782, which extends downwardly over the flanged pulley 707 on the shaft 702 on the box 691 and which 10 belt communicates motion to the material distributing rods or needles 714 and the tamping bars 728 on the inner surfaces of the sides 691^X of the box 691, through the pulleys 709 and to the series of belts 725—726—735—736—737 and 738 on the outer surfaces actuating said 15 needles or rods and tamping bars.

Over the sprocket wheels 781 on shaft 776 and 776^X extend endless sprocket chains 783, which also extend over the sprocket wheels 751 on the ends of the crank shafts 749 on the outer surfaces and lower end of the 20 hopper 740 and which chains transmit motion to the material distributing rods on the sides and ends of said hopper.

Upon the rear end of the shaft 776 which extends a considerable distance in rear of the rear supporting bar 25 760 is a loose pulley, 784.

Upon the upper surfaces of the forward and rear bars 758 at the upper ends of the standards 757 and in a position above the shaft 760^X on the hopper supporting bars 760 is mounted in the journal boxes 785^X the power 30 shaft 785 upon the forward end of which shaft is a band pulley 786.

Over the band pulley 786 and the large band pulley 769 on the stud shaft 768 extends an endless belt 787.

Upon the rear end of shaft 785 and in rear of the journal boxes is a band pulley 788.

789 indicates a balance arm one end of which arm is loosely connected with the rear end of shaft 785, outside of pulley 788 and extends normally in an upward direction and through the upper end of said arm extends a 40 shaft 790, which is short in length and on ends of the shaft are band pulleys 791 and 792.

Over the band pulley 788 on shaft 785 and the band pulley 791 extends an endless belt 793 and over the band pulley 792 and the band pulley 784 on shaft 776 45 extends an endless belt 794.

Connected rigidly at one end with the lower end of the balance arm 789 is a short bar 795 upon the other end of which bar is an adjustable slotted weight 796 which acts to keep the tension on the belt 794 and transmit the 50 power through said belt in the upward and downward movement of the hopper 740.

The power which operates shafts 776 and 776^X is communicated from shaft 442 upon the upper surface of the upper horizontal beams 43 of the main frame of the machine, and from the loose pulley 448 on said shaft close to the band pulley 449. Upon said beams 43 about one third the distance forwardly from the rear ends of said beams are mounted the standards 798 (see Figs. 1—2 and 4) in the upper ends of which is journaled a rotary 60 shaft 799, upon which are the large band pulley 800 and a smaller band pulley 801.

Over the band pulleys 448 and 800 extends an endless belt 802.

Upon the upper ends of the rear vertical bars or

standards 757 of the hopper supporting frame are the 65 brackets 803 in which are journaled the ends of a rotary shaft 804, upon which is a band pulley 805.

Over the band pulleys 801 and 805 extends an endless belt 806.

Upon the said shaft 785 near the band pulley 788 is a 70 band pulley 807 and upon the shaft 804 directly beneath the pulley 807 is a band pulley 808.

Over the band pulleys 807 and 808 extends an endless crossed belt 809.

The mechanism for automatically controlling the operation of the shafts 776—776^X and 785 consists of a bevel gear 810 on the shaft 776 within the transverse bar 760. This gear meshes with a bevel gear 812 on the shaft 813, which extends at right angles to shaft 776. In order to support this shaft 813 two bars 814 and 814^X are connected at their ends with the inner surfaces of the transverse bars 760 supporting the hopper and parallel with the bar 760^X and at short distances apart. Upon the upper surface of these bars 814 are journal boxes 814° in which the shaft 813 is mounted. Upon the 85 shaft 813 near the outer surface of the bar 814 is a gear wheel 815. Upon the shaft 813 and connected with the gear wheel 815 is the loose portion 816 of a clutch the other portion 817 being keyed on said shaft. Extending around the shaft between the portion 815 and 816 of 90 the clutch is a coiled spring 817^X which retains the portions of the clutch normally apart. Upon the supporting bar 814 and journaled in the journal box 814° is a short journal 819 upon which is mounted a gear wheel 820, which meshes with the gear wheel 815. Upon the 95 outer surface of the bar 814 a short distance forward of the gear wheel 815 is a post 821 with which post is pivotally connected one end of a dog 822, the other end of which dog engages with said gear wheel 820. With the inner surface of the supporting bar 814 is connected one 100 end of a bracket 823, the other end of which bracket extends downwardly a short distance and is bent at right angles and a portion extended outwardly and transversely to the bar 814. With the side of the bracket 823 is pivotally connected the inner end of a clutch operating lever 824. With said inner end is connected a vertical portion 825^X which extends in rear of the outer portion 816 of the clutch. The outer end of lever 824 extends outwardly a sufficient distance to come into contact with the upper longitudinal beam 43 of the 110 main frame of the machine in the movement downward of the hopper.

Upon the forward ends of the shafts 762 and 762^X are the clutches 825, which engage with the respective loose band wheels 765 on said shafts. Upon these 115 clutches are clutch operating levers 826 and 827. With the lower end of the lever 826 is connected the outer end of a sliding bar 828, said outer end having a loop or ring 829, extending around the lever. The inner end of the bar 828 passes through a slotted guide box 830 on the 120 upper surface of the transverse bar 760, thence to within a considerable distance from the outer end of shaft 819 and connected at one end with said end of the bar is a strap 831, the other end of which strap is connected with and wound upon said shaft 819. Upon one side of the slotted box 830 is pivoted a bell crank lever 832. With the upper end of the lever is connected a cord 833, the other end of which cord is connected with the dog

822, which engages with the gear wheel 820. With the inner surface of the forward transverse bar 758 on the vertical standards 757 is connected the upper end of a bar 834, the lower end of which bar extends downwardly toward the lower arm of the bell crank lever 832 and a portion of said end bent at right angles in a position to be met by the said arm in the upward movement of the hopper 740.

The upper portion of the levers 826 and 827 are connected pivotally with the outer ends of the forwardly extended bars 835, which bars are rigidly connected with the vertical standards 757, at their upper ends. With the extreme upper end portion of the lever 826 is connected one end of a connecting cord 836, the other end of which cord is connected with one arm of a bell crank lever 837, which lever is pivoted in a horizontal position to the upper end of a vertical post 838, which post is connected with the inner surface of the side bar 759 on the standards 757 at a point a short distance rearwardly from the forward standard. With the other arm of the bell crank lever 837 is connected one end of a cord 839, which cord is crossed with the cord 836, and the other end of said cord extended in the direction of the other side of the hopper supporting frame 756, and connected with one arm of a bell crank lever 840, which lever is pivoted horizontally upon the upper end of a post 841, secured to the inner surface of the side bar 759 and in a like position as the post 838.

842 indicates a brake lever pivoted at its lower end to the inner surface of the vertical standard 757 forward of the post 841, the upper end of said lever extending the same height as the post. With this lever is connected one end of a cord 843, the other end being connected with the other arm of the bell crank lever 840.

35 With the upper end of lever 842 is connected one end of a cord 844 the other end of said cord being connected with the upper end of the clutch operating lever 827. The lower end of the brake lever 842 is bent at right angles (see Figs. 2 and 37) and upon said end is a brake block 844, which bears upon the periphery of the brake wheel 766 on the shaft 762. When the clutches 825 cause the band pulleys to operate with the shafts 766 and 766^X in the descent of the hopper the brake lever 842 is released.

45 Upon the shaft 776 and engaging with the loose pulley 784 is a clutch 845, and a clutch lever 846. One end of the lever 846 is pivotally connected with the outer end of a stationary bar 847, the inner end of which bar is connected with the rear transverse bar 760 on the hopper. The other end of the lever 846 extends outwardly to a position in rear of the rear vertical standard 757 and with said end is connected one end of a cord 848, the other end of which cord is connected with the upper arm of a large bell crank lever 850, which is pivotally connected with the outer surface of the standard 757, the lower end of which lever is bent at right angles and extended in an outward direction and in a vertical line with the bar 851 on upper horizontal beam 43 of the main frame of the machine.

60 The lower end of the clutch operating lever 827 extends downwardly to a point a short distance below the position of the transverse bar 760 connected with the hopper 740, and is bent laterally at an angle and extended to a position adjacent to and below the line of 65 the upper horizontal beam 43, and with the inner sur-

face of said lever is pivotally connected one end of a keeper 852--see Fig. 42. With the rear surface of the adjacent standard 757 connected with the longitudinal supporting beam 425 and at a point a short distance upwardly from the lower end of the standard is connected 70 a keeper, supporting plate 853 which extends outwardly from said standard and in which is a rectangular shaped opening 854, through which the keeper 852 extends.

Upon the rear surface of the standard 757 is pivoted a 75 latch bar 855, the outer end of which bar extends past the opening 854 and engages with the rearwardly inclined lug or projection 856, on bar 852.

Upon rear surface of the sliding bar 760 on the hopper is connected the upper end of a releasing bar 857 the 80 lower end of which bar extends downwardly and is bent at an angle and extended to a position in a vertical line with the inner end of the pivoted latch releasing bar 855.

Upon the lower surface of the upper longitudinal 85 beam 43 and above the releasing bar 855 is a sliding plate 858, which is supported in position by strap hangers 859, the ends of which hangers are connected with the respective inner and outer surfaces of the beam. Upon the forward end of the said plate 859 is an extension 90 860 at right angles and inwardly and in which extension is a vertical slot 861, through which slot the lower end of the clutch operating lever 827 extends, and which plate serves to draw inwardly upon the lever when the clutches 825 are caused to impart motion to 95 the band wheels 765 on shafts 762 and 762^X.

With the rear end of the sliding plate 858 is connected one end of a cord or wire 862, the rear ends of which cord extends rearwardly to a position opposite the rear standard 50 of the main frame of the machine and is connected with one arm of a bell crank lever 863 pivotally connected with a bracket on the inner surface of said corner post 42.

Upon the rear corner post 42 of the main frame is a large band wheel 864 upon the side of which is a pin 105 865, which pin contacts with the other arm of the bell crank lever 863 in the rotation of said wheel. Upon said band wheel 864 is an endless band 866, which also extends over a small band wheel 867 on the rotary shaft 314. During an interval of time in which the band 110 wheel makes one revolution the hopper 740 descends and rests upon the receptacle for the material upon the carriages 64.

The devices for permitting the gate 634 on the forward end of the main frame to drop into position in the 115 receptacle for the material at the proper time consists of a ratchet wheel 868 on the outer end of the rotary shaft 651, carrying the gate hoisting ropes 653.

A pawl 869 is pivoted upon the outer surface and forward end of the upper longitudinal beam 43 with the rear end of which pawl is connected rigidly an arm 870 which extends upwardly a short distance.

Upon the upper surface of the longitudinal beam 43 a short distance forward of the strap 457° supporting standard 757 is connected rigidly a short vertical post 871 upon the forward surface of which post is pivoted a bell crank lever 872, and with the lower end of which lever is pivotally connected one end of a rod 874, the other end of which rod is pivotally connected with the upper end of the arm 870 on the pawl 869, engaging 130

with the ratchet wheel 868. The horizontal portion of the bell crank lever extends rearwardly a considerable distance.

Upon the outer end of the transverse bar 760 on the 5 hopper is secured the inner end of a rod or bar 876, which is in a vertical line with inner end 875 of the bell crank lever 872 on the post 871. In the descent of the arm 760, the rod 876 strikes crank arm 875 and releases the pawl 869 which is weighted so as to return in 10 engagement with the ratchet wheel 868.

Upon the said post 871 and upon the outer surfaces and near the upper end of said post is pivoted a bell crank lever 877, the lower arm of which lever extends rearwardly past the line of the rear surface of the post 15 and in the path of the rod 876 on the bar 760, and is first met in the downward movement of the bar 760 preceding the contact of the rod 876 with the bell crank lever 872, this bell crank lever 877 setting in operation the cotton layer feeding devices to the receptacle and 20 also the devices for raising the layer supporting and guiding plate hereinafter described.

The devices for operating the drop bottom doors 752 and 752^X in the hopper 740 consist of cords 878, connected with the respective pins 754 on said doors and 25 connected together at 879 on said doors, and from said point a double cord 880 is extended upwardly over the sheaves 881 in the forward surface of the transverse bar 760 on the hopper 740 and thence over a second sheave 882 on the outer end of bar 760, thence downwardly on 30 the forward surface of the standards 757 a short distance and connected with pins or staples 883 on said standards. When the hopper is in an elevated position the cord 880 is taut and upon its movement downwardly the slack in the ropes permits the doors 752—752^X to open downwardly and discharge the material.

At the forward end of the main frame of the machine is a mattress receiving table or bench 884. This table is composed of longitudinal slats 885, connected at their forward ends with a transverse bar 886 supported by 40 legs 910 in which are rollers 891. These slats are arranged at equal distances apart, the pair of outer slats on each side of the table having longitudinal slots 887, which slats are secured to the bars 886, adjustably by the adjusting screws 888. The rear ends of the slats 45 composing the table with the exception of the rear ends of the outer pair of slats, are connected with a short transverse bar 889. The outer pair of slats are connected with short transverse bars 890 as seen in Fig. 40 which are arranged at a point a considerable distance 50 forward of the line of bar 889, the inner ends of which bars extend inwardly toward each other to the line of the outer edge or surfaces of the two bars in the longitudinal central portion of the table.

In the outer pairs of slats are longitudinally extending slots 891.

892 are adjusting screws extending through slots 891 into the transverse bars 890.

Upon the rear surface of the bars 889 are hooks 893 and upon the forward ends of the channel beams 66, 60 supporting the lower carriages are transverse bars 894, with which the said hooks 893 engage.

The outer pairs of slats of the table, for the purpose of making the table narrow in width in correspondence with the adjustment of the various parts of the machine, 65 are moved forwardly in position see Figs. 39 and 40

upon the loosening of the adjusting screws at the forward and rear ends of the table.

890^X is a lug on the inner surface of the legs 890 and which strikes the board 145 on the corner posts 41 in the forward movement of the table.

The devices for holding taut the closed end of the mattress cover and also holding the flaps at the open end in position to receive the material compressing plates consists of a carrier 895, consisting of vertical side plates 896 arranged in a parallel position in the 75 space between the two longitudinal slats in the longitudinal central portion of the table. These plates extend upwardly a considerable distance above the plane of the upper surface and a like distance below the plane of the lower surface of the table and are connected together by a transverse plate 897 at the top and by a transverse plate 898 located a short distance above the lower ends of said plates.

At the upper ends of the plates 895 are forward extensions 899. Between these forward extensions 899 is 85 a transverse connecting plate 900.

901 is the upper mattress cover holding bar which is pivoted at its forward end to the transverse rod 902 extending through the plates 895 at a point a short distance below the upper ends of said plates and near their 90 rear surfaces and extends rearwardly nearly to the rear end of the table and turned upwardly at its extreme end. The forward end of the bar 901 extends to a position in line vertically with the inner surfaces of the plate 900 and with said end of the bar is connected the 95 lower end of a short upright bar 903 having ratchet teeth 904 which engage with the lower surface of the plate 900.

Upon the top plate 897 is secured one end of a spring plate 905 the other end of which plate is curved upwardly and bears upon the forward surface of the bar 903. In the movement upwardly of the rear end of bar 901 to support the open end of the mattress cover the ratchet bar 903 engages with plate 900 and holds the bar in its adjusted position.

Upon the side of the bar 901 is a hook 901^X which is located a short distance forward of its rear end and engages with the open end of the mattress cover.

906 indicates the lower mattress cover supporting bar which is pivoted to a transverse rod or bolt 907, 110 extending through the plates 895 near their rear surfaces, which bolt is located a short distance above the plane of the upper surface of the slats 885 of the table, the rear end of the bar extending in length a short distance in excess of bar 901, the extreme end being 115 curved downwardly. Upon this bar is a cover supporting hook 908.

Between the same slats 885 and in the space in which the carrier 895 moves longitudinally upon the table is a wide sliding block 909 in the sides of which are slots 120 909^X which receive the adjacent parallel slats 885, the slotted parts being supported by the said slats. The upper end of block 909 extends upwardly about one half the distance of the carrier 895, upon said end is a bar 1000, extending transversely to the table. Connected with the ends of this bar which are above the outer slats 885 are connected one end of a chain 1001 upon the outer end of which chain is a hook 1002 which also engages with the ends of the mattress cover and holds the cover extended.

- The lower end of block 909 extends downwardly the same distance as the carrier 895 and with the said end is connected the forward end of a bar 1003, which bar extends rearwardly between the plates 895 of the carrier and beneath the lower surface of the transverse plate 898 connected with said plates 895, thence between the opposite channel beams 66 of the separate lower carriages and connected with the transverse bar 195 connecting the rack bars 191.
- 10 With the under surface of the slats 885 upon each side of the carrier 895 are connected rigidly the longitudinal bars 1004. Upon the under surface and rear end of one of said bars 1004 is a trip block 1005, having a rearwardly inclined forward end. The bar 1003 upon its lower surface and forward end is provided with ratchet teeth 1006.
- 15 A counter balanced pawl 1007 is pivotally connected with a pivot bolt 1008 extending through the vertical plates 896 of the corner at the lower ends of said plates 20 the upper end of which pawl engages with the ratchet teeth 1006 on the bar 1003. Upon the engaging or upper end of said pawl is a pin 1009 extending laterally therefrom and through a slot 1010 in the side plate 896 of the carrier 895.
- 25 A coiled spring 1012 is connected at one end with a transverse bolt 1013, extending through the plates 896 of the carrier at a point a short distance above the planes of the table, the other end being connected with the upper end and rear surface of the block 909.
- 30 A link 1014 is connected rigidly with the rear end of the lower cover supporting bar 906, which link extends downwardly beneath the bar 1003.
- 35 The tension on the mattress cover is maintained by the carrier 895 and when the block 909 and bar 1003 are drawn rearwardly by the rack bar 191, the pin 1009 on the pawl 1007 comes into contact with the block 1005 beneath the table and releases the pawl 1007 and the spring 1012 draws the carrier back in the contraction of the spring.
- 40 For the purpose of feeding the coarse material to the hopper 740 in the main frame of the machine a horizontal endless conveyer is arranged in position a short distance in rear of the main frame of the machine and which consists of separate rollers 1016—1017 over which 45 extends horizontally the endless broad belt or apron 1018. The rollers 1016 and 1017 are mounted upon shafts 1019 and these shafts are supported at their ends in uprights or standards 1020 (see Figs. 1 and 3), which extend upwardly from the floor the usual height of a table.
- 50 Upon the end of the forward shaft 1019 is a large band wheel 1021 and upon shaft 320 upon the corner posts 42 on the main frame of the machine is a small loose band wheel 1022, held by spring controlled clutch so as to rotate with the shaft in one direction only, 55 over which band wheels extend an endless belt 1023.
- Above the endless belt 1018 is a vertical spout 1024 which is supported by two straps 1025 and 1026, the upper strap 1025 being secured at its ends to the rear ends of the longitudinal upper beam 43 of the main frame of the machine and the lower straps to the corner posts 42.
- 60 Upon the lower end of the pipe 1024 is an outwardly and downwardly inclined flange or hood 1027 which is arranged in position a short distance above the travel-
65 ing apron 1018.

With the lower portion of the spout 1024 a short distance above the hood 1027 is connected an ordinary blast fan case and fan 1028, in which is the fan shaft 1029.

Upon the shaft 320 upon the standards 50 of the 70 main frame of the machine which has a reverse movement is a loose band wheel 1030, controlled by a spring clutch the same as pulley 1022.

Over the band wheel 1030 and the shaft 1029 in the fan case 1028 extends an endless belt 1031. 75

Upon the shaft 320 is keyed a sliding sleeve upon which is a clutch which engages with a clutch on the side of pulley 1030. The sleeve is held in engagement with the clutch by a spring 320° on shaft 320. This permits the loose pulley rotation in one direction and 80 also in a reverse direction on the shaft. The upper end of spout 1024 extends in height above a horizontal plane extending through the upper end of the hopper 740, and is then bent at right angles and extended to a position vertically above the hopper and is then bent 85 at right angles and extended downwardly to a position near the entrance to said hopper as seen in Figs. 1 and 3. The horizontal portion of the spout is supported in a forked standard 1032 on the transverse beam 52 on the standards 50 of the main frame. 90

For a purpose of supplying fine material to the cotton layers when drawn within the mattress filling receptacle separate spouts 1033 and 1034 are arranged in position upon the far side of the main frame of the machine or its side of machine upon which the lever 584 is located. 95 The lower ends of these spouts are provided with outwardly and downwardly inclined flanges which are the same as the flange 1027 on spout 1024. The lower ends of the spouts are arranged a short distance above the horizontal conveyer which consists of separate 100 rollers 1035 and 1036 as seen in Figs. 1 3 and 7, the rollers being mounted upon shafts 1037, which are journaled at the ends in uprights or standards 1038, extending upwardly from the floor or ground about one half the distance of the standards 1020, supporting the 105 endless conveyer 1018. Over the rollers 1035 and 1036 extend an endless apron 1039.

Upon the shaft 1037 carrying the roller 1035 of the conveyer which extends a short distance from the outer surface of the standard 1038, toward the frame 110 of the machine are mounted separate pulleys 1040—1041.

Upon the outer extended end of shaft 314 on the corner posts 42 of the main frame of the machine is a large band pulley 1043 over which pulley and the 115 band pulley 1041 extends an endless belt 1043X.

Upon each spout is a blast fan case and fan 1044, oppositely located and near the lower ends of the spouts the fan shafts being connected and forming one shaft 1045, upon which shaft is a band pulley 1046, 120 over which pulley and the band pulley 1040 on the conveyer shaft 1037 is extended an endless belt 1047.

Upon the forward end of the main frame of the machine is a vertical chute 1048 which as illustrated is composed of sheet metal narrow in width and of the 125 proper length to distribute the fine material. The chute is composed of thin plates the ends of which are movable inwardly and adjusted to correspond with the decrease in width of the mattress filling receptacle. These ends consist of a narrow vertical portion 1049 130

from which extending inwardly a short distance and parallel with each other are the forward and rear portions 1050 of the chute, the upper ends 1050^X of which portions are bent in opposite directions rearwardly upon the upper surface of the beam 45 in one direction and forwardly upon the upper surface of a transverse bar 1051 on upper beam 43 of the main frame and these bent parts are slidable upon said bar and beam. The central portions of the chute consist of vertical flat plates 1052, the upper end of the rear plate being connected with the beam 45 and the upper end of the forward plate being connected with the bar 1051. The portions 1050 of the ends extend upon the inner surface of the flat plates 1052, telescopically—See Fig. 3. 15 The adjusting rods 1053 having screw threaded ends are fitted in lugs 1054 upon the front and rear portions 1050 of the chute and at points near its upper and lower ends and these rods extend through boxes 1055 upon the plates 1052.

20 The upper ends of the distributing spouts 1033 and 1034 extend directly upward from their position above the apron 1039 about the height of spout 1024, thence bent at right angles and extended to position above the opening in the chute 1048, the upper end of the 25 spout 1033 being above one end of the chute and the spout 1034 above the opposite end of said chute at which points the spouts are bent again at right angles and extended downwardly within the chute 1048.

The spouts 1033 and 1034 are supported at their 30 lower ends by the supporting bar 1056, connected with the lower ends of said spouts and the upper ends of the forward standards 1038 supporting the endless apron 1039.

The frame supporting the cotton layer carrying rollers and the mechanism for automatically feeding the layers to the mattress filling receptacle consists of the vertical standards 1060 arranged in advance of the forward corner posts 41 of the main frame, within the line of the sides of the main frame of the machine, the 40 normal position of the table or bench 884 at its forward end being a short distance in advance of a line extending transversely through said standards. The standards 1060 extend upwardly to a position a short distance above the horizontal plane of the upper longitudinal beams 43 of the main frame of the machine and with the inner surfaces of said forward ends of said beams are connected rigidly the rear ends of the upper supporting beams 1061, the forward ends being connected with the outer surfaces of the standards 1060. 45 At points on said standards a short distance below the beams 1061 and with the outer surfaces of said standards are connected the forward ends of the horizontal beams 1062, the rear ends of which beams are connected with the inner surfaces of the corner posts 50 41, on the main frame of the machine.

Upon the forward vertical surfaces of the standard 1060 and at a point a short distance downwardly from their upper ends is journaled the ends of a transverse shaft 1063, upon which are cog gear 1064, located at 60 points a short distance inwardly from the journal boxes 1063^X.

1065 indicates a downwardly and rearwardly inclined guiding table slightly narrower than the space between the standard 1060.

65 Upon the inner surface of the longitudinal upper

beams 1061 adjacent to the standards are blocks 1065^X and upon the inner surface of the lower beams 1062 at a point about one third the distance rearwardly from said standards toward the corner posts 41 are similar blocks 1065^X. With these blocks 1065^X are connected 70 the grooved guide plates 1066^X within the grooves in which plates are inserted the narrow plates 1067^X which are connected with the upper end of the inclined table 1065.

With the under surface of the plates 1067^X on table 75 1065 are rigidly connected the lower ends of the rack bars 1068^X. The upper ends of these bars extend a considerable distance above the line of the upper portion of the table 1065 and engage with the cog gear 1064.

The lower end of the table 1065 extends to a point 80 a considerable distance above the plane of the mattress supporting table 884.

Upon the lower end of the table 1065 is a narrow extended portion 1066 which extends within the sides 127 of the mattress filling receptacle and upon the forward ends of the telescopic plates 107 and 108 in the bottom of the mattress filling receptacle—See Fig. 12.

With the under surface and lower end of the extension 1066 is connected the transverse angle or guide plate 1067 and upon the lower surface of the main portion of table 1065 at a point a considerable distance upwardly from the plate 1067 is connected rigidly an angle plate 1068, the outer portion of which plate is bent at right angles and extended downwardly a short distance. Within the plates 1067 and 1068 are the ends of the sliding or telescopic plates 1069 which also extend within the receptacle for the mattress filling material between the sides 127, thus enabling the corresponding reduction in width of the lower end of the table 1065 to conform to the reduction in width of the mattress filling 95 receptacle when the reduction becomes necessary.

Upon the upper surface of the upper beam 1061 at a point about one third the distance from the inner ends of the beams toward the forward ends is journaled the ends of a transverse shaft 1070 upon which shaft intermediate its ends is a roll of cotton batting 1071 of the usual commercial thickness and width.

With the upper surface of the upper beams 1061 at a point a slight distance forward of shaft 1070 are the posts 1072, extending upwardly a short distance and 110 with said posts is connected the ends of a transverse bar 1073. With this bar at a point intermediate its ends is connected rigidly the upper end of a guide beam 1074, the lower end of which beam extends forwardly and downwardly and is connected with the upper surface of transverse bar 1075, which bar is connected at its end with the lower surface of the beams 1062 at a point a short distance rearwardly of the standards 1060.

Upon the upper surface of the beams 1061 at a point about two thirds the distance from their rear ends in the direction of their forward ends are journaled the outer ends of the idle shaft 1076, upon which is mounted separate rolls or bolts of cotton batting 1077—1078 and arranged apart upon said shaft, the outer vertical surfaces of the rolls or bolts 1077 and 1078 being considerably within a vertical line extending through the longitudinal outer portions of the inclined table 1065. At a point upon the upper surfaces of the beams 1061 a short distance in rear of shaft 1070 is journaled the ends of a 125

power shaft 1079, upon which is a roller 1080 of the same length as the roll of cotton batting 1071. Upon said beam and at a point intermediate the shaft 1076, carrying the cotton rolls 1077—1078 and the forward ends of 5 the beams 1061 is journaled the ends of a power shaft 1081, upon which are separate rollers 1082. In order to feed the cotton batting from the rolls, two shafts 1083 and 1084 are journaled upon the beam 1061 at their ends intermediate the shafts 1070 and 1076, and upon 10 these shafts are rollers smaller in circumference than the rollers 1080 and 1082. The shaft 1084 is in two parts, the inner ends of said parts being journaled in the respective sides of the beam 1074.

Upon the beams 1062 in a vertical line with the shafts 15 1083 and 1084 are journaled the ends of the roller shafts 1085 and 1086.

An endless apron 1087 extends over the roller 1080, thence upon the lower surface of the roll of cotton batting 1071, thence forwardly over the roller on the roller 20 shaft 1083, and thence downwardly over the lower surface of the roller shaft 1085. Endless aprons 1088 extend over the rollers 1082, thence upon the lower surface of the cotton batting rolls 1077, 1078 and over the roller 1084 downwardly upon the lower surfaces of the 25 rollers on the roller shafts 1086.

Upon the outer ends of the shafts 1081 and 1079 extending beyond the outer surface of the beam 1061 on the left side of the machine are band wheels 1089 over which extend an endless crossed belt 1091.

30 The separation of the roller shaft 1084 into two parts permits a variance of the size of the cotton batting rolls and in order to keep the endless aprons under pressure upon the cotton batting rolls belt tighteners consisting of rollers or shafts 1092 upon which are rollers which 35 bear upwardly against the lower surface of the endless apron 1087. The ends of this roller shaft are held in the longitudinal slots of the rearwardly inclined bars 1093, which are connected with the outer surface of the beams 1061—1062 near the position of the journal boxes 40 for the roller 1083.

In order to hold the roller under pressure with the apron, cords 1094 are connected with the outer ends of the roller shafts 1092, which extend upwardly parallel with the bars 1093, thence over the rollers 1095 on the 45 outer surfaces of beams 1061, thence over the pulleys 1096 near the corner posts 41 and with the outer end of said cords are connected a weight 1097.

1098 indicates the tension roller shafts for each roll of cotton batting 1077—8, the journals of which rollers 50 are held within the guide strips 1099 on the beams 1061 and 1062 and which strips are inclined downwardly and forwardly, the inner journals being held in the slots in the forwardly inclined bar 1074. Cords 1100 are connected at their inner ends with the respective inner 55 and outer ends of the separate rollers or shafts 1098, the outer end of which cords extend forwardly over pulleys 1101 1102 on the beams 1061 and pulleys 1102^X shaft 1063 and are provided with weights in like manner to cords 1094. The free ends of the cotton batting pass 60 downwardly between the opposing surfaces of the aprons 1087 and 1088, thence between the transverse guide plates 1103 and 1004, provided with flanges 1105 at their upper ends which are secured to the lower surfaces of the beams 1062, the lower ends of which plates

are bent rearwardly in a corresponding inclined plane 65 to that of the table 1065.

In order to sever the cotton batting when the desired length is drawn from the rolls on the respective shafts 1070 and 1076, arms or bars 1105 are connected rigidly at their upper ends with the lower surfaces of said 70 beams 1062, the lower ends of which arms extend downwardly and are inclined forwardly at an angle to said beams. In these arms 1105 are longitudinal slots 1106 (see Fig. 44) in which are vertically movable shaft bearings or blocks 1107, the outer surfaces of which 75 blocks extend laterally upon the outer surfaces of the bars 1105 and retain the blocks within said slots. Within the slot 1106 and between the lower ends of blocks 1107 and the lower ends of the slots are coiled springs 1108.

Through the lower ends of the blocks 1106 extend the ends of a rotary shaft 1109, upon the said ends of said shaft are pinions 1110.

Upon the shaft 1109 is a roller 1112 in the surface of which are pins 1113 extending outwardly a short distance. 85

Through the upper ends of the blocks 1107 extend the ends of a rotary shaft 1114 and upon said ends are cog wheels 1115, which mesh with the pinions 1110.

Upon the shaft 1114 and adjacent to the inner surface of the gear 1115 are pinions 1116. 90

Through the bars 1105 a short distance above the upper ends of slots 1106 extend the ends of a rotary shaft 1117, upon the ends of which shaft are mutilated gear 1118, which meshes for an interval of time in rotation with the pinion 1116 on shaft 1114 and thereby forcing the block or bearing 1107 downwardly compressing the spring 1108 and bringing the toothed cutters on the roller 1112 in contact with the cotton batting. 95

On the shaft 1117 on the right hand side of the machine is a small band wheel 1119. 100

Upon the upper surface of the forward end of the upper beam 43 of the main frame of the machine and in rear of the end of shaft 1079 is journaled a stud shaft 1120, upon which is a band wheel 1121 over which and the band wheel 1119 extends an endless belt 1122. On the adjacent end of shaft 1079 is a small spur gear 1123 and on the stud shaft 1120 is a gear wheel 1124 upon the outer surface of which is a pin 1125. 1126 is a bell crank lever pivotally connected to the said outer surface of the beam 43 one arm of which lever extends to a position so as to be acted upon by the pin 1125—see Fig. 39. With the other arm of said lever is connected the forward end of the cord 1127, which cord extends rearwardly nearly to the rear end of the machine and is 115 connected with the bell crank lever 403, operating the clutch lever 395 on the standards 42 of the main frame of the machine—see Figs. 7 and 22.

The power operating the cotton batting feeding and cutting devices is transmitted from a band pulley 1128 120 on the gate raising shaft 651 through an endless belt 1129 (see Figs. 3—5—39) over the loose band wheel 1130 on the shaft 1081 carrying the cotton batting feeding endless aprons 1088. Between these band wheels 1089 and 1130 is a band wheel 1131, and upon the outer 125 end of shaft 1063 is a loose band wheel 1132, over which wheel 1132 and the band wheel 1131 extends an endless belt 1133.

The mechanism acting automatically to set in motion the cotton batting feeding devices and also arrest the movement of said devices consists of a clutch 1134 on the outer end of shaft 1081 with which is connected a clutch 5 operating lever 1135. The upper end of lever 1135 is pivotally connected at its upper end with a laterally extended bar 1136, the inner end of which bar is pivotally connected with the upper end of a post 1137 in the upper surface of the beam 1061.

10 With the lower surfaces of the guide plate 1066 a short distance upwardly from its lower end is pivotally connected a bell crank lever 1138 and upon the lower end portions of the rack bars are two lugs 1139—1139^X the lug 1139^X coming into contact with one arm of the 15 bell crank lever 1138. With the upwardly extended arm of said lever is pivotally connected one end of a rod 1140, the other end of which rod is pivotally connected with the clutch operating lever 1135.

With the lower end of the clutch operating lever 20 1135 is pivotally connected one end of a latch bar 1141 upon the lower surface of which bar is an inclined shoulder 1142 which engages with the inner surface of the beam 1062 to throw the clutch 1134 in engagement with the band wheel 1130. In order to disengage the 25 latch a bell crank lever 1143 is pivotally connected with the outer surface of beam 1062, one arm of which lever extends beneath the latch bar 1141.

With the upwardly extended arm of the bell crank lever 1143 is connected a cord 1144, the other end of 30 which cord is connected with the upwardly extended arm of a bell crank lever 1145, pivotally connected with the beam 1062 at a point about midway the ends of said beam.

With the horizontal arm of the bell crank lever is 35 connected one end of a cord 1146, the other end of which cord is connected with the shaft 1109 carrying the cotton batting cutting devices. In the rotation of the mutilated gear 1118 the movable bearings 1107 are forced downwardly in order to engage with the pinion 40 1116. In this movement the cord 1146 actuates the bell crank levers 1143 and 1145 and releases the latch 1141.

The mechanism for operating the table 1065 automatically consists of a clutch 1147 on the outer end 45 of shaft 1063, operating the table 1065, and a clutch operating lever 1148.

On the outer surface and forward end of the beam 1062 is a bracket 1149 upon the upper surface of which is pivoted horizontally a bell crank lever 1150.

50 With the inner arm of the bell crank lever is connected a link or cord 1151, the other end of which cord is connected with the clutch operating lever 1148.

With the end of the outwardly extended arm of the bell crank lever 1150 is connected one end of a cord 55 1152, the other end of which cord extends rearwardly and is connected with one arm of a bell crank lever 1153 which is pivotally connected with the outer surface of a post or block 1154, on the outer surface of the beam 1062 at a point near the corner post 41 of the main frame 60 of the machine—see Fig. 38.

Upon the upper surface and forward end of the beam 43 of the main frame is a post 1155 upon the outer surface of which is pivotally connected a bell crank lever 1156—see Fig. 42. With one arm of this lever is connected a cord 1157, the other end of which cord is con-

nected with the horizontal arm of the bell crank lever 1153 on the beam 1062.

With the vertical arms of the bell crank lever 1156 is connected one end of a cord 1158, the other end of which cord is connected with the vertical arm of the bell crank lever 877 on the post 871, this lever being actuated by the rod 876 in the descent of the gate.

With the lower end of the clutch operating lever 1148 is pivotally connected one end of a latch 1159 upon the under surface of which is an inclined shoulder 75 1160, which engages with a bar 1161 on the inner surface of the standard 1060 and which extends forward a short distance.

Upon the shaft 1063 near the inner surface of standard 1060 on the left hand side of the supporting frame 80 is a ratchet wheel 1162 and on the inner surface of the standard is a pawl 1163 engaging with the ratchet.

On the inner surface of standard 1060 are the brackets 1164, through perforations in which extend a vertically movable bar 1165. On the rear surface and near the 85 upper end of the bar 1165 is a shoulder 1166 and on the outer side of the pawl 1163 is a pin 1167, which extends transversely to and above the shoulder 1166. In order to disengage the pin from the shoulder 1166 a swinging block 1168 is pivoted on a pivot 1169, extending transversely through the upper end of standard 1060. A narrow extension of said block extends downwardly a short distance and on the outer surface and upper end of the rack bar 1068^X is a pin 1170, which contacts with the extension of block 1168 and the lower edge of 90 the body of the swinging block comes into contact with the rear surface of the upper end of the bar 1165, which bar is flexible and the shoulder is released from pin 1167 in the upward movement of the table 1065.

Upon the inner surfaces of the standard 1060 and at a 100 point a short distance upwardly from the lower end is a horizontally extended block 1171, upon the end of which is a bell crank lever 1172, the inner arm of which is pivotally connected with the lower end of the vertically movable bar 1165, the outer or vertical 105 arm of the bell crank lever is in the path of and is actuated by the contact of a horizontally and rearwardly extended hook 1173 connected with the legs 910 of the table or bench 884 when moved forward in the forward movement of the lower carriages. See Fig. 38. 110

Upon the inner side of the upper bracket 1164 supporting the bar 1165 is a bell crank lever 1174, with one arm of which lever is connected one end of a cord 1175, the lower end of which cord extends downwardly and is connected with the outer end of a bar 1176, which bar 115 is pivotally connected with the inner surface of standard 1060 and extends outwardly beneath the outer end of the latch bar 1159, and in the upward movement of the table 1065 the upper lug 1139^X on the under side of the rack bars 1068^X come into contact with the rearwardly 120 extended arm of the bell crank lever 1174, and thus releases the latch bar 1159 and the shaft 1063 ceases to operate.

In the operation of the machine power is transmitted through the belt 318 from the engine to the main shaft 125 316, and from said shaft to the principal shafts 804 through the belts 449, 802 and 806, and from thence through shaft 785 and 776 to the power conveyers for raising and lowering the material distributing hopper and distributing the material in the receptacle for the 130

mattress filling material in the lower carriages 64 which are shown in the drawings in a forward position in readiness for attaching the mattress cover, and also from said shaft 316 to the principal shaft 1081 in the supporting frame for the cotton batting feeding devices, and from said shafts to the ancillary shafts upon the machine when coupled in position. The energy of shaft 316 is also communicated to shaft 320 which transmits the power to the material conveyors 1018 and 1039, upon which the quantity of material respectively coarse and fine is placed to fill the mattress cover.

In the filling of the mattress cover initially the carriages 64 are in a forward position, as seen in Fig. 12, and the inclined pan or table 1065 is in a raised position. 15 The mattress cover supporting devices on the table 884 are moved rearwardly in position and the cotton layer drawing devices are also moved rearwardly to a position near the head block 265. The end closing gate 634 to the mattress filling receptacle is in a downward position 20 between the inwardly movable sides 127 of said receptacle and in rear of the cover grasping devices 157. The transverse shaft 81 is within the yoke bars 252—the sides 127 of the receptacle are moved in. The 25 cotton layers are spread upon the upper surfaces of the plates 107—108, forming the bottom to the mattress filling receptacle and the requisite quantity of fine and coarse material placed in the receptacle between the sides 127. The open ends of the mattress cover are placed over the bars 175 of the hinged cover grasping plates 158, and the upper ends of plates moved upwardly and secured by the plates 164. The hooks 901^X and 908 on the upper and lower cover holding bars 901 and 906 respectively are caused to engage with the open 30 ends of the mattress cover and the other or closed end is connected with the hooks 1002 on the transverse bar 1000 on the carrier 895. The main clutch operating and hand lever 584 is then operated to throw the clutch 577 in engagement with the band pulley 575 and shaft 444 is set in motion to wind the ropes 446 which raises the rear transverse track beam 426 and the upper carriages moves forward by gravity, the forward hanger bars 459 supporting the carriages 457 comes into contact with the trip lever 570 of the track closing devices and the forward and rear sections of the elevated tracks are 40 coupled together. The transverse shaft 483 on the upper carriages comes into contact with the rod or lever 632 which lever actuates the clutch operating lever 629 and causes the clutch 599^X to engage with the band 45 wheel 599 and power is communicated to shaft 442, which shaft unwinds the ropes 434—436—438, supporting the longitudinal beams 425 and these beams move 50 downwardly the required distance and the upper carriages enter the receptacle, compressing the telescopic parts of the head block 265 and compress the material between the compression plates 487—488 and the plate 107—108, the limit of the downward movement of the beams 425 being controlled by the rods 520 on said beams and the ropes 521 on the beams 43, the hooks on 55 the coupling rods 547 engaging with the loops 545 on the bar 544 on the upper carriage. In the downward movement of beam 425 the weighted end of bar 589 moves downwardly and the weight 590 draws on the rope 587 disengaging the pawl 586 from the ratchet 60 wheel on shaft 444, which shaft permits the ropes 446

to unwind and the rear ends of the track beams 455 move downwardly into a horizontal position. In the forward movement of the upper carriages 457 the shaft 483 engages with the pivoted yoke bars 532 on the standards 47, and which turn upon their pivots, are held in position by ratchet segments 536 and in the downward movement of the carriages 457 into position, the laterally extended bars 541 come into contact with the pivoted bar 538 which releases the ratchet segments 536 and the forward end of the yoke bar 532 being released drops into a horizontal position. The bar 540 on the beam 425 comes into contact with the spring held bell crank lever 335 which yields and permits the bar to pass the lever. The beam 425 also comes into contact with the arm 679 of the bell crank lever 678 connected with the hook 677 on the box or casing 668 on the forward corner post 41 which operates the lever 654 and causes the clutch 653 to transmit power to the gate raising shaft 651 from the belt 666 leading from the main shaft 316 and the gate 634 moves upwardly. 85

In the upward movement of the gate the bar 416 comes into contact with the bell crank lever 645 and the hook 151 is raised by the rope 155 from engagement with the board 145 in the guide boxes 144 on the corner posts 41, and the board moves forward, thus releasing the compression on the spring 153 on the rack bars 137 which act to close the sides 127 of the mattress filling receptacle and the sides move outwardly in position as seen in dotted lines in Fig. 9. In the downward movement of the carriages the releasing or latch plate 516 on the upper carriages comes into contact with the plate or board 268^X on the frame 264 connected with the head block 265 and the plate 516 moves upwardly releasing the shaft 504 which moves rearwardly and disengaging the hooks 510 from the loops 512 on the compressing plates 487. 95

In the upward movement of the gate 634 the transverse slideable gate bar 416 comes into contact with the end of the rock shaft 415, on the corner post 47, which operates the rod 412 and the bell crank lever 410 on standard 50 and the clutch 407 communicates power from shaft 316, through the band pulley 392 and shaft 309 and thence to shaft 305, which latter shaft winds the chains 308, connected with the connecting bar 195, to the rack bars 191, and the mattress cover is drawn forward and at the same time rotation is imparted to the large gear wheels 80, on the lower carriages, and the gear wheels 482, on the upper carriages, thence to the respective rollers on the upper and lower carriages, these rollers being successively put in motion by the triple sprocket chains 103, in the lower carriages and the triple sprocket chains 479 on the upper carriages. The open end of the mattress cover is then grasped by the jaws 491 on the endless chain 492 on the upper carriage and the jaws 117 on the sprocket chains 105 on the lower carriages—the long bar 1003 connected with the block 909, on the table 884 moves forward with the rack bars 191, carrying along the carrier 896. 110

In its rearward movement the transverse connecting bar 195 connecting rack bars 191 and traveling in the angles of guide plates 196 on the standards 47 and 50, comes into contact with the bell crank levers 382 on the sliding bars 379 in the angle plates 196, which releases the yoke bars 251 within which the transverse shaft 81 is retained during the time the lower carriages are in a for- 125 130

- ward position and the arm 1008 on pawl 1007 on the carrier on the mattress supporting table 884 comes into contact with the block 1005, on the under surface of the table 884 near its rear end, and the pawl is disengaged 5 from the rock bar 1006 and the spring 1012 recoils drawing the carrier 896 forwardly and withdrawing the hooks 901^X and 908 from the mattress cover. The rearwardly moving rack connecting bar then comes into contact with the bell crank lever 377 on the sliding bar 376, 10 supported by the angle plate 196, which operates the clutch lever 357 and the clutch 356 on shaft 320 transmits the power from shaft 316 to the shaft 296, carrying the chains 302 on the lower carriages and both upper and lower carriages are drawn rearwardly in the direction 15 of shaft 296, the lower carriages moving on the track rails 57, and as the carriages move rearwardly the cog wheels 193 on the shafts 79 on the lower carriages are caused to rotate in a reverse direction and the rollers 77 and 462 on the respective lower and upper carriages act 20 to draw the mattress cover forwardly and eject the mattress from between the rollers upon the table 884, and at the same time the head block 265 holds the material within the mattress cover and the upper compressing plates 487—488 and the lower plates 107—108 are drawn 25 from the mattress cover and off of the mattress filling material and the forward hanger bars 459 on the upper carriages come into contact with the trip levers 570 and the rack bar 566 moves rearwardly causing a reverse movement of the gear wheel 560, disengaging the hook 30 556 and 553, releasing the forward section of track 456, and the trip lever upon reaching the end of plate 567 is tripped by the hanger bar 459 and the hanger passes in rear of the trip lever, the transverse connecting bar 195 then strikes the pivoted lever 422 on corner post 42 35 which releases clutch 407 and stops the movement of shaft 305. In the rearward movement of the upper and lower carriages the coupling rod 547 meets the rods 547° on the lower track rails and releases the hooks 548 from the loops 545 on the upper carriages 457, the rear end of 40 the plate connecting shaft 503 on said carriages comes into contact with the angle plate 294 on the transverse beams 263, causing a partial rotation of the spool 507 on the shaft and the engagement of the hooks 510 with the loops 512 of the compressing plates 487. 45 In the rearward movement of the upper and lower material compressing carriages and on the upper end movement of gate 634 the projection 890^X on the legs 890 of the bench or mattress supporting table 884 comes into contact with the forward surfaces of the spring controlled movable board 145 on the forward corner posts 47 and the board moves rearwardly the hooks 151 taking a position in rear of the board and the releasing bar on the vertical plate 158 of the mattress cover grasping devices, connected with the rack bars, moves forward 50 and comes into contact with the lugs 190 on the inner surfaces of the sides 127 of the mattress filling receptacle and hinged plates 162, fall upon the telescopic plates 107—108 within the said receptacle and thereby releasing its grasp upon the mattress cover, the transverse bar 126 on the rear ends of the carriages with which the chains 302 are connected comes into contact with the vertical arm of the bell crank lever 616, on the bracket 615, on the transverse beam 263, and the clutch 602, on shaft 316, is operated to communicate power to the 55 rope winding shaft 442, through the belt 601, and the track hoisting beams 425, move upwardly and at the same time the transverse shaft 81, on the lower carriages comes into contact with the vertical portion of the latch releasing lever 366 on the upper surface of the lower beam 44, which releases the clutch lever 357 and 70 clutch 356 and the movement of shaft 320 is stopped, the cotton layer drawing devices which remained in contact with its head block now being in position at the forward end of mattress filling receptacle, spring 430 retracting beam 427. 75
- In the upward movement of the track raising and lowering beams 425, the laterally extended bar 540, near the forward surface of standard 47, before referred to, in its upward movement comes into contact with the lower surface of the bell crank lever 335, which 80 causes the clutch 328 on the shaft 320 to engage with the loose band wheel 325 and transmit power from shaft 316, through the gear 322 and 297 to shaft 296, and the lower carriages 64, move in a forward direction. At the same time the necessary quantity of coarse 85 material on the endless apron or table 1018, required to fill the mattress cover, is forced by the blast fans through the spouts 1024 into the hopper 740 and upon the doors 752 and 752^X, through the power from shaft 320 to the fan shaft 1029 and the material conveyer shafts 1019, 90 the laterally extended bar 591, before referred to, raises the weighted bar 589, which releases the tension on the rope 587, and the pawl 586 reengages with the ratchet wheel 585 on shaft 444, the inwardly extended bar 621 on said beam 425 near standard 50 moves upwardly the forward end of lever 619 on corner post 42, and the clutch 602 on shaft 316 is released from the band wheel 600, the brake block 624 locks the wheel 622 on shaft 596, and the upward movement of the 95 upper carriages are stopped. 100
- In the forward movement of the lower carriages referred to plates 107—108 which supported the head block 265 pass beneath it and the forward ends of the side closing rack bars 140 on the lower carriages come into contact with the rear surfaces of the movable 105 board 145 in standards 41 and the board moves forwardly compressing springs 153, and is engaged by the hook 151, the rack bars causing the rotation of the gear wheels 139 and the sides 127 of the receptacle on the lower carriages move inwardly in position, the ends of the transverse shaft 81 meets the yoke on yoke bar 251 which moves into a vertical position and secured by locking bar 252, the rear ends of the rack bars 140 coming into contact with the lower ends of the hooks 197 and raises the engaging portions of the said hooks from 110 the rack connecting bar 195, the rear extensions 281^X of the head block holding up the cover grasping plates 162 and preventing their fall in rear of the head block. In the forward movement of the table or bench 884, the hook 1173 on the legs 910 of said bench comes into 115 contact with the bell crank lever 1172, on the standard 1060, supporting the cotton layer feeding and cutting mechanism and the pawl 1163 on standard 1060 and the inclined pan or table 1065 moves downwardly within the guide plates 1066^X, the lower end of the 120 table extending between the sides 127 of the material filling receptacle, the lug 1139^X on the rack bars 1068^X come into contact with the bell crank lever 1138, which causes the clutch 1134 to engage with the band wheel 1130 on shaft 1081 and the layers of cotton batting 125 130

are unrolled and pass downwardly through the throat plates 1103—1104 upon the inclined pan or table 1065 to the mattress filling receptacle, and on the rotation of the shaft 1080, the pin 1125 of the gear wheel 1124 on 5 stud shaft 1120 actuates the bell crank lever 1126, and the cord 1127 extending rearwardly to the rear end of the machine and actuates the bell crank lever 403, which causes the clutch lever 395 to engage the clutch 394 and actuate the shaft 314, the cotton batting in the 10 meantime having been fed down to the plates 107—108 in the mattress filling receptacle and the forward ends pass beneath the tube 237 of the cotton layer drawing devices, which bear down upon the cotton batting and the plates 107—108, and at the same time the power is 15 conveyed through the belt 1129 and 1091 to shaft 1079, thence to shaft 1117, causing a rotation of the mutilated gear 1118, which forces downwardly the journal box 1107, and bringing the teeth 1113 on shaft 1109 in contact with the cotton batting and the cotton batting is 20 separated by the picking action of the pins, and in the interval of time in which the separation takes place of the cotton batting the cord 1146 is operated and the bell crank lever 1143 and the latch 1141 on the clutch lever 1135 is released, and the shaft 1081 ceases operation 25 and also the unwinding of the cotton batting material.

In communicating power to shaft 314, to operate the cotton layer drawing devices, the blast fans 1044 are operated from the same shaft, which fans take up the 30 fine material on the conveying aprons 1039 and delivers the material through the pipes 1033—1034 to the chute 1048 on the forward end of the main frame, which falls upon the upper surface of the cotton batting in passing within the receptacle over the plates 107—108, and 35 at the time the cotton batting is very near the head block 265, within the receptacle the pin 865, on the band wheel 864 on the corner post 42, comes into contact with the bell crank lever 863, which causes the engagement of the clutch 825, on the shaft 762, on the hopper supporting frame 756, the ropes 764 unwind and 40 the hopper 740 and the box frame 691 moves downwardly the slotted guide bars 698 spreading the sections of track 456 the brake block 844 is released from the brake wheel 766 on shaft 762, the rod 876 on the end of 45 the bar 760 connected with the hopper 740 comes into contact with the bell crank lever 877, on the upright 871 on the upper longitudinal beam 43, which actuates bell crank lever 1150 and the clutch lever 1148 and causes the clutch 1147 to engage with the band wheel 50 1132 on shaft 1063, and the inclined table 1065 moves upwardly, the pin 1170 on the rack bar 1068^X, operates to force the upper end of bar 1165 backward, releasing the pawl 1163, thereby holding the table 1065 in a raised position, the upper lug 1139^X comes into 55 contact with the bell crank lever 1174, on the upper bracket 1194 on standard 1060, which releases the latch 1159 and lever 1174, through the cord 1175 and the movement of shaft 1063 ceases. The rod 876, referred to, also comes into contact with the lever 872, on the 60 said upright 871, which releases the pawl 869, on the outer surface of beam 43 from engagement with the ratchet wheel 868 on shaft 651, supporting the gate 634, and said gate falls into position between the sides 127 of the material filling receptacle, and at the same time

the lower end of the depending bar 857 on the transverse bar 760 on the hopper 740 releases the latch 855 and the clutch lever 827 and the clutch 825 on shaft 762 and the said shaft ceases to operate and the brake block 844 holds the brake wheel 766 on shaft 762 and the downward movement of hopper 740 is checked, the box 691 65 resting on the sides of the receptacle. In the downward movement of the hopper 740, the ropes 880, connected with the doors 752—752^X are slackened and the doors move in the hinges downwardly and discharge the quantity of the mattress filling material into the 70 receptacle on the lower carriages between the sides 127, and in the same movement the bell crank lever 850 on the standard 757 comes into contact with the bar on the upper longitudinal beam 43, which operates the clutch lever 846, which causes clutch 845 to engage 75 with the loose band pulley 784 on shaft 776, and the power is communicated through sprocket chains 783 to the crank arms 720 on the hopper and through the crossed belt 780 to the shaft 702 on the box frame 691, and thence to material distributors or rods and tampers 80 on the hopper and the box frame respectively, which in their reverse movements spread the material evenly from the gate to the head blocks in one direction and from side to side of the receptacle.

The lever 824 on the bracket 823 on the transverse bar 814 on the frame 756, which comes into contact with the upper surface of the longitudinal beam 43 in the completion of the downward movement of the hopper 740, lowers the dog 822 on the gear wheel 820 and the strap 831, is wound on the shaft 819, carrying gear 820 95 during the time of the operation of the distributing devices on the hopper, and then clutch lever 826 releases the brake block 766 on the brake wheel 844 and causes the clutch 825 to engage with band wheel 765 on shaft 762^X and the hopper 740 moves upwardly, the section of track 456 are drawn toward each other and at the same time the dog 822 engages with the gear wheel 820, which acts to hold the clutch lever 826 when the lever 824 leaves the beam 43, and the action of the material distributing devices also cease when the lever 850 leaves the bar 851 on the upper longitudinal beam 43. When the bell crank lever 832 on the forward transverse bar 760 on the hopper 740 in moving upwardly meets the lower end of the fixed bar 834, on the forward transverse bar 758 of the frame 756, the dog 822 is raised in position, which 100 releases the clutch 825 and also throws on the block 766 on the brake wheel 844 on shaft 762, which stops the upward movement of the hopper 740. Another mattress cover is then connected with the cover holding and grasping devices and the hand lever 584 is again 105 operated and the operation of the mechanism is repeated. In the downward movement of the upper carriages the material is compressed within the receptacle with the weight of each carriage.

Such modifications may be employed as are within 110 the scope of the invention.

Having fully described my invention what I now claim as new and desire to secure by Letters Patent is—

1. In a material compressing machine the combination with the material supporting traveling receptacle and with the upper compressing means of rods pivotally connected with the sides of the said receptacle and hooks upon the upper ends of said rods springs connected with said rods and the sides of the traveling receptacle loops upon the 115 120 125

- compressing means adapted to be engaged by said hooks and stationary devices in the path of the lower ends of said pivoted rods.
2. In a material compressing machine the combination with the lower material supporting carriage and track rails of the upper material compressing carriage and upper suspended track rails therefor, raising and lowering means for said upper track rails and rods pivotally connected with the sides of said lower carriages forwardly directed barbed hooks upon the upper ends of said rods spring connected with said rods and the sides of said lower carriage, transverse bar upon the upper carriage and loops upon said bar adapted to be engaged by said hooks and stationary outwardly extended rods upon the lower track rails adapted to meet by the lower ends of said rods upon the rearward movement of the said carriages.
3. The combination with the upper compressing carriage and the material compressing plates secured at one end thereto, of a supporting shaft and supporting devices on said carriage within which said shaft is journaled, a hook on said shaft and a loop on said plates and means for communicating a partial rotary movement to said hook.
4. The combination with the upper material compressing carriage and the compressing plates secured at one end thereto of a longitudinal supporting shaft for said plates and separate rotatable and non rotatable sliding parts, an external spiral thread upon said the non-rotatable part and a grooved support for the latter part, a hook on said part and a loop on the compressing plate and means for imparting a forward movement to the rotatable part of said shaft.
5. The combination with the upper carriage and the material compressing plates of loops on said plates and hooks on said carriage supporting said plates having separate yielding parts.
6. The combination with the upper carriage and the material compressing plates, of loops on said plates, hooks on said carriage having separate parts, sliding connecting devices for said parts and an expanding spring.
7. The combination with the upper material compressing carriage and the compressing plates secured at one end thereto, of loops on their free ends, self extensible hooks engaging with the loops and a rocking support for said hook.
8. The combination with the upper material compressing carriage and the compressing plate secured at one end thereto, of loops on their free ends, a sliding shaft upon said carriage, a hook on said shaft engaging with said loop, means for communicating a sliding movement to said shaft in one direction and a shaft retracting spring.
9. The combination with the upper material compressing carriage and the compressing plate secured at one end thereto, of loops on their free ends, a sliding shaft on said carriage, a hook on said shaft engaging with the said loop, means for communicating a sliding movement to said shaft in one direction and a latch for holding said shaft and a retracting spring.
10. The combination with the upper material compressing carriage and the compressing plates secured at one end thereto, of loops on said plates, a longitudinally extended shaft on said carriage, having rotatable and non rotatable telescopic parts and an external screw thread upon the rotatable part of said shaft and a grooved support therefor, a spiral spring on the said rotatable portion of the shaft acting upon the non rotatable portion of the shaft to extend said portion in one direction, means for sliding the said non rotatable part telescopically in the opposite direction and a notch in the sliding part of said shaft and a depending latch, engaging with the said notch and a hook on the rotatable portion of said shaft engaging with the loops on said compressing plates.
11. In a material compressing machine for mattress covers the combination with the main frame, a lower carriage supporting the mattress cover and the upper compressing carriage, an elevated track in said frame for said upper carriage, means for raising and lowering said track compressing plates secured at one end to the ends of the respective upper and lower carriages, means for drawing a mattress cover over said plates and a frame connected with the main frame beneath which said lower carriage is movable, means for drawing the compressing plates from said mattress cover and means for drawing the said upper and lower carriages rearwardly in position and devices on the upper carriage acting automatically to raise the free ends of said upper compressing plates.
12. In a mattress filling machine a receptacle for the material comprising separate parallel carriages movable toward each other, hollow tubes in said carriages and nuts upon said tubes and shafts having right and left hand screw threads and sprocket wheels on said shafts and an endless sprocket chain.
13. In a material compressing machine the combination with the main frame and the lower receptacle for the filling material, a frame connected with the main frame having one end extending within the receptacle, hinged cover grasping plates on the sides of the receptacle, a head block supported by said frame and rearwardly extended guide plates upon the ends of the head block adapted to prevent the said hinged cover grasping plates from falling in rear of the head block.
14. In a material compressing machine a head block consisting of hollow bars telescopically connected with each other, expanding springs within said telescopic parts of the head block and retaining devices on the said bars acting to limit the withdrawal of telescopic portions thereof.
15. In a cover filling apparatus hinged cover extending devices for extending the sides of the opening in the cover.
16. In a cover filling apparatus hinged plates and cover grasping plates extending therefrom and adapted to extend the sides of the opening in a cover.
17. In a cover filling apparatus hinged plates and cover grasping extensible plates adapted to extend the sides of the opening in a cover.
18. In a cover filling apparatus the combination with a sliding plate of hinged self locking cover grasping plates for holding the sides of the opening in a cover in an open position.
19. In a cover filling receptacle the combination with its sides of plates supported thereby and separate plates hinged to the plates on the sides of the receptacle and T extensions on the latter plates adapted to extend the sides of an opening in a cover.
20. In a filling machine for mattress covers a receptacle for the material and plates supported by the sides of the receptacle and cover grasping plates hinged to the former plates and self locking devices for the hinged plates.
21. In a filling machine for mattress covers the combination with the receptacle for the material and its sides of material compressing plates and sliding cover grasping hinged plates adapted to draw a cover over said plates mounted on the sides of said receptacle, self latching devices for said plates and releasing devices on the receptacle.
22. In a filling machine for mattress covers the combination with the receptacle for the material and its sides of cover grasping devices comprising the main sliding plates mounted on the sides of said receptacle extensions at the lower ends of said plates and separate plates hinged to said extensions and securing plates hinged to the upper ends of the sliding plates engaging with the plates hinged to said extensions, and a spring latch securing the hinged plates with each other.
23. In a filling machine for mattress covers the combination with the receptacle for the material and its sides of sliding plates thereon, separate cover grasping plates hinged to the former plates and spring latches for the hinged plates and turn buttons, a pivoted releasing bar on the sliding plate adapted to come in contact with said turn button and a stationary device on the sides of the receptacle in the path of the pivoted releasing bar.
24. In a filling machine for mattress covers the combination with the receptacle for the material and its sides of sliding plates mounted thereon, power actuated devices connected with and moving said plates on said sides, hinged cover grasping plates connected with the sliding plates, self fastening devices on the hinged plates and releasing devices on said plates and stationary blocks on the sides of said receptacle in the path of the releasing devices.
25. In a cover filling machine the combination with the

- receptacle for the material and its sides and with the rollers in the bottom of said receptacle, a rotary power shaft, gear wheels on said shaft, sliding rack bars actuating said gear wheels and means for operating the rack bars, power transmitting devices acting to transmit the power from the power shaft to said rollers in succession and sliding cover grasping hinged plates mounted on the sides of said receptacle connected with the said rack bars.
26. In a cover filling machine the combination with the receptacle for the material and its sides and with rollers in the bottom of said receptacle, a rotary power shaft gear wheels on said shaft, sliding track bars actuating said gear wheels, power transmitting devices acting to transmit the power from the power shaft to said rollers in succession, sliding grasping plates for a cover mounted on the sides of said receptacle and connected with the rack bars and means on the rack bars acting to draw the grasping plates for a cover to the sides of the receptacle.
27. In a cover filling apparatus the combination with the receptacle for the material, upper and lower supporting plates for a cover, means for introducing the material between said plates, a table for supporting a cover and tension imparting devices on the table for extending a cover.
28. In a filling apparatus for covers the combination with a supporting frame of power transmitting wheels upon said frame, an endless chain upon said wheels and self releasing grasping devices upon said chain adapted to grasp a cover.
29. In a filling apparatus for covers the combination with a supporting frame, of power transmitting wheels upon said frame, endless chains upon said wheels and flexible and rigid plates connected with said chains adapted to grasp a cover.
30. In a filling apparatus for covers the combination with a supporting frame of a rotary shaft wheels on said shaft, an endless chain on said wheels, grasping devices on said chain acting to grasp a cover and means acting to feed a cover to the grasping devices.
31. In a filling machine for covers the combination with the receptacle for the material having separate extensible parts, of a table connected with the receptacle, said table having separate adjustable parts.
32. In a filling machine for mattress covers a table and a sliding carrier mounted upon said table and hanger bars extending from the carrier adapted to support a cover.
33. In a cover filling machine for mattress covers a table having a longitudinal slot, a sliding carrier within the slot on said table and bars having hooks extending from said carrier.
34. In a cover filling machine for mattress covers, a table having a longitudinal slot, a sliding carrier within the slot on said table, bars connected with the carrier and hooks thereon, adapted to support a cover and a spring acting upon the carrier to draw the hooks from the cover.
35. In a cover filling machine for mattress covers a table having a longitudinal slot, a sliding carrier within said slot and a self securing pivoted bar upon said carrier adapted to support a cover.
36. In a cover filling machine for mattress covers a table having a longitudinal slot a sliding carrier, a bar pivotally connected with the carrier and devices upon said bar for supporting a cover, a rack pivotally connected with the rear end of the said bar engaging devices on the carrier for the rack and a spring on the said carrier retaining the rack in position.
37. In a filling machine for mattress covers the combination with the receptacle for the material, of a table connected therewith, a carrier upon said table and supporting bars for a cover connected with the carrier between which a cover is adapted to be extended.
38. In a filling machine for mattress covers the combination with the receptacle for the material of a travelling supporting means on the bottom of the receptacle, means for compressing the material and a table connected with the receptacle and a carrier supported by the table and bars upon said carrier adapted to support and extend a cover.
39. In a filling machine for mattress covers the combination with the receptacle for the material, of a table connected therewith, independent supporting means within the receptacle for the material, means for compressing the material within the receptacle, grasping devices acting to draw a cover within the receptacle over the material supporting means and sliding mechanism upon the table supporting a cover in an extended position.
40. In a filling machine for mattress covers the combination with the receptacle for the material of a table connected therewith, independent supporting means within the receptacle for the material, means for compressing the material within the receptacle, grasping devices acting to draw a cover within the receptacle over the material supporting means, sliding supporting devices upon table for supporting a cover in an extended position and means self acting to withdraw the supporting devices from a cover.
41. In a filling machine for mattress covers the combination with the receptacle for the material and sliding grasping devices for cover upon the sides of said receptacle, of a table connected with said receptacle, a sliding carrier upon said table and bars connected with said carrier extending toward said receptacle and engaging devices for a cover upon said bars, a sliding block upon said table and transverse bar on said block, devices on said bar for supporting a cover, a rack bar connected with said block and supported by one of the bars on the said carrier and a pawl on the carrier engaging with the rack bar, a pin connected with the pawl and a spring connected at one end with the carrier and the other end with said sliding block, means for drawing the grasping devices for a cover upon the sides of the receptacle and means for drawing rearwardly the rack bar and a releasing or trip block on the table in the path of the pin on said pawl.
42. In a filling machine for mattress covers the combination with the receptacle for the material and rollers in the bottom of said receptacle, a rotary power shaft, gear wheels on said shaft, power transmitting devices for conveying power from said shaft to said rollers, sliding rack bars actuating said gear wheels and a connecting bar for the rack bars, a table connected with the forward end of the receptacle and a sliding carrier on said table and bars on said carrier extending toward said receptacle adapted to support a cover, a sliding block on said table and a bar connected with said block at one end and with the said connecting bar to the rack bars, a rack on the bar connected with said block and a counter balanced pawl in the carrier engaging with said rack, a coiled spring connected at one end with the carrier and with the sliding block at the other end, a transverse bar on said block and devices thereon for supporting a cover and a pin on said pawl and a trip block on the said table in the path of the said pin.
43. In a material compressing machine the combination with the main frame, a receptacle for the material, traveling supporting means for the said receptacle, a head block within the receptacle and a supporting frame therefor and adjusting devices connected with the said frame and the head block and also with said frame and the main frame.
44. In a material compressing machine the combination with the main frame, a traveling receptacle for the material, a head block within the receptacle and a supporting frame adjustably connected with the head block.
45. In a material compressing machine the combination with the main frame and a receptacle for the material and traveling supporting means for said receptacle, of a head block and a supporting frame, extensible sides to said frame and vertically adjustable supporting devices for said frame connected therewith and with said main frame and the said head block.
46. In a material compressing machine the combination with the main frame, a receptacle for the material and a head block within the receptacle, means for moving the receptacle in the direction of the head block and a supporting frame, rotary shafts journaled at their ends in the ends of said frame and bars connected with said main frame and extensions of said bars having racks and gear wheels on said shafts engaging with said racks.
47. The combination with the lower material supporting carriages and the sliding rack bars, of means for drawing the said rack bars and also said carriages rearwardly in

- position and self engaging means on the rear ends of said carriages and engaging with the rear ends of the rack bars upon the rearward movement of the carriages.
48. The combination with the lower material supporting carriages and the sliding rack bars, of means for drawing the rack bars and also said carriages rearwardly in position, hooks upon said carriages and pivoted bars supporting said hooks, devices in the rack bars with which the hooks engage and means in the path of the said bars for releasing the said hooks.
49. The combination with the lower material supporting carriage and the sliding rack bars and a connecting bar of hooks on the carriages, means for releasing the hooks from the connecting bar and means in the hooks self acting to hold said hooks from engagement.
50. The combination with the lower material supporting carriages and the sliding rack bars and a connecting bar of hooks on the carriages engaging with the said bar, means for disconnecting the hooks from the said bar and auxiliary self expanding bars on the said hooks.
51. The combination with the main frame, the lower material supporting carriages, the track rails, sliding rack bars on said carriage and rods in suitable supports upon the sides of said carriage, retracting springs connected with said rods, devices in the path of the forward end of the said rods on the main frame and hooks on said carriages engaging with the rack bars and releasing devices for said hooks in the path of the rear ends of said rods.
52. The combination in filling machine for mattress covers with the lower carriages and the movable sides of brace bars upon said carriages and sliding supports for said sides upon said brace bars, vertical shafts upon said carriages and devices upon said shaft for moving the sides inwardly and outwardly in position and a gear upon the lower ends of the said shaft and recoiling rack bars upon said carriages actuating said gear.
53. The combination in a filling machine for mattress covers with the lower carriages and the movable sides of brace bars upon the outer sides of said carriages and sliding pins supporting said sides extending through said brace bars, vertical shafts and supports therefor upon the brace bars, gear wheels upon said shaft and rack bars connected with the said sides and actuated by said gear wheels, horizontal bars on suitable bearings upon the sides of said carriage and racks upon said bars and gear wheels on the lower ends of the vertical shafts engaging with said rack bars, springs acting to move said rack bars in one direction and devices in the path of said rack bars for moving the said bars in the opposite direction.
54. The combination with a suitable carriage and the track rails and with the rack bars journaled upon the sides of the carriage of a spring actuating said bars in one direction, a frame and a sliding device on the frame in the path of the said bars, means for holding said carriage from movement, a catch for holding the sliding devices in a retracted position and a spring acting to move said devices in the direction of the said bar upon the release of the catch.
55. In a filling machine for mattress covers the combination with the main frame, the lower carriages and track rails, movable sides to said carriages and brace bars upon said carriages, sliding supporting devices for said sides upon said brace bars and rack bars extending outwardly from said sides, arms supporting said bars, vertical shafts upon said carriages and cog wheels upon said shafts engaging with the rack bars on said sides, longitudinally extended sliding bars upon the sides of said carriages and gear wheels upon said shafts engaging with said rack bars, lugs on said bars and coiled springs extending around said bars bearing upon said lugs at one end and at the other end upon the supporting arms, a sliding board on the main frame in the path of said bars and boxes upon said frame for the ends of said board, pivoted bars upon said main frame and springs upon said bars and adapted to be contracted in the forward movement of the sliding board and hooks upon said pivoted bars engaging with said sliding board.
56. The combination in a filling machine for mattress covers with the main frame of a receptacle for the material and movable sides, supports for said sides and mechanism acting to move said sides inwardly and outwardly in position, an end gate to said receptacle hoisting mechanism upon said main frame for the end gate, power storing reacting devices on said frame actuating the side moving mechanism to the receptacle when released and releasing devices actuated by the gate in its upward movements.
57. The combination with the main frame and the lower material compressing carriages of inwardly movable sides to said carriages and devices actuating said sides, a traveling bench or table connected therewith, means for moving forwardly and rearwardly said compressing carriage and a sliding board on the forward end of the said main frame and springs actuating the board rearwardly in position, recoiling mechanism connected with and actuating said side moving devices and also contacting with said movable board and moving said board forwardly and compressing said springs, a hook engaging with said movable board, a vertically movable end gate upon the main frame and sliding devices on said frame connected with the said hook and actuated by said end gate in its upward movement to release said hook and devices on the said bench contacting with the said board on the rearward movement of said carriages.
58. The combination with the main frame and the lower material compressing carriages and the sliding rack bar and a connecting bar, a main driven shaft and a power driving shaft and power transmitting devices connecting said shafts, draft devices on the driven shaft connected with the rack bar and a lever on the main frame adapted to be actuated in the rearward movement of the rack connecting bar and power disconnecting devices on the main shaft connected with said lever.
59. The combination with the main frame and the receptacle for the material of an end gate, a rotary shaft upon said frame, hoisting devices upon the shaft for said gate and means upon said frame self acting to raise and lower said gate.
60. The combination with the main frame and the receptacle for the material of an end gate a rotary shaft upon said frame, hoisting devices upon said shaft for said gate, a ratchet wheel on said shaft and a pawl, means for communicating power to said shaft and hoisting said gate and means for releasing said pawl.
61. The combination with the main frame and the receptacle for the material and a carriage supporting said receptacle and the track of means for imparting tractive power to the said carriage and self coupling devices on said frame and carriage.
62. The combination with the main frame and the receptacle for the material and the carriages supporting said receptacle and the track rails of a transverse shaft on said carriages, pivoted yoke bars on said frame and means for locking said bars.
63. The combination with the main frame and the movable carriages and the track rails of a transverse shaft on said carriages, yoke bars pivoted on said frame, adapted to couple with said shaft, self locking devices for the yoke bars on said frame, means for releasing said yoke bars and gravitating weights on said bars.
64. The combination with the main frame and the lower carriages and track rails of a transverse shaft on said carriages, yoke bars pivotally connected with said frame, adapted to couple with said shaft, self locking devices for the yoke bars and means for releasing said devices.
65. The combination with the main frame and the lower carriages and track rails of a transverse shaft on said carriages, pivoted bars on said frame having an upper forked end, a hinged bar on said frame, having a hook upon one end engaging with said pivoted bar, a bolt extending through said hinged bar and a spring upon said bolt, bearing inwardly against said bar and a crank arm upon said frame adapted to move said bar outwardly and disengage said bar from said pivoted bar.
66. The combination with the main frame and the lower carriages and the sliding rack bars and the transverse connecting bar, of means for drawing said rack bars rearwardly, a pivoted yoke bar on said frame, a transverse shaft on said carriages adapted to be coupled with the yoke bar, a locking bar on said frame for said yoke

- bars, releasing devices for the locking bar and mechanism actuating said releasing devices in the path of the connecting bar for the rack bars. 77. The combination with the main frame, the vertically movable carriage raising and lowering beams, the upper compressing carriages and the raising and lowering cables and the cable winding shaft connected with said cables of the lower carriages the sliding rack bars and connecting bars, a main power rotary shaft and a rotary power driven shaft on said frame and power transmitting devices connected therewith and said cable winding shafts, power connecting and disconnecting devices connected with the main shaft, a lever on the main frame actuated by the connecting bar to the rack bars in its rear movement. 85 90 95
67. The combination with the main and the lower 5 carriages, the tracks therefor and the sliding rack bars and transverse connecting bar of guiding plates for the ends of the connecting bar on the main frames, a pivoted yoke bar on the main frame, a transverse shaft on said 10 carriages adapted to be coupled with the yoke bars, locking bars on said frame for the yoke bars, releasing devices on said frame for the locking bars, sliding bars on the guiding plates for the connecting bar to the rack bars and connecting devices connecting said bars with the releasing devices, bell crank levers on the guiding plates connected with the sliding bars actuated by the said 15 connecting bar to the rack bars and openings on the guiding plates for the bell crank levers and springs for returning said levers to a normal position. 160
68. The combination with the main frame of the machine and the upwardly and downwardly movable carriage supporting beams, means for raising and lowering said beams and adjustable suspensory devices connected with said beams and said main frame. 78. The combination with the main frame, the vertically 95 movable carriage raising and lowering beams, the upper compressing carriages and the raising and lowering cables and the cable winding shaft, the lower carriages, the main rotary driving shaft and a rotary driven shaft on said frame and power transmitting devices connected therewith, power connecting and disconnecting devices connected with the main shaft and a recoiling lever upon 100 the main frame connected with the power connecting and disconnecting devices and disconnecting said power and devices on the lower carriages adapted to contact with said lever on its rearward movement. 105
69. The combination with the main frame the longitudinally 20 vertically movable carriage supporting beams on said frame, raising and lowering means therefor and ropes on said main frame and rods on said beams and adjusting nuts connected with the said rods and the said ropes. 79. The combination in a material compressing machine 105 with the upper and lower compressing members and with transverse power transmitting shafts thereon of differential gear on said shafts meshing with each other.
70. The combination with the main frame and the longitudinally 25 extended vertically movable carriage supporting beams of auxiliary pivoted track beams adapted to be inclined in position. 80. The combination in a material compressing machine 110 with the upper and lower compressing members and transverse power transmitting shafts thereon of adjustable differential gear on said shafts meshing with each other. 115
71. The combination with the main frame the longitudinally 30 extended vertically movable carriage supporting beams, raising and lowering means therefor, auxiliary pivoted track beams on the vertically movable beams and means for inclining said auxiliary track beams. 81. The combination in a mattress filling machine with the main frame of the machine and the lower carriage and the track rails of elevated track rails, and raising and lowering devices therefor rearwardly movable suspended upper carriages upon the upper track rails and vertical coupling bars on the sides of the lower carriage and slotted plates upon the sides of the upper carriages adapted to receive said bars when said upper carriages are lowered in position and means for moving said upper and lower carriages rearwardly in position simultaneously. 120 125
72. The combination with the main frame and the longitudinally 35 extended vertically movable carriage supporting beams, of auxiliary pivoted track beams pivoted at their forward ends to the vertically movable beams and raising and lowering devices for the rear ends of said auxiliary track beams. 82. The combination in a material compressing machine 130 with the upper and lower compressing carriages and with transverse power transmitting shafts on said carriages and devices actuated by said shafts to draw a cover between said carriages of adjustable differential gear on said shafts meshing with each other. 135
73. The combination with the main frame and the longitudinal carriage supporting vertically movable beams, of auxiliary track beams pivoted at their forward ends to the said vertically movable beams, a transverse shaft on the main frame and raising and lowering devices thereon connected with the rear ends of said auxiliary track beams. 83. In a mattress filling machine the combination with the receptacle for the material, a carriage supporting said receptacle, a head block within the receptacle, an upper compressing carriage and an elevated track, track beams for said carriages supporting the track, means for raising and lowering the track supporting beams, and a vertically adjustable frame connected with the head block and said main frame. 140
74. The combination with the main frame and the longitudinal carriage supporting vertically moving beams of raising and lowering devices therefor, auxiliary track beams pivoted to said vertically movable beams, a rotary shaft upon said main frame and raising and lowering devices thereon for said auxiliary track beams, power transmitting means for communicating power to said shaft and raising the auxiliary track beams and securing devices on 145 said shaft and main frame for holding said shaft from reverse movement and releasing devices operated by the vertically moving beam to release the securing devices upon the downward movement of said beams. 84. In a mattress filling machine the combination with the main frame, the lower carriages and the material compressing plates and with the upper carriage and the upper material compressing plates elevated track rails for the upper carriage and means for raising and lowering said track rails, means on the upper carriages and upper compressing plates for securing the free ends of said plates, means for drawing a cover over said upper and lower plates, a head block on the lower carriages and a vertically adjustable frame supporting the head block connected with the main frame and devices on the said frame releasing the plate engaging devices on the downward movement of the carriages. 150
75. The combination with the main frame and the vertically 150 movable carriage raising and lowering beams, of a rotary power shaft and auxiliary track beams pivoted to said vertically movable beams, means for raising and lowering said latter beams, and raising and lowering devices on said rotary shaft connected with the auxiliary track beams, a ratchet wheel on said rotary shaft and a self acting pawl on the main frame, a lever pivoted on the main frame and a weight, a connecting rope or cable connected with the said lever and said pawl and a bar on the vertically movable beam beneath said lever. 85. The combination with the main supporting frame of a main track having a movable section of track rails and means for coupling the ends of the movable section with the ends of the main track rails. 155
76. The combination with the vertically movable carriage supporting beams of pivoted auxiliary track beams, means for elevating the ends of said beams and traveling devices supported by the auxiliary track beams and means for reversing the direction of movement of the traveling devices. 86. The combination with the main supporting frame of a main track movable sections of track rails, carriages upon the main track rails and coupling devices for coupling the end of movable sections of the rails with the ends of the main track rails. 160
77. The combination with the main supporting frame of a main track and movable sections of track rails, carriages

- upon the main track rails and mechanism actuated by the carriage in passing over the track, rails for coupling and uncoupling said section of track rails with the main track rails.
- 5 88. The combination with the main supporting frame, an elevated main track and laterally movable sections of the track and mechanism for drawing said movable sections in alignment with the main track rails.
89. The combination with the main supporting frame, 10 the longitudinal vertically movable carriage supporting beams, the transverse track beams and traveling supporting devices therefor on the longitudinal beams of the longitudinal main and sections of track rails, carriages upon said track rails, means for moving the sections of parallel track rails laterally in position on the transverse track beams, transverse bars connected with the parallel track rails on the respective main and sectional track rails and self engaging devices on said bars engaging with each other.
- 10 90. The combination with the main supporting frame the longitudinal vertically movable carriage supporting beams, the transverse track beams and traveling supporting devices therefor on the longitudinal beams and hangers on the transverse beams and longitudinal main and sections of track rails supported by said hangers, material compressing carriages and hangers upon said longitudinal track rails connected with said carriages connecting devices for connecting the ends of the main and sectional track rails and a lever actuating said devices in the path of 30 one said hangers supporting the carriage.
91. The combination with the main supporting frame, the longitudinal vertically movable carriage supporting beams, the transverse track beams and traveling supporting devices thereon on the longitudinal track beams, hangers on said transverse beams and longitudinal main and sections of parallel track rails connected with said hangers, material compressing carriages and hangers upon the said longitudinal track rails connected with said carriages, transverse connecting bars connected with the adjacent 40 ends of the main and sections of parallel track rails, hooks upon said transverse bars, and a sliding plate actuating one of said hooks and an operating wheel with which the said sliding plate is eccentrically and pivotally connected.
92. In a filling machine for mattress covers the combination with the main frame and the compression carriages of elevated main and sections of parallel track rails and transverse supporting track beams and means self acting to move said sections of track rails laterally in position upon said beams.
- 45 93. In a filling machine for mattress covers the combination with the main frame and sections of parallel track rails and the transverse track beams supporting said main and sections of parallel track rails, means for raising and lowering said transverse beams, track rail drawing devices acting to draw the ends of the rails in the track sections in alignment with the ends of the main track rails, a sliding rack bar on one of the track rails communicating powers to the track rail drawing devices and a trip lever connected with the track bar and adapted to move with the 50 rack bar in the forward and rearward movement of the carriages and a spring for holding said trip lever in a normal position.
94. In a mattress filling machine the combination with the upper material compressing carriages and with the longitudinal track rails supporting said carriages, a guide plate upon the lower surface of said rails having notches at the ends of a flange on the side of the rail and a lip, a movable bar within the said flange supported by said lip, a T trip lever pivotally connected with the sliding bar 60 adapted to enter said notches and spring plate on the ends of said guide plate.
95. In a filling machine for mattress covers the combination with the receptacle for the material and with material compressing mechanism of material feeding mechanism co-acting to impart alternate reciprocal movements to and from the receptacle.
- 65 96. In a material compressing machine the combination with the receptacle for the material of a vertically movable self discharging hopper for the material.
- 70 97. In a material compressing machine the combination with the receptacle for the material of a movable hopper raising and lowering devices therefor and means acting to discharge the quantity of the material to be compressed from the hopper.
- 75 98. In a material compressing machine the combination with the main frame and the receptacle for the material, a movable hopper raising and lowering devices therefor and a bottom within the hopper having hinged parts and devices on the main frame supporting said parts and adapted to release said parts upon the downward movement of the 80 hopper.
99. In a material compressing machine the combination with the main frame and the receptacle for the material, of a movable hopper and a supporting frame for said hopper and a sliding bar within said frame connected with the hopper, raising and lowering devices for the hopper, a bottom to said hopper having hinged parts, pins connected therewith, sheaves on the said sliding bar and a cord connected with said pins extending over said sheaves and connected with the hopper supporting frame.
100. In a material compressing machine the combination with the main frame, the longitudinal vertically movable carriage supporting beams and means for raising and lowering said beams of a material discharging hopper supported by said beams.
- 105 101. In a material compressing machine the combination with the main frame the longitudinal vertically movable supporting beams and means for raising and lowering said beams, a hopper and a frame supporting said hopper mounted on said supporting beams and raising and lowering means on the hopper supporting frame for said hopper.
- 110 102. In a material compressing machine the combination with the main frame the receptacle for the material longitudinal vertically moving supporting beams and means for raising and lowering said beams of a hopper mounted on said supporting beams, material compressing means adapted to be extended within the receptacle, raising and lowering devices for said hopper and raising and lowering devices for said material compressing means and power actuated mechanism connected with and imparting movement to said raising and lowering devices to said hopper and to said compressing means alternately.
- 115 103. In a material compressing machine the combination with means for compressing the material of means self acting to distribute the material within the receptacle.
- 120 104. In a material compressing machine the combination with the receptacle for the material of a hopper and material distributing devices upon the hopper movable in opposite directions within the receptacle.
- 125 105. In a material compressing machine the combination with the receptacle for the material of a hopper material distributing and tamping devices on said hopper and devices acting to impart alternate opposite movements to said distributing and tamping devices.
- 130 106. In a material compressing machine the combination with the receptacle for the material and with material distributing devices acting to distribute the material within the receptacle of a material retaining frame adapted to be mounted upon the sides of the receptacle to prevent scattering of the material.
- 135 107. In a material compressing machine the combination with the receptacle for the material of a material retaining frame, adapted to be seated upon the sides of the receptacle and material distributing devices upon said frame.
- 140 108. In a material compressing machine the combination with the receptacle for the material of a hopper and a material retaining frame extending around the lower portion of the hopper and supported thereby, means on the hopper and frame for distributing the material within the receptacle and means for compressing the material after distribution.
- 145 109. In a material compressing machine the combination with the receptacle for the material of a hopper and discharging means within the hopper for discharging into the receptacle the quantity for compression, means extending around the lower portion of the hopper for preventing scattering and devices on the hopper for distributing the material within the receptacle discharged from the hopper and compressing means acting to compress the material within the receptacle.
- 150 110. In a material compressing machine the combination with the receptacle for the material of a hopper and discharging means within the hopper for discharging into the receptacle the quantity for compression, means extending around the lower portion of the hopper for preventing scattering and devices on the hopper for distributing the material within the receptacle discharged from the hopper and compressing means acting to compress the material within the receptacle.
- 155 111. In a material compressing machine the combination with the receptacle for the material of a hopper and discharging means within the hopper for discharging into the receptacle the quantity for compression, means extending around the lower portion of the hopper for preventing scattering and devices on the hopper for distributing the material within the receptacle discharged from the hopper and compressing means acting to compress the material within the receptacle.
- 160 112. In a material compressing machine the combination with the receptacle for the material of a hopper and discharging means within the hopper for discharging into the receptacle the quantity for compression, means extending around the lower portion of the hopper for preventing scattering and devices on the hopper for distributing the material within the receptacle discharged from the hopper and compressing means acting to compress the material within the receptacle.

110. In a filling machine for mattress covers the combination with the main frame and the receptacle for the material of a vertically movable hopper material distributing devices on the hopper and a guiding frame for said hopper, a rotary shaft upon said hopper, raising and lowering devices on the hopper and rotary power transmitting shafts on said hopper and said hopper supporting frame, a balanced arm on one of the said rotary power transmitting shafts on said frame and power transmitting devices on said shafts and said arm and the shaft on said hopper and power transmitting devices on the latter shaft transmitting power to the material distributing devices. 85
111. The combination with a receptacle for the material of distributing devices adapted to be extended within said receptacle and a supporting frame and crank arms for communicating motion to said devices on said frame. 90
112. The combination with the hopper of distributing rods upon said hopper, bearings upon said rods on the hopper and crank arms for communicating vibratory movement to said rods. 95
113. The combination with the hopper and with perforate plates thereon and distributing rods within said plates and perforate plates connected with the upper ends of said rods thimbles on said plates, shafts on the hopper and crank arms on said shafts. 100
114. The combination with a receptacle for the material of a hopper crank arms upon said hopper and reciprocating material distributing devices upon the crank arms. 105
115. The combination with the receptacle for the material and a suitable supporting frame adapted to be supported upon the sides of the receptacle of material distributing rods having heads, perforate plates through which said rods extend thimbles on said plates and crank arms within said thimbles and lugs on said rods and springs between said plates and lugs. 110
116. In a filling machine for mattress covers the combination with the hopper of an adjustable frame and adjustable shafts upon said hopper supporting the said frame. 115
117. In a filling machine for mattress covers the combination with a suitable supporting frame with the material distributing rods and the crank arms supporting said rods of shafts with which arms are connected and power transmitting devices on said shafts and means for reversing the movements of said shafts. 120
118. In a filling machine for mattress covers the combination with a hopper, a frame extending around said hopper, a supporting means on said hopper connected with said frame, material distributing devices on said frame and hopper, a rotary shaft on said frame and power transmitting devices on said shaft and said frame actuating the distributing devices. 125
119. In a filling machine for mattress covers the combination with a hopper, a frame extending around said hopper, supporting means on said hopper connected with said frame, a rotary power shaft on said frame, material distributing and tamping devices on said frame and hopper, power transmitting devices on said shaft and said frame, actuating the material distributing devices and tamping devices. 130
120. In a filling machine for mattress covers the combination with a supporting frame, a vertically movable hopper, raising and lowering means therefor, power actuated mechanism communicating power to the lowering means and causing the descent of the hopper and mechanism acting to reverse the power and actuate the raising means. 135
121. In a filling machine for mattress covers the combination with a supporting frame of a movable hopper material distributing devices on said hopper raising and lowering means for said hopper, power actuated mechanism for actuating the raising and lowering means to said hopper and transmitting power to said material distributing devices and power reversing mechanism on said hopper controlling the upward movement of the hopper. 140
122. In a filling machine for mattress covers the combination with the main frame a movable hopper and a hopper supporting frame, raising and lowering means on the same frame for the hopper material distributing de- 145
123. In a filling machine for mattress covers the combination with the hopper and hopper raising and lowering mechanism, the main power shaft and the power transmitting devices from said shaft to said raising and lowering mechanism, of engaging and disengaging devices on the power shaft, a lever actuating said devices and a driven wheel and a projection on said wheel actuating the said lever in its rotation. 150
124. In a filling machine for mattress covers the combination with a supporting frame of a movable hopper, raising shafts on said frame and lowering means for the hopper on said shafts, reverse power transmitting devices for transmitting power from one shaft to the other and a brake and brake lever and power transmitting devices loosely connected with said shaft, mechanism for connecting and disconnecting the loose transmitting devices with the said shafts and actuating the brake lever. 155
125. In a filling machine the combination with laterally movable track rails of a vertically movable frame between the said rails, raising and lowering devices for said frame and sliding connecting devices connecting said rails and said frame. 160
126. In a filling machine the combination with a supporting frame and laterally movable elevated track beams on said frame of a vertically movable frame, inclined slotted guide plates on the said movable frame and supporting axles or journals, wheels on the ends of the journals extending respectively within the slots in said guide plate and also supported by said track beams and means for raising and lowering said frame. 165
127. In a filling machine the combination with a supporting frame and laterally movable elevated track beams on said frame of a vertically movable frame having extensible parts upwardly and outwardly inclined slotted guide plates on the said movable frame and supporting axles or journals, wheels on the ends of the journals extending respectively within the slots in said guide plates and also bearing upon said track beams and raising and lowering devices for said movable frame. 170
128. In a filling machine for mattress covers the combination with the main frame and elevated main tracks and laterally movable sections of track rails, a vertically movable frame adapted to move between said movable sections and means therein and upon said sections of track for moving said sections to and from each other and coupling devices for coupling said main and sections of track rails. 175
129. In a filling machine for mattress covers the combination with the main frame and elevated main tracks and laterally movable sections of track rails and with compression carriages upon said track rails of a vertically movable frame adapted to move between said movable sections, means on said frame for moving said sections in opposite directions, means for moving said frames and fastening devices for said movable sections of track rails on the main tracks and means actuated by the carriages for operating the rail fastening devices. 180
130. In a filling machine for mattress covers the combination with the main frame and the longitudinal carriage supporting beams and the transverse track beams of parallel main track rails and sections of main track rails and hanger frames supporting said main and section of track rails and rollers within said frames mounted on the transverse track beams, having extended journals, a frame adapted to be extended between the parallel sections of track rails and upwardly and outwardly inclined grooved plates on said frame and a roller within the grooves mounted on the extended journals of said rollers in the hanger frames and raising and lowering means for said frame. 185
131. In a filling machine for mattress covers the combination with the main frame and the longitudinal carriage supporting beams and the transverse track beams of parallel main track rails and sections of main track rails and hanger frames supporting said main and section of track rails and rollers within said frames mounted on the transverse track beams, having extended journals, a frame adapted to be extended between the parallel sections of track rails and upwardly and outwardly inclined grooved plates on said frame and a roller within the grooves mounted on the extended journals of said rollers in the hanger frames and raising and lowering means for said frame. 190

- nation with the main frame the elevated main track and laterally movable sections of track rails and a receptacle for the material of a vertically movable hopper and a hopper supporting frame, material distributing devices on the hopper, material compressing carriages on the said main tracks and a main driving shaft on the main frame, mechanism on the hopper and hopper supporting frame actuated by the power shaft for lowering the hopper and devices actuated by the hopper for moving outwardly and inwardly the movable track sections, mechanism on the hopper communicating power to and actuating the material distributing devices on the hopper and mechanism acting to raise the hopper after the discharge of the material and its distribution within the receptacle, means for connecting the ends of main and sections of track rails and devices acting to move the carriages upon the track rails to a position above the receptacle and raising and lowering devices acting to lower the carriages and compress the material.
132. In a filling machine for mattress covers the combination with the main frame and the receptacle for the material of a longitudinal carriage supporting beams, raising and lowering means therefor on the main frame and main driving shaft, a vertically movable end gate to the receptacle and a rotary shaft on said main frame and raising and lowering devices on said shaft for the said gate, power transmitting devices transmitting power from the main driving shaft to the shaft supporting said gate devices for connecting the power from the main driving to the rotary shaft actuated by the said carriage supporting beams in their downward movement and raising the gate.
133. In a filling machine for mattress covers the combination with the main frame and the receptacle for the material of a vertically movable end gate, upper and lower compressing carriages for compressing the material and compressing plates, a main driving shaft on said main frame, rotary winding shafts actuated by the main shaft, power controlling devices on the main shaft and winding and unwinding devices on the winding shafts connected with the respective upper and lower carriages, means on said carriages for drawing a cover over said plates, a rack shaft on the said frame actuated in the upward movement of the said gate and a link connecting the rack shaft with the power controlling devices on the main shaft.
134. In a filling machine for mattress covers the combination with the main frame and the receptacle for the material of a vertically movable end gate, a rotary shaft on said frame and raising and lowering devices thereon connected with the end gate, a ratchet wheel on the said shaft and a self engaging pawl on the main frame, a vertically movable hopper on the main frame and mechanism actuated by the hopper in its downward movement to release the said pawl.
135. The combination with the main frame and the receptacle for the material of an end gate, a rotary shaft upon said frame, hoisting devices upon said shaft for said gate, a ratchet wheel on said shaft, a self engaging pawl on said main frame engaging with the ratchet wheel, a vertically movable hopper on said main frame and a transverse supporting bar on said hopper and a rod on said bar, a post on the main frame, a bell crank lever on said post in the path of and actuated by said rod and a rod connecting the bell crank lever and said pawl.
136. In a filling machine for mattress covers the combination with the main frame and the elevated carriage supporting tracks and the upper and lower material compressing carriages, the rack bars and the connecting bar of guide plates on the main frame for the ends of the connecting bar, rotary winding shafts on said main frame and winding and unwinding devices thereon connected with the respective carriages, a main driving shaft on said main frame and power transmitting devices connected therewith and the rotary winding shaft power controlling devices on the main shaft and devices on the guide plate in the path of the connecting bar to the rack bars actuating the power controlling devices on the said main shaft.
137. In a filling machine for mattress covers the combination with the receptacle for the material, of means acting to feed layers of fibrous material within the receptacle and material compressing means and a hopper and mech-
- anism coacting to discharge the material from the hopper within the receptacle.
138. In a filling machine for mattress covers the combination with the receptacle for the material of sliding grasping devices for drawing layers of fibrous material within the receptacle and means for operating said devices.
139. In a filling machine for mattress covers the combination with the receptacle for the material of sliding layer grasping devices within the receptacle having adjustable parts.
140. In a filling machine for mattress covers the combination with the receptacle for the material and the sides to said receptacle of a sliding apparatus upon the sides of the receptacle and a layer grasping device within the receptacle coacting to grasp layers of fibrous material.
141. In a filling machine for mattress covers the combination with the receptacle for the material and the sides of said receptacle of self locking fabric drawing sliding devices mounted upon and engaging with said sides and releasing means therefor.
142. The combination with the receptacle for the material and the sides of said receptacle of a sliding plate, a guide block upon the sides of said receptacle, a pivoted oscillating securing device on said sliding plate adapted to engage with said guide block.
143. The combination with the receptacle for the material and the sides of said receptacle of a sliding plate and a runway or guide block upon said sides, having a return bent portion and a groove, an extension plate on the sliding plate extending within the said groove, having an opening, a vibrating locking bar on the sliding plate, having one end extending within said opening, a spring acting to retain said end within said opening, said guide block having notches adapted to be engaged by the locking bar and means for releasing said locking bar.
144. The combination with the receptacle for the material and the sides of said receptacle of sliding plate mounted thereon, self engaging devices on said plate engaging with the sides of the receptacle, suitable bearings upon the sliding plate and rock shaft arms on said shaft, a vibrating inrawing fabric grasping device within the receptacle, power transmitting devices connected therewith and also with one of the arms on the rock shaft and operating devices connected with the other arm of the rock shaft.
145. The combination with the receptacle for the material and the sides of said receptacle of sliding plates mounted thereon, self locking pivoted oscillating bars upon said plates having upwardly extended portions and securing means on the sides of the receptacle with which portions of the locking bar is adapted to engage bearings on the said sliding plates and rock shafts on said plates, arms on said rock shafts which arms are adapted to come into contact with and act as a brake to the upturned portions of the locking bars, pulleys on the sliding plates and operating cables connected with the arms on the rock shafts and extending over said pulleys.
146. The combination with the receptacle for the material and the sides of said receptacle of a sliding plate mounted thereon, pivoted locking bars upon said plates, having vertically extended rear end portions and securing means for said bars upon the forward ends and the sides of the receptacle and vertical plates upon the locking plates, between said ends bearings on the sliding plates rock shafts on said bearings, arms on said shaft adapted to come into contact with and act as a brake to the upwardly extended portions of the locking bars pulleys on the sliding plates and operating cable connected with the arms on the crank shaft and extending over said pulleys and blocks on said cables adapted to come into contact with the vertical plates on the locking bars.
147. The combination with the receptacle for the material and the sides to said receptacle of sliding plates therein having upward extensions rock shafts journaled therein and arms on the outer and inner ends of the rock shafts, locking devices on the outer side of the sliding plates adapted to hold said sliding plate from movement, downwardly and forwardly extended portions of the sliding plates within the receptacle and a pivoted frame on said plates adapted to be vibrated, bell crank levers on

- said plates and ropes connecting the said levers with the said frame, rods connected with the said bell crank levers and the arms on the outer ends of the rock shafts, pulleys on the sliding plates and operating cables connected with 5 the arms on the outer ends of the rock shaft, extending over said pulleys and means actuated by the cable to release the locking devices on the sliding plates.
148. In a cover filling machine the combination with the inner frame, a forwardly and rearwardly movable carriage 10 and a receptacle for the material upon said carriage of a head block within said receptacle and stationary supporting devices therefor upon the main frame, means for operating the said carriage and self engaging layer drawing device upon the sides of said receptacle adapted to 15 come into contact with the head block and engage with the sides of the receptacle.
149. In a cover filling apparatus the combination with the receptacle for the material of material compressing plates within the receptacle, means for introducing the 20 filling material between the plates and means for drawing layers of fibrous material within the receptacle between said plates.
150. In a cover filling apparatus the combination with the receptacle for the material of upper and lower material 25 compressing plates, means for drawing layers of fibrous material between said plates and means for introducing the filling material between said plates and devices upon the receptacle for drawing a cover over the said plates.
151. In a cover filling machine the combination with the 30 main frame and the upper and lower material compressing carriages and vertically movable track rails supporting said upper carriage of material compressing plates upon said carriages, raising and lowering means for said track rails, means for introducing the filling material between 35 said plates and devices on the sides of the receptacle for drawing layers of fibrous material between said plates and power actuated devices communicating power to the layer drawing devices and sliding grasping devices on the sides of the receptacle for drawing a cover over said plates and 40 means on said main frame communicating power to said cover grasping devices.
152. In a filling machine for mattress covers the combination with the receptacle for the material of an inclined sliding table or pan adapted to be extended within 45 and withdrawn from the receptacle.
153. In a filling machine for mattress covers the combination with the receptacle for the material of an inclined sliding table or pan adapted to be extended within and withdrawn from the said receptacle and raising and 50 lowering means for said table.
154. In a filling machine for mattress covers the combination with the receptacle for the material of an inclined sliding table or pan, said pan having adjustable parts.
155. In a filling machine for mattress covers the combination with the receptacle for the material of a supporting frame rollers upon said frame adapted to support 55 layers of fibrous material and mechanism self acting to communicate power to the rollers and feed the layers toward the receptacle.
156. In a filling machine for mattress covers the combination with the receptacle for the material of a supporting frame, rollers upon said frame adapted to support 60 layers of fibrous material and sliding layer grasping devices upon said receptacle.
157. In a filling machine for mattress covers the combination with the receptacle for the material and a supporting frame of rollers upon said frame adapted to support 65 layers of fibrous material and a sliding layer grasping table, means for raising and lowering said table and sliding layer grasping devices on the receptacle and means for communicating power to said devices.
158. In a filling machine for mattress covers the combination with the receptacle for the material and a supporting frame of rollers upon said frame adapted to support 70 a continuous length of fibrous material and means self acting to separate the fibrous material in divisible parts.
159. The combination with the supporting frame and 75 means on said frame for supporting continuous lengths of fibrous material of mechanism self acting to separate the material in equal divisible parts.
160. In a filling machine for mattress covers the combination with the supporting frame of a table, means for drawing over said table a length of fibrous material 85 and self acting material separating devices upon said supporting frame.
161. In a filling machine for mattress covers the combination with the receptacle for the filling material of a supporting frame, rollers upon said frame adapted to 90 support continuous lengths of fibrous material and self releasing sliding grasping devices upon the receptacle adapted to draw the material within the receptacle.
162. In a filling machine for mattress covers a supporting frame and a receptacle for the filling material, 95 means upon the said frame for supporting continuous lengths of fibrous material and means self acting to draw the said material within the receptacle and devices on the said frame self acting to separate the material into divisible parts.
163. The combination with the supporting frame of rollers, adapted to support continuous layers of material mounted on said frame, power transmitting shafts on said frame transmitting power to said rollers, a table, means for drawing the material over the table, movable material separating devices adapted to be moved toward said table and mechanism actuated by said devices for controlling the movement of said power transmitting shafts.
164. In a filling machine for mattress covers the combination with the supporting frame of rollers mounted on said frame and adapted to support continuous layers of fibrous material, power operated shafts on said frame transmitting power to and actuating said rollers a table, arms upon said frame, shafts upon said arms actuated by 100 the power operated shafts and movable material separating devices upon said arms movable toward said table and mechanism on said shafts for controlling the movement of the power operated shafts.
165. In a filling machine for mattress covers the combination with the supporting frame of rollers mounted on said frame and adapted to support continuous layers of fibrous material, power operated shafts on said frame transmitting power to and actuating said rollers, a table arms on said frame having slots and sliding shaft bearings in said slots and springs upon which said bearings are yieldingly supported, a rotary shaft mounted in said bearings and material separating devices on said shaft and stud shafts on said bearings, gear on the stud shafts engaging with the gear on the shaft carrying the material separating devices, pinions on the stud shaft and mated gear on the power transmitting devices adapted to engage at intervals with the said pinions.
166. The combination in a filling machine for mattress covers with the receptacle for the material and a supporting frame of an inclined sliding table adapted to be 105 extended within the receptacle, rack bars on said table, a rotary shaft on said frame and cog wheels on said shaft engaging with the rack bars, power transmitting devices connected with and actuating said shaft and raising 110 said table and mechanism on the supporting frame, self acting to release the shaft and lower said table.
167. The combination in a filling machine for mattress covers with the receptacle for the material and a supporting frame of an inclined sliding table adapted to be 115 extended within the receptacle and grooved table guiding plates, rack bars on said table, a rotary shaft in said frame and cog wheels on said shaft engaging with the rack bars, power transmitting shafts on said frame and idle shafts on said frame adapted to carry continuous layers of 120 fibrous material and actuated by the power transmitting shafts and loose and fixed band wheels on said shaft and loose band wheel on the shaft carrying said cog wheels, clutches on said shafts and clutch levers and latch bars on said levers, a bell crank lever on said table, guiding 125 plates and a rod connecting one arm of said lever and one of the power transmitting shafts and a lug on the sliding table adapted to come into contact with one of the arms of the bell crank lever.
168. The combination in a filling machine for mattress 130

- covers with the main frame and the receptacle for the material of an auxiliary frame and an inclined sliding table in said latter frame, means for raising the table in position and self securing devices on the main frame for holding the table in a raised position, a vertically movable hopper on the main frame and mechanism on the main frame actuated on the downward movement of the hopper to release the securing devices to the end gate. 169. The combination with the main frame the forward end rearwardly movable lower carriages and the traveling bench or table connected therewith and with an auxiliary frame, an inclined table guide plates on said frame and a rack shaft, rack bars on said inclined table and cog wheels on said shaft, a ratchet wheel on said shaft and a pawl on said auxiliary frame devices on said frame connected with and raising said pawl, a hook on said table and devices on the said auxiliary frame in the path of said hook actuating the pawl raising devices in the rearward movement of said carriages. 170. The combination in a filling machine for mattress covers with the main frame and the main driving shaft and the receptacle for the material within said frame of an auxiliary frame and power transmitting shafts therein, means connected with the said shafts for supporting and feeding continuous layers of fibrous material within the receptacle, a power shaft on the main frame and power transmitting devices connected therewith and said main driving shaft and power connecting and disconnecting devices on the main shaft and mechanism on the auxiliary frame actuated by the power transmitting devices to the material feeding means connected with and actuating the power connecting devices on the main shaft. 171. The combination with the main frame, the main driving shaft and the receptacle for the material and the sliding grasping devices thereon and with the winding shaft of winding devices connected with the sliding grasping devices, power transmitting means connected with the main and winding shafts and power connecting and disconnecting devices on said main shaft, an auxiliary frame and mechanism thereon for feeding continuous layers of material within the receptacle and controlling the power connecting devices on the main driving shaft. 172. In a filling machine for mattress covers the combination with the receptacle for the filling material of draft devices for drawing lengths of fibrous material within the receptacle, a chute and means for discharging mattress filling material from the chute upon the fibrous material during its passage within the receptacle. 173. In a filling machine for mattress covers the combination with the main frame and the receptacle for the material of a power actuated shaft on said frame sliding grasping devices on the receptacle for the fibrous layers and draft devices on said shaft connected with the sliding devices on the receptacle and material conveying devices actuated by said shaft. 174. In a filling machine for mattress covers the combination with the receptacle for the material and with means for drawing layers of fibrous material within the receptacle of means for discharging fine mattress filling material upon the layers. 175. In a filling machine for mattress covers the combination with the receptacle for the material with the means for feeding layers of fibrous material within the receptacle of means for discharging fine mattress filling material upon the layers in its passage. 176. In a filling machine for mattress covers the combination with the receptacle for the material and with draft devices for drawing lengths of fibrous material within the said receptacle, of means for supporting continuous lengths of the said material, devices for separating the material into divisible parts and means for discharging fine mattress filling material upon the fibrous material in its passage. 177. In a filling machine for mattress covers the combination with the main frame and the receptacle for the material of an auxiliary frame, a vertically movable hopper on the main frame, means on the auxiliary frame for supporting and feeding layers of fibrous material to the receptacle, a main power shaft on the main frame, power transmitting shafts in said auxiliary frame actuating the material feeding means and mechanism on the main frame and auxiliary frame actuated by the hopper in its downward movement to communicate power from the main shaft to the power transmitting shafts on the auxiliary frame. 178. In a filling machine for mattress covers the combination with the main frame and the main driving shaft and the receptacle for the material of an auxiliary frame, rollers thereon adapted to support continuous lengths of fibrous material, power transmitting shafts on said latter frame and means actuated by said shaft for communicating motion to and feeding the said material to the receptacle, power transmitting devices connected with the main driving shaft and the power transmitting shafts, loose band wheels in the said shafts and clutches on said shafts and clutch operating levers, a vertically movable hopper on the main frame and transverse bars supporting said hopper and a rod connected with one of said bars, bell crank lever on the auxiliary frame and connecting devices connecting said levers with the clutch operating lever and bell crank lever on the main frame in the path of and actuated by the rod on the hopper supporting bar in its downward movement and connecting devices connecting said bell crank lever on the main frame with the bell crank levers on the auxiliary frame. 179. The combination in a filling machine for mattress covers with the main frame of a chute on said frame having laterally extensible parts, an adjusting rod on said chute having screw threaded lugs and screw threads on said parts within which said rod extends. 180. In a filling machine for mattress covers the combination with the main frame and with the receptacle for the material of a hopper, discharging means on the hopper for discharging a quantity of material into the receptacle and a pipe leading to the hopper and a material discharging apparatus for discharging the quantity of material into the hopper. 181. In a filling machine for mattress covers the combination with the main frame and with the receptacle for the material of a hopper, a conduit leading to the hopper and a movable table supporting the mattress filling material and an air suction and blast apparatus connected with the conduit. 182. In a filling machine for mattress covers the combination with the main frame and the receptacle for the material of draft devices acting to draw layers of fibrous material within the receptacle, a chute for discharging fine filling material upon the layers of fibrous material, a pipe leading to the chute and an air suction and blast apparatus connected with the pipe. 183. The combination in a mattress filling machine with the main frame, the main driving shaft, the receptacle for the material and sliding grasping devices on the receptacle for grasping layers of fibrous material, of a power driven shaft on the main frame and power transmitting devices connected therewith and with the main driving shaft draft devices on the driven shaft connected with the material grasping devices, a chute on the main frame and pipes for conveying filling material to the chute and an air suction and blast fan and a fan shaft on the said pipe and power transmitting devices on said latter shaft connected with the power driven shaft actuating the layer grasping devices. 184. The combination with the main frame the receptacle for the mattress filling material and the hopper upon said frame of a pipe conveying material to said hopper and suction and blast fan in said pipe and a fan shaft, an operating shaft on said main frame and power transmitting devices connected therewith and said fan shaft, an endless traveling apron and a shaft operating said apron and power transmitting devices connected therewith and the shaft operating said fan shaft. 145
